UNITED STATES PATENT OFFICE.

ALEXANDER DOW, OF NEW YORK, N. Y., ASSIGNOR TO DOW COMPOSING
MACHINE COMPANY OF NEW YORK.

TYPE SETTING AND JUSTIFYING MACHINE AND THE ART RELATING THERETO.

No. 833,955.

Specification of Letters Patent.

Patented Oct. 23, 1906.

Application filed March 31, 1900. Serial No. 10,949.

To all whom it may concern:

Be it known that I, ALEXANDER Dow, engineer, a citizen of the United States of America, and a resident of Park Row Building, city of New York, State of New York, have invented certain new and useful Improvements 5 in Type Setting and Justifying Machines, of which the following is a specification.

My invention relates to a machine for setting and justifying movable printers' types for use in all branches of the art of printing. While it is in the broadest sense a single organism controlled by the manipulation of selecting-keys alone and mechanism set 10 thereby to perform harmoniously and automatically all those operations necessary to the perfect composition and justification of lines of type of any desired length, yet there are many parts of my justifying apparatus which I consider broadly new and which are capable of 15 use either by themselves or in connection with other mechanisms for setting or justifying type.

My machine embraces means for selecting 20 and assembling individual types into lines, automatically justifying the lines to a uniform length, and composing these justified lines into columns and pages, the only manual act performed being the manipulation of 25 the keyboard.

The type-setting machine which is described in this application is the subject of 30 Patent No. 637,858, granted to me November 28, 1899. The type-setter, however, will be described in this application to some extent, 35 because its operations control the operations of the justifier, and the line must first be set before it is justified, and the operations are continuous and the combinations 40 are correlative. The justifying mechanism which is the subject of this application may, however, be adapted for use and may be used to justify lines of type set by any type-assembling mechanism in which the 45 lines of type can be delivered from the setter into a suitable raceway arranged in operative relation to the justifier.

In my machine the type-setter sets a line 50 of type consisting of any desired number of words and introduces after each word a space of uniform size, which in the further description of the machine will be called a "false space," because it is used only temporarily to separate the words, being subse- 55

moved and replaced by a permanent space. 55 After the line of type has been composed containing words and false spaces of uniform size its length is automatically measured and compared with the standard length of line desired. It will be observed that inasmuch 60 as the line contains a given number of false spaces of uniform width the actual length of the line will be its measured length with the false spaces in less the aggregate of those false spaces, and in determining the 65 length of a line it is only necessary to know the actual measurement of the line with the false spaces in and the number of the false spaces to know the actual length of the line without the false spaces. This calculation 70 is one which is automatically made by the machine, and the constant of the false spaces is automatically provided for. The difference in length between the actual length of the line after the false spaces have been deducted and the standard length of the line 75 desired I will designate as the "gap." The amount of this gap must be distributed between the words in the line in order to justify the line—that is to say, it must be divided up 80 into as many parts as there are words in the line less one, and a space equal to one of these parts or one of a series of spaces, the aggregate of which series is equal to the gap be inserted between all the words in the line in order 85 to bring the line to a standard length. The distances between words will hereinafter be called "word-spaces." It is very desirable that the line should be spaced with regular 90 foundry-made spaces as distinguished from spaces which are manufactured by the justifying-machine itself in the process of justification. Such foundry-made spaces are employed in my machine, and they will be frequently referred to in the specification and 95 claims as "true spaces." However, many parts of my machine could well be used in machines which manufacture their own spaces. The division of the gap by the number of word-spaces in the line gives as a quotient the size of a space which will exactly 100 justify the line if one of said spaces is inserted in each word-space in the line. Such a space may conveniently be called an "ideal space." If a machine is supplied with true spaces of 105 the exact size of what is found to be the ideal space for any given line, all that it is necessary to do to justify the line is to supply one of said

spaces to each word-space in said line. If, however, the machine is not supplied with this exact size of space, it becomes necessary to select and supply to the line a combination of spaces of the two sizes which most nearly approach the size of the ideal space, selecting the proper number of each sized space, so that the total number of spaces supplied to the line, which is always equal to the number of word-spaces in the line, will justify the line.

The problem of justification may be described as follows: In lines of type composed of a variable number of words whose length are indefinitely variable to insert spaces of proper thicknesses to cause all the lines so spaced to be of uniform length. The purpose of my justifying-machine is to measure the length of the gap and divide it into a number of parts equal to the number of word-spaces in the line, then working from the result so obtained to select true spaces, either of equal size or two sizes approximating one another, of a number equal to the number of word-spaces in the line and to select, if it is necessary to select spaces of two sizes, the proper number of each of these two sizes to justify the line. In the justification of type there are two elements which enter into the problem, one is that the line of type possesses a certain amount of elasticity and the second is that the conformation of the letters and imperfection of human vision make it impossible for the eye to perceive minute differences of space between words. Spaces, therefore, of varying thickness may be used for justification, and the aggregate of these spaces may be less than the actual gap by an amount equal to the elasticity of the line. In an average line of from seven to twelve words the elasticity of the line will amount to about .010". The aggregate of the spaces inserted, therefore, may be .010" greater than the gap as originally measured—that is to say, the gap when originally measured is measured with a certain pressure on the line. If this pressure be increased, the line may be compressed to an extent equal to about .010". .010" is, however, about the limit of elasticity, and it is not safe to count upon a greater degree of elasticity. Hence in calculating the space to be used for justifying a line of ten or twelve words .010" is as great a variation as can be permitted. If it is desired to justify lines with spaces of equal width, it is possible to construct a machine on my principle which will do it; but it will require that the spaces shall vary from one another by a very small dimension, such as .001". If the maximum variation between line and standard which can be taken care of through the elasticity of the line be .010", then uniform spaces must be used, the thickness of which when multiplied by the number of word-spaces in the line will not vary

from the gap more than .010". If standard line measures x and the actual line set measures $x + y$ and the number of word-spaces be ten, then $y \div 10$ will equal the width of the spaces to be used. If the spaces available for use be as follows

$$\begin{aligned} .050" \times 10 &= .500" \\ .051" \times 10 &= .510" \\ .052" \times 10 &= .520" \\ .053" \times 10 &= .530" \end{aligned}$$

75

it will be seen that the spaces differing by .001" in an eleven-word line will when added together vary from one another by an amount equal to the full limit of elasticity of a line. 80 Therefore in order to justify lines with spaces all of one size when the size of an ideal space for any line may be anywhere between .030" to .080", the total range of variation being .050", fifty sets of spaces must be provided, 85 each one differing from its adjacent space by .001". Fifty sets of spaces would require a large machine with a wide range of movement, which would involve high cost and complication. I have found, however, that the 90 number of sets of spaces can be greatly reduced and all lines practically justified and the machine simplified by using only ten series of spaces which differ from one another in width by .005" or any other suitable 95 arbitrary increment and selecting a certain number from each of any two adjacent series of spaces, which when added together will justify the line. Thus, for example, if the gap equals .472" and the number of word-spaces be nine the size of the ideal space to justify this space would be $.472 \div 9 = .052"$ approximately. If now the spaces available for use in the machine are .030", .035", .040", .045", $.050" \times 9 = .450"$, $.055" \times 9 = .495"$, 100 .060", .065", .070", .075", the two sizes of spaces which are nearest the size of the ideal space are .050" and .055". Multiplying each of these by nine gives .450" and .495". Nine spaces of either size, therefore, will not come 105 near enough to just filling the gap to be within the limit of elasticity. Hence we cannot use all spaces of the same size, but must select two spaces differing from one another in size and use a proper number of each to justify the line. If we take

$$\begin{aligned} 4 \times .050" &= .200" \\ 5 \times .055" &= .275" \end{aligned}$$

110
.475"

120

we will have a series of nine spaces, the aggregate of which will be within the limit of elasticity of .472" and will justify the line.

The examples just given clearly exhibit 125 the fact that the selection of the proper combination of spaces for any line can be determined by two distinct operations. First, the determination of the thickness of a uniform ideal space which would justify the line 130

when inserted between all the words; second, the determination of what combination of two adjacent sizes of spaces, if necessary, varying from one another in thickness by a suitable increment—as, for instance, .005"—will approximately aggregate in thickness the same amount as would the total number of the uniform or ideal spaces. The first operation is evidently one of plain division, which is accomplished by me through the agency of what I call the "justifying" or "dividing" plates. Though I am aware that there are other ways of accomplishing this result, and I therefore do not wish to be limited to the use of dividing-plates, as certain important features of my invention could be employed in connection with other means for dividing the gap, I do, however, consider the construction, combination, and correlation of my dividing-plates to be broadly new, and I consider them and the combination of them with other features of my machine to be important parts of my invention. The second is an operation of averaging, and the final selection of the proper combination of spaces depends upon the movement of what I call the "averaging" mechanism. This averaging mechanism is, as far as I am aware, broadly new, and it is an important feature of my invention when considered as a piece of mechanism by itself or when combined with other parts of my machine.

In considering the first operation of justification, involving the division, of the gap into a definite number of equal parts, it may be considered an operation of pure division to be effected mechanically.

The law governing the action of the justifying or dividing plates may be stated as follows: Having selected a plate of any one arbitrary inclination, which we call the "unit" inclination or tangent of the unit-plate, and having inserted this unit-plate into a given gap, it is obvious that its forward movement from a zero starting-point to its point of contact with the walls of the gap would be proportionate to the width of the gap and dependent upon the inclination of the plate. This forward movement may be caused to indicate upon some prearranged scale the width of a space adapted to exactly fill this particular gap or to automatically select or eject or actuate mechanism for selecting or ejecting some space that would fill this gap. In the same manner if the gap was to be occupied by two spaces it must be divided into two equal parts, and by selecting a plate having an inclination or a tangent twice as great as the tangent of the first or unit plate the act of inserting it into the same gap would cause it to advance but one-half the distance of the first plate, and on the same prearranged scale it would indicate that a space of one-half the thickness was to be inserted in the two positions. In a like manner a triang-

lar or inclined plate having a tangent three times the tangent of the unit-plate would serve to exactly divide the gap into three equal parts. A triangle four times the inclination of the unit-plate would serve to divide the gap into four equal parts, and so on, by plates of proper proportions the gap can be divided into any number of equal parts. It therefore follows that if a series of such triangles or inclined plates were arranged in a group in any manner such that the selection of a plate for dividing the gap into a particular number of parts was mechanically or automatically made and this plate caused to advance, filling the gap, its forward movement from a fixed zero position would be an absolute indication in a proportionate scale of the thickness of a series of spaces of equal width necessary to aggregate the width of this gap. I have herein described these triangles as inclined plates, for the reason that in practice I deem such construction practical and convenient; but it is obvious that other applications of this principle might be used. Other constructions are no doubt possible, and I do not, therefore, limit myself to the use of plates, recognizing that special conditions might make some constructions more desirable than others.

I next proceed to a description of the principle according to which special and auxiliary mechanism controlled and brought to a primary setting by the action of the dividing-plates just described is capable of determining what proportion of two different sizes of spaces varying by any arbitrary increment must be selected to fill a certain gap and to cause the same to be ejected between the words of lines of type undergoing justification. I will first consider the abstract principle as applied to the determination of quantities without reference specifically to the matter of spacing type, and will then point out in what manner this principle is applied and embodied in automatic mechanism for this special purpose. Let us assume an arbitrary scale, the graduations of which are equal distances apart and of any convenient magnitude—say, for instance, for purposes of illustration, one-tenth of an inch, starting from zero and reading one, two, three, &c., through whatever range may be adaptable for the purpose in hand. Now suppose some quantity—say A, Fig. 95—has been divided into—say X—equal parts and the quotient resulting from this equal division be indicated by a pointer taking up a certain position on this scale. Let us assume that this quotient is, say, thirty-seven and indicates that a series of measures X in number and containing thirty-seven units of any nature whatever would together amount to the quantity A. Assuming, further, that we have no measures containing quantities between, for instance, thirty, thirty-five, and forty units, it

is obvious that a series of measures containing thirty-five units and a series of measures containing forty units in a certain proportion and together amounting to X in number could be so selected that the total number of units in the two series would approximate closely to the total units represented by X measures of thirty-seven units each. The selection for this purpose of a proper proportion of each size of measure is determinable through a mathematical law and can be indicated in the following manner: Let us assume a secondary scale whose total length, to satisfy the case above mentioned, is equal to five of the unit-divisions above—i. e., its total length must be equal the distance on the first scale from one graduation representing a measure which we have, say thirty-five, to the next graduation representing a measure which we have, say forty, which in this particular case is five units of the first scale, but which might vary in different cases. Let this total length be graduated into equal parts X in number and let us place one end of this scale in coincidence with the graduation marked "37" of the scale above. It will then be in a position as indicated in the diagram marked Fig. 96. It will then be obvious that a certain number of the divisions of this secondary scale will rest between the graduations of the first scale marked "35" and "40," and a certain number of the divisions of the secondary scale will rest between graduation "40" and "45." It can be then shown by the help of a mathematical demonstration hereinafter given that the number of divisions of this secondary scale embraced between "35" and "40" of the first scale will be the correct number of measures containing thirty-five units, and the number of divisions embraced between the graduation "40" and "45" of the first scale will be the correct number of measures containing forty units, which when added together will aggregate the nearest possible amount to the original quantity A , which could be summed up by the use of two measures of different sizes and containing a number of units varying by some fixed quantity. It is obvious that these units herein mentioned can refer to quantities of any sort, measures of length, measures of volume, weight, coinage, or anything else. As applied in this machine, however, it determines the combination of spaces of two sizes varying by any increment whatever that will aggregate the nearest possible to the width of the gap previously referred to in the justification of lines of type.

As applied to my machine for the purpose of justifying type the graduations "35," "40," "45," &c., of the primary scale represent the boundaries of zones in which the space-selecting device operates. As long as the space-selecting device operates in one zone it will supply the line with spaces of the

size, and when it passes into the next zone it will supply spaces of the next size. The divisions of the secondary scale represent the number of space-supplying operations of the space-selecting device for any line, and the 70 number of such divisions which fall in one zone of the primary scale represent the number of spaces of one size to be supplied to the line, while the number of said divisions which fall in the next zone represent the number of 75 spaces of the next size to be supplied to the line, the total number of spaces supplied to the line being equal to the number of word-spaces in the line, and the total width of said spaces being sufficient to justify the line. It 80 is obvious that in practice a zone boundary of the primary scale is apt to fall at some point, between graduations of the secondary scale, in which case the number of the thinner spaces is indicated by the graduation of the secondary scale nearest to the zone boundary of the primary scale, the balance of the graduations representing the thicker spaces, as before, and any error introduced by this variation from a theoretical result would be less than the limit 85 of elasticity, and hence not affect the result.

In the above description I have pointed out the manner in which the divisions of the secondary scale would indicate the proportion of thinner and thicker spaces that would 95 be required for justifying any given line of type, and I propose now to describe, briefly, the mechanical means by which spaces are automatically ejected from their cases in the same proportion as would be indicated by 100 the divisions of this secondary scale, were such a scale actually employed and read.

In the machine a series of space-magazines are arranged side by side, each magazine being provided with a space-forcer. A 105 space-ejector carriage is mounted on a way so as to travel on a line parallel to the line of magazines and pass from the zone of one to the zone of the other. The zone of a magazine is the distance from where the space-ejector can begin to eject spaces from that magazine to the point where as it travels it will cease to do so. The zones of all the magazines are of equal width, and each zone may be likened to one of the grand divisions 110 of the primary scale. The space-ejector carriage is given a primary setting in its ways, assuming a certain position in the zone of one of the space-magazines. Then the carriage is caused to travel by a series of equal steps on 115 its way a distance equal to the length of the secondary scale, which is equal in length to the zone of a space-magazine, and the number of steps which it takes is equal to the number of divisions on the secondary scale, 120 and it is equal to the number of spaces to be ejected. At each step the space-ejector is caused to eject a space from the magazine within the zone of which it happens to be, 125 and the number of each size of space which 130

will be ejected when the space-ejector operates in two zones will be equal to the number of steps taken in each zone, moving from thinner to thicker spaces.

5 From the foregoing statement of the laws governing the automatic justification of type it will be understood that in practice I employ a small number of sizes of spaces—say ten in number—which differ from one another 10 by a comparatively large dimension—say .005—and when necessary select a proper number of each of two adjacent sizes which will aggregate a thickness either exactly equal to the gap or near enough to it to be within 15 the limit of elasticity.

If the space-ejector carriage be so connected to the dividing-plates as to be moved by them proportionally to their longitudinal motion and to any desired extent and the 20 total operative range of motion of the space-ejector carriage be divided into a number of equal parts, equal to the number of sizes of spaces with which the machine is provided—say ten—and a series of ten spaces carrying 25 magazines, each containing spaces differing by .005" in order be located one opposite each of said divisions, so that the zone of each magazine shall correspond to one of said divisions and the space-ejector carriage 30 be given a primary setting on its way by the dividing-plates and the space-ejector carriage after being set be moved from the direction of the thinner toward the thicker spaces a distance equal to the zone of a space- 35 magazine and by a number of steps of equal length and equal in number to the number of spaces to be ejected and a space be ejected at each step from the space-magazine within the zone of which the space-ejector happens 40 to be then the spaces ejected, whether from one space-magazine or two adjacent ones, will justify the line. The operation lies in giving to the ejector-carriage automatically its primary setting, this primary setting being determined by the width of the gap and 45 the number of word-spaces in the line, and then giving to the carriage a step-by-step motion from its position of primary setting toward the thicker spaces a number of steps 50 equal to the number of spaces to be ejected, the total distance covered by such step-by-step motion being always equal to the width of a magazine zone.

Referring to the drawings, in which the 55 same characters of reference indicate the same parts throughout the entire specification, Figure 1 is a front elevation of the justifying end of the machine, the ends of some of the parts being broken off. Fig. 1^a is a similar view of the setting end of the machine, certain of the parts being also broken off. Fig. 2 is a plan view of the mechanism shown in Fig. 1, and Fig. 2^a is a plan view of the mechanism shown in Fig. 1^a. Figs. 1 and 1^a and 60 2 and 2^a put together, respectively show a

front elevation and a plan of the entire machine. Fig. 3 is an end elevation of the right-hand side of the type-setter, the upper portion of the type-cases and their frames, together with the upper portion of the device 70 for reciprocating the type-forcers being broken away. Fig. 4 is a detail showing the connections of the justifier-starting key with the main line clutch and shaft. Fig. 5 is a transverse vertical section of the type-setter, 75 showing the justifier-starting key and its connection to the main line clutch and shaft and the type-depressor bar and its operative mechanisms. Fig. 6 is a horizontal section of a detail of the type-depressor bar and its 80 guide. Fig. 7 is a full-sized front elevation of the pivoted stick. Fig. 8 is a vertical transverse section similar to Fig. 5, but showing in detail the type-setting keys and operative mechanism therefor and also the space-key and its operative mechanism. Fig. 9 is a plan of a part of the keyboard and space-key, showing the connections of the space-key with the mechanism for locking the space-key when a desired number of types 90 have been set and released again upon the operation of the justifier. Fig. 10 is a detail plan of the cam and operating mechanism for communicating the motion of the space-key to the justifying mechanism. Fig. 95 11 is an enlarged detail of the space-pin operated by the cam. Fig. 12 is an enlarged detail of the pin in operative position when ejected. Fig. 13 is a detail view of the mechanism for operating the pivoted stick, showing part of the setter in horizontal section. Fig. 14 is an enlarged detail, partly in vertical section and partly full elevation, of the cam and lever mechanism by which the pivoted stick is operated. Fig. 15 is a vertical 100 section to the left of the setter, showing in full elevation the mechanism and its connections with the line-shaft and cam for moving the line-carrier through the line-raceway. Fig. 16 is a rear elevation of the segmental 100 gears and the connection by which power is communicated from the driving mechanism to the line-carrier arm. Fig. 17 is a detail of the segmental gear. Fig. 17^a is a detail view showing the line-carrier and line-raceway in 115 traverse section and its connection to the line-carrier arm. Fig. 18 is a detail of the connection between the line-carrier arm and the line-carrier, showing the carrier and the line-raceway in vertical transverse section. 120 Fig. 19 is a plan of the line-carrier, the connection of the line-carrier arm being in section. Fig. 20 is a vertical longitudinal section of the line-carrier. Fig. 21 is an enlarged detail view, partly in section, of the 125 pivoted stick, the line-raceway and the caliper mechanism with its connections. Fig. 22 is a vertical longitudinal section of the line-carrier, showing its dog and the line-pusher. Figs. 23 and 24 are details of the 130

8 mouth of the stick, showing devices for maintaining pressure upon the type as they enter the stick from the type-raceway. Fig. 25 is a front elevation of a portion of the line-race-
 5 way, showing the position of the line-carrier arm and line of type when approaching the word-separating mechanism. Fig. 26 is a detail view, partly in vertical longitudinal section, of the word-raceway, showing friction-plates in the upper raceway. Fig. 27 shows the same parts in a slightly-advanced position and having a part of the front of the machine broken away to show the connection of the auxiliary line-pushing device, which
 10 operates to push the line forward to the word-separator after the line-carrier has reached the limit of its motion. Fig. 28 is a vertical longitudinal section of a portion of the line-ways and of the wards by which the line is checked in its forward motion by each false
 15 space and held that each word may be separated by the word-separating mechanism. Fig. 29 is a perspective view of the lower line-raceway in enlarged size, showing the wards in position and the lifting-table and
 20 type approaching the wards. Fig. 30 is a perspective view of the specially-nicked type used in the machine, showing ward-nicks to permit its passing over the wards. The false
 25 spaces shown in Fig. 28 not having these nicks will be stopped by the wards until lifted over them by the word-lifter. Fig. 31 is a vertical elevation of the same portion of the raceway shown in Figs. 25 and 27 with the line advanced almost to its extreme
 30 limit by the auxiliary pushing device, one word lifted above the wards and showing the ward by which the line is stopped for the separation of a word. Fig. 32 is an enlarged
 35 detail, in vertical longitudinal section, of the word-lifting table by which the line is separated into words, also of the word-friction plate and auxiliary line-pusher and type in position, a word having been separated.
 40 Fig. 33 is a detail of the word-forcer in the act of moving a word from the word-separating mechanism through the word-raceway to the galley. Fig. 34 is a vertical transverse section of the word-forcer and lineway and lift-
 45 ing-table in the position of Fig. 33. Fig. 35 is an underneath view of a portion of the upper wordway and word-forcer and also of the end of the auxiliary line-pusher. Fig. 36 is a plan view of the dividing mechanism in
 50 its position while the line is being composed or has just been composed and before the justifying mechanism is set in operation, with its actuating mechanism for stepping up under the influence of the spacing-key and
 55 also the actuating mechanism for moving it forward, so as to give it and the space-ejector carriage a primary setting. Fig. 37 shows the same parts in their relative positions after the line has been completed and measured
 60 and the justifying has begun and the divid-
 65

ing mechanism has moved forward and taken a position determined by the width of the gap and the number of spaces to be inserted in the line and has given the space-ejector carriage a corresponding primary setting. Fig. 38 is a horizontal longitudinal section of the dividing-plate carriage and mechanism for raising and lowering it and also for permitting its lateral motion. Fig. 39 is a vertical longitudinal section of the same. Fig. 40 is a transverse section through the dividing-
 70 plates and their carriage, showing the rack by which it is given a vertical motion. Fig. 41 is a detail, partly in section, of the splined pinion and their shaft, by which the driving-plate carriage is raised and lowered and allowed a lateral motion under the influence of its actuating mechanism. Fig. 42 is a vertical transverse section of the dividing mechanism. Fig. 43 is a transverse section of the machine, showing the dividing mechanism and the actuating device by which it is moved forward and backward and also the device for raising and lowering the caliper mechanism. Fig. 44 is a plan of the device for actuating the caliper-head vertically. Fig. 45 is a vertical section of the caliper-head and lineways in full size. Fig. 46 is a side elevation of the device for actuating the caliper-head vertically. Fig. 47 is an enlarged view of a vertical transverse section of the caliper-head and lineways and a portion of the mechanism for its vertical adjustment. Fig. 48 is a vertical transverse section of the line-raceway and caliper-head, shown in side elevation in Fig. 21, the actuating mechanism for which is shown in full elevation in Fig. 46. Fig. 49 is a vertical transverse section of the machine, taken on a plan between the dividing and averaging mechanism and parts beyond it in full elevation. Fig. 50 is a view identical with Fig. 49, except that the parts are shown in the primary position for setting. Fig. 51 is a plan of Fig. 50. Fig. 52 is a transverse section through the averaging-cams, showing the device by which the motion of the averaging-cam carriage is limited by the averaging-cam stop. Fig. 52^a is a side elevation of the averaging-cam, showing in dotted lines the first three cams of the series, which are omitted in the practical construction of the machine. Fig. 52^b is an end elevation of the averaging-cams as they are used in the machine. Fig. 53 is a detail of the lever and cam by which the space-ejector cam is thrown out of connection with the word-shaft at a desired period. Fig. 54 is a front elevation, partly in section, of the averaging mechanism and the device for stepping forward the space-ejector carriage a predetermined number of steps. It also shows the connection of the device by which the carriage is given its primary setting. Fig. 55 is a vertical transverse section of the space-ejector carriage and its supporting devices,

showing the device for returning it to its primary position and for returning the ejector-rods to their normal position and locking the carriage between its steps. Fig. 56 is a plan 5 of the same part of the machine shown in Fig. 55, showing friction-clutch and locking mechanism of the carriage. Fig. 57 is a vertical transverse section of the machine just beyond the section shown in Fig. 56, showing 10 the cam and levers for operating the false-space-extractor mechanism and the galley-operating mechanism. Figs. 58, 59, 60, 61, 62, and 63 are full-sized detail plan views of 15 successive positions occupied by the device in performing the various functions which it has to perform. Figs. 64 and 65 are plan views of the mechanism by which the false-space extractor is made to perform the motions shown in Figs. 58 to 63, the side elevation 20 of which is shown in Figs. 57, 64, and 65, also showing the galley-depressing mechanism. Fig. 66 is a front elevation, partly in section, of a part of the galley, showing the type- 25 support plate and the type-depressor and device for holding the type in proper position when introduced into the galley. Fig. 67 is a similar view of the same part in full front elevation with a part broken away to show 30 the friction device of the galley, the type-depressor being depressed. Fig. 68 is a vertical section of the galley, type-support plate, and type-depressor, and indicates the connections of the support-plate-operating mechanism. Fig. 69 is a similar view of the same 35 parts with the addition of the operative mechanism of the type-depressor of the galley. Fig. 70 is a vertical longitudinal section of the end of the word-raceway, showing the 40 last friction-plate, which acts as a locking-dog and which falls behind the type which has been pushed into the galley and prevents their being pushed out of the galley by the galley-follower. Fig. 71 is a vertical trans- 45 verse section of a space-channel, showing the spaces in position and the relation of the channels to the ejector mechanism. Fig. 72 is a front elevation of the space-channels, partly in section at the lower ends, showing 50 the bend of the channels to deliver the types in the raceway upon their edges. Fig. 73 is a transverse section of the space-channels. Fig. 74 is a side elevation looking at the machine from the left side, showing the driving- 55 wheel and shaft and the train of gears which are connected to the driving-shaft for driving the word-shaft. Fig. 75 shows the connection of the main driving-shaft with the word-shaft by a train of gears and also a friction- 60 clutch on the main driving-shaft, which connects it with the word-shaft. Fig. 76 is a sectional detail of the friction-clutch on the driving-shaft. Fig. 77 is a plan view, partly 65 in horizontal section and with part of the mechanism removed, of the word-shaft and

its connections and the index mechanism and its connections. Fig. 78 is an enlarged horizontal section of the index mechanism, showing its connections with the main line-shaft. Fig. 79 shows a part of the same structure 70 shown in Fig. 78 with the addition of a locking device for locking the ratchets of the index mechanism. Fig. 80 is a vertical elevation of the index mechanism looking at it from the right-hand side. Fig. 81 is an enlarged plan view of the index mechanism and word-shaft, practically the same parts as are shown in Fig. 77, but differently illustrated, some being in full lines and some in section. Fig. 82 is an enlarged view of the same parts 80 shown in Fig. 80 with some omissions and some parts differently illustrated and showing the series of lever connections by which the motion of the space-key is communicated to the index mechanism. Fig. 83 is a plan 85 view of the space-ejector mechanism, the space-channels being shown in section and many of the connecting parts being omitted for the purpose of clearness. Fig. 84 is a bottom view of the pivoted forcer of the space-ejector carriage. Fig. 85 is a front elevation 90 of the device by which the justifier-starting key is locked while the previous line is being justified. Fig. 86 is a plan of the connections of the justifier-key with the main line-shaft. 95 Fig. 87 is a sectional view of the main line-shaft and clutch and the connections of the justifying-key therewith. Fig. 88 is a side elevation of the locking device and its relation to the justifier's key. Fig. 89 shows the 100 position of the locking device and its connection to the galley-follower, the follower being at the edge of the galley, the line being completely justified. Fig. 90 shows the same 105 parts while the line is in process of justification and the follower is in the galley. Fig. 91 is a diagrammatic view of the parts of the machine by which the length of the line is measured and divided into a number of parts equal to the number of spaces to be inserted 110 to justify it and by which the space-ejector carriage is given its primary setting. It also shows in detail the space-ejectors and the means by which the space-ejector is caused to eject spaces of the same or varying thicknesses. 115 Its position in this figure is the one in which it will eject uniform spaces of the same number and thickness as the false spaces inserted while setting. Fig. 92 is an identical diagrammatic view to that of Fig. 91, but 120 showing the parts in a different position, justifying a line differing in length from the standard. Fig. 93 is a diagram and table by which the thickness of the ideal space to justify any line may be determined by the 125 use of a simple formula therein given. Fig. 94 is a detail of the gage-block and a portion of a dividing-plate, showing the manner in which the dividing-plates are constructed to adapt them to use with a broad-faced block 130

rather than a point. Fig. 95 is a diagram of a scale divided into an equal number of parts. Fig. 96 is a diagram similar to Fig. 95 with an additional scale equal in length to one of the 5 grand divisions of scale Fig. 95 and divided into an equal number of parts and applied to the first scale at any point.

In describing the machine I shall divide it into a number of parts as independent from 10 one another as possible, so as to simplify, as far as may be, the description.

The setter.—The setter consists of a series of channels or cases mounted parallel to one another in front of the machine and each carrying 15 a series of type, each channel containing the same letter or character. Below these type-channels are a series of horizontally-moving ejector-bars located in position to eject the bottom type from each channel 20 into a raceway; mechanism for operating the ejector-bars when they are brought into operative relation with the operative mechanism; a keyboard consisting of a series of keys, one key for each type character 25 and ejector-bar and mechanism for throwing the ejector-bar by the action of the key into operative relation with the ejector-actuating mechanism; a raceway located longitudinally of the machine and into which the 30 type are ejected by the ejector-bars, a friction-bar which forms one side of the raceway and which rises and falls as thinner or thicker type are ejected into the raceway, the friction-bar being raised by the action of each 35 ejector-bar a distance corresponding to the thickness of the type ejected; a type-assembling frame sweeping back and forth across the raceway and reciprocating constantly, having two type-forcer feet, one at each end 40 of the frame opposite to one another and each of which with the reciprocation of the frame comes to the center of the raceway and to the mouth of the type-receiving channel, which is there located, so that the types 45 ejected into the raceway on either side of the type-receiving channel will be forced to the center and left there; a type-receiving channel or stick located at right angles to the raceway and at its center, and a type-de- 50 pressor having a vertical reciprocating motion into and out of the mouth of the stick to force into it types as they are brought to the center of the raceway by the assembling-frame. The stick is divided into two parts, 55 an upper stationary-part and a lower movable part. The lower movable part is pivoted, and when filled with sufficient type an automatic mechanism of the justifier is set in motion and the stick is turned from a vertical 60 cal to a horizontal position and brought in line with the justifier-raceway and the line of type contained in the stick is pushed out of it into a line-carrier which travels in the justifier-raceway.

65 The main connecting-link between the set-

ter and the justifier is the space-key. Every time the space-key is struck it sets in motion a part of the justifying mechanism, which causes several separate mechanisms of the justifier to be stepped forward one step for 70 each motion of the space-key and to assume positions according to the number of steps taken, which are equal to the number of words in a line, such positions being appropriate for the justification of that particular 75 line. In practice I insert into the line a number of false spaces equal to the number of words—that is to say, one false space in the place where each true space is to be inserted and one more at the end of the line. This 80 causes the various mechanisms controlled by the space-key to take as many steps as there are words in the line. Later I will describe how the space-ejector, although set to eject one more space than required, is made inactive for one step.

Dividing-plates.—The first mechanism which is acted upon by the space-key is the dividing-plates. These plates, as heretofore explained, consist of a series of triangular or 90 inclined plates or surfaces having operative faces inclined to the plane of their movement. I have illustrated these operative faces in the form of plates mounted rigidly one above the other in a frame which is capable of vertical 95 and horizontal motion. In order that the further operation of the machine may be understood, it is necessary that I should here explain in greater detail than has heretofore been done the mathematical formula and the 100 mechanism by which the dividing-plates are constructed and operated.

In order to determine the size of ideal spaces necessary to justify any given line, it is only necessary to know the number of 105 words in the line and the difference in length between the line unspaced and the standard, which for the sake of brevity we have arbitrarily designated the "gap." If now there should be but two words in the line, the thickness of the space needed for justification would be exactly equal to the gap. In order, therefore, to determine the space, it is only necessary to measure the actual length of the gap, and we have the width of the 110 space. For the purpose of the present discussion we will assume that we have an ordinary line of type in an ordinary printer's stick and a series of independent inclined plates all graduated on their surfaces with a 115 scale identical in each case. If now a triangular or inclined plate be selected having an arbitrary inclination or tangent—such, for instance, as one to one hundred—and be inserted into the gap and its point of contact 120 with the type marked on the plate as a primary position, if then the gap be widened—say ".010"—and the plate be pushed into the gap again to contact with the type it would 125 have moved longitudinally one inch, and 130

with each increase in the width of the gap the motion of the plate in entering the gap will be proportional thereto. Hence the plate may be graduated to read not only the 5 distance of its own motion, but also the width of the gap which is proportional to that motion. Thus one inch of travel of the plate means .010" widening of the gap and .1" of travel .001" widening of gap. If, therefore, the surface of the unit-plate be graduated with a scale which will read accurately 10 the width of the gap, the width of space to be used—there being but one needed—will be the reading of the width of gap upon the 15 surface of the plate at its point of contact with the line of type. If now the tangent of the plate be increased from one to one hundred to two to one hundred, the graduation remaining the same, it will be perceived that 20 the plate having a tangent of two to one hundred will enter the same gap only one-half the distance traveled by a plate having a tangent of one to one hundred. If, therefore, the graduation on the surface of the plate be 25 such as to read the actual width of the gap at the point of contact of the plate having a tangent of one to one hundred, the reading opposite the point of contact of the plate having a tangent of two to one hundred will be one-half 30 of the first reading and will indicate the width of each of two spaces which taken together will fill the gap. If, therefore, the line consists of three words and two spaces are to be inserted, these two spaces, each 35 one-half the width of the gap, will justify the line. If now a plate having a tangent of three to one hundred be employed and graduated in identically the same scale as a unit-plate one to one hundred, the third plate will 40 enter the gap one-third the distance entered by the unit-plate, and the reading on the surface of the third plate, of a scale identical to that of the unit-plate, will be one-third of the gap and will be the width of each of the three 45 spaces, which, taken together, will fill the gap and justify the line. This same system may be continued indefinitely. In practice lines seldom occur of less than four or five words and range from that to about twelve 50 words, so that in ordinary practice one set of triangular or inclined plates will be used—eight in number, varying by 1-100—i. e., from four to one hundred to eleven to one hundred—which will serve to justify any 55 line not having more than twelve words nor less than five.

If type be set without spaces, the set line must always be less than standard. Hence the measurement of the gap and the number 60 of words will give all the information necessary to determine the thickness of the ideal space required for justification. In my machine, however, I introduce false spaces of uniform thickness, the action of introducing

which and the spaces themselves are used to 65 perform certain operations in justification.

The thickness of the false space is arbitrarily determined to be about an average space thickness. When a line is set with false spaces in, it will closely approximate standard; but it may be longer or shorter. If longer, the false spaces must be substituted by true spaces somewhat thinner than the false spaces; if shorter, by true spaces somewhat thicker than false spaces. The dividing-plates, therefore, in determining true spaces must be arranged so as to determine ideal spaces thicker or thinner than the false spaces. If the line was always shorter than standard, all the inclined plates might be laid off having their operative faces diverging from the same point; but if the line may be longer or shorter than standard a different construction becomes necessary. When a line is set with any number of words and a corresponding number of false spaces, this line may be exactly of standard length, and this is true for any number of words and false spaces within the whole range of the machine. It will be perceived, therefore, that if the set 80 line with false spaces in be exactly standard true spaces of the same number and thickness must be substituted for the false spaces. Hence for all plates there must be some point at which they will all indicate or control the 85 introduction of spaces of uniform thickness and of the same thickness as the false spaces. This is accomplished by laying off the plates from a point one to one hundred, two to one hundred, three to one hundred, &c., and then 90 extending the lines thus laid off on the opposite side of the point. Thus the relation of the plates is reversed. Plate 3 on one side of the point is wider than plate 2 and narrower than plate 4, while on the other side plate 3 is 95 narrower than plate 2 and wider than plate 4, as illustrated in Figs. 92 and 93. The plates laid off as above described are then mounted in a common support, so that the operative edges of all plates will be in the same vertical 100 line at the point from which they are laid off and at that point all plates will have the same width.

When a line is of exactly standard length, the action of the dividing-plates will be for all 115 numbers of words to introduce true spaces of the same width as false spaces. When the line is shorter than standard, the action of the dividing-plates will be to determine an amount equal to the gap divided by the number 120 of word-spaces in the line and to add to this amount to the width of the false space to determine the true space. If the line be longer than standard, the action of the dividing-plates will be to determine an amount 125 equal to the gap divided by the number of word-spaces and to subtract this amount from the width of the false space to deter-

mine the ideal space. Thus it will be seen that the dividing-plates deal with the actual set line with the false spaces in and add to or subtract from the width of the false space to determine the ideal space.

If the exact reading of the scale of each plate at the point of contact with the type is to be accepted as the exact measurement of the spaces to be used for the justification, it will be necessary to provide a large number of spaces to be used for the purpose of justification, because the width of the spaces indicated by the scale upon the plates will vary very slightly, and in order to have a sufficient range for the selection of spaces of the exact width spaces must be provided which do not vary from one another by a width greater than .001". This range of variation has been demonstrated to be such as to require at least fifty sets of spaces which vary from one another by .001" only. This is too large a number of spaces for practical use, and I have therefore devised a means by which the number may be reduced and equally good justification accomplished.

In practice a series of dividing-plates are secured to a rigid carrier which has a positive vertical and lateral motion, one of these motions being for the purpose of selecting the plate corresponding to the number of word-spaces in the line, the other being for the purpose of moving the selected plate into operative relation to the gage-block. The machine is provided with a mechanism for measuring the length of the line and setting a gage-block correspondingly opposite the ways of the plate-carriage. The guides or ways upon which the dividing-plate carriage travels is a fixed surface. The gage-block is moved by the measuring or caliper device is a movable surface, and when once set by the measurement of the line in a desired position opposite to the ways of the plate-carriage it is by suitable means fixed permanently in position. It takes a position, therefore, corresponding in location with the length of the line measured and establishes a fixed distance between itself and the ways of the plate-carriage. If now the plate-carriage be moved into the space between its ways and the gage-block, it will enter that space a distance dependent upon the particular plate which is opposite the gage-block, and the particular plate which is opposite the gage-block will be dependent upon the number of times the space-key has been struck and the number of steps up which the carriage has taken, bringing the plates one after the other into the horizontal plane of the gage-block. The distance of travel of the plate-carriage into the space between the ways and the gage-block will determine the primary setting of the space-ejector carriage, because the two are positively geared together, and while they move in different directions they move

correspondingly. The positive connections between the dividing-plates and the space-ejector carriage are such that having advanced the space-ejector carriage to its primary setting the dividing-plates can at once return to their zero position without disturbing the setting of the space-ejector carriage and are ready to receive fresh impulses of the space-key when the succeeding line is set.

Averaging mechanism.—In the preamble I have stated the mathematical law which I have discovered and which I have made the basis of that part of my machine which I have called the "averaging mechanism." This law governs the selection of two sizes of spaces differing from one another by, say, .005" or any other arbitrary increment, if two sizes be necessary, and the choice of the requisite number of each of these two sizes to make up the requisite aggregate thickness of space to justify the line. The averaging mechanism is designed for the purpose of causing the space-ejector carriage to step forward from its place of primary setting a distance equal to the width of a space-magazine zone and by a number of steps equal to the number of spaces to be inserted in the line and one additional step, the purpose of which will be hereinafter described. The step-by-step motion of the space-ejector carriage is always from the position of primary setting near any particular space-magazine in a direction toward the next thicker space, and this as the machine is arranged is from left to right. Upon the under side of the space-ejector carriage is a rack which meshes with a pinion upon the shaft of which is a friction-ratchet the pawl for which is mounted upon the end of a lever and capable of any throw which may be given to the lever. The lever is pivoted about its center and under its far end run a series of cams, all mounted upon a transverse shaft and differing in elevation from one another by a calculated amount. The cams and their carriage are mounted so as to have a horizontal transverse motion under the end of the pawl-lever, and the particular cam which happens to be under the pawl-lever will determine the throw of the pawl and the consequent length of the step of the carriage. The space-key of the keyboard is connected by appropriate mechanism with a stop which limits the position of the averaging-cams. As the space-key is struck a number of times equal to the number of words in the line the stop is moved forward one step for each stroke of the space-key, each step being of equal length. When the last step has been taken and the justifier-lever is moved and the justifying apparatus is set in motion, the averaging-cam carriage is by an appropriate mechanism moved forward against the stop and set at a position which will bring under the pawl-lever one or the other of the averaging-cams, which has been

prearranged to correspond with the number of steps which the stop of the averaging-cam mechanism has taken—that is to say, if the stop moves four steps a certain cam will be brought under the pawl-lever; if six or eight steps, the sixth or eighth cam will be brought under the pawl-lever. If now the cam-shaft be revolved a number of times equal to the number of words in the line, the carriage will be made to take a number of steps equal to the number of words in the line. It is therefore a mere matter of measurement to provide a cam on the averaging-shaft which will cause the ejector-carriage to move a distance which multiplied by the number of spaces in the line will be equal to the exact width of a zone of a space-magazine. Thus it will be seen that the altitude of the cam determines the length of the carriage-steps. The number of revolutions of the cam will determine the distance the carriage is to move. It is merely, therefore, a matter of measurement to determine a series of cams which if brought successively under the pawl-lever will cause the carriage to move the same distance when operated an unequal number of times—that is to say, the four-space cam must cause the carriage to make four steps which in the aggregate will be equal to the width of a space-magazine zone. The five-space cam must cause the carriage to take five steps which in the aggregate will be equal to the same distance, and so on, the carriage traveling the same distance in all cases, but in a varying number of steps. In other words, these cams must give to the carriage a number of steps equal to the number of spaces to be justified, the length of the steps being proportional to the reciprocal of the number of such spaces—that is to say, if the machine was constructed so as to justify lines containing but one word-space there would have to be a cam which would move the carriage the width of a zone in one step. If the machine was adapted to justify a line having two spaces, then the two-space cam would have to move the ejector-carriage the width of a zone in two steps. In other words, the two-space cam would have to have one-half the throw of the one-space cam, the third cam for the same reason would have to have one-third the throw of the one-space cam, the four-space cam one-fourth the throw of the one-space cam. In Fig. 52^a I have shown a set of the cams used in the machine and in addition have shown in dotted lines the cams which would be used were the machine constructed to justify for one, two, and three spaces. From the above it will be seen that the set of cams vary in an arithmetical progression from the first or primary cam—that is to say, the primary cam has a unit of throw, the second cam one-half the unit, the third cam one-third of the unit, the fourth cam a one-fourth of the unit, and so on, so that

when the cam corresponding to the number of word-spaces in the line to be justified is in position to actuate the ejector-carriage the cam will give to the ejector-carriage a number of periodic variations equal to the number of spaces to be justified, the length of which variations is proportionate to the reciprocal of the number of spaces to be justified. The manner in which the ejector of the carriage travels out of the zone of one-space magazine and into the zone of another, taking a number of steps in each zone, has been heretofore described. The peculiar mechanism for insuring the accurate selection of a proper number of each of the spaces needed will be hereinafter more fully described. It is illustrated in Figs. 49, 50, 51, 52, 53, 54, and 83, 84.

As has been previously stated, when the line is set it is spaced with false spaces of uniform thickness in all cases, and one more space is added at the end of the line. It is then transferred to a line-carrier and measured, then carried to the other end of the machine, separated into words, the false spaces extracted and true spaces inserted, and the line placed in the galley.

In a subsequent portion of the specification it will appear that the parts which act in unison to justify the lines after they have been set by the space-key and the dividing-plates are the word-separator, the averaging mechanism, the true-space ejector, the word-forcer, by which the word when separated from the rest of the line is carried to the galley, and the false-space extractor. The word-forcer must move as many times as there are words. The true-space ejector must move one less times than the number of words, or as many times as there are true spaces to be inserted in the line. The false-space extractor must move as many times as there are words, because there is one more false space than true spaces, and the averaging-cams, while it is unnecessary for them to turn a greater number of times than the number of spaces, are for convenience geared to the same driving mechanism as the word-forcer, so that they make as many revolutions as the throws of the word-forcer.

In the form of my machine which I have herein described in order to insure the actuation of the word separator and forcer a number of times equal to the number of words and to carry the whole line from the word-separator to the galley it is necessary to actuate the space-key a number of times equal to the number of words and insert not only a false space at each point where a true space is to be inserted, but also to insert one after the line is complete. This last false space is also necessary for the purpose of controlling the last word in the line. This action of the space-key will step up the dividing-plates, the averaging-cam stop, and the index mech-

anism a number of times equal to the number of words in the line. The dividing-plates must be stepped into operative relation to the gage-block only so many times as there are word-spaces in the line. Hence it is caused to make one step before its first plate is brought into operative relation to the gage-block. The averaging-cam stop is stepped forward a number of times equal to the number of words in the line, and the cams are so proportioned that the motion given to the carriage by each revolution of the averaging-cam multiplied by the number of spaces in the line will equal the arbitrarily-determined width of a space-magazine zone.

Later on it will be seen that the driving mechanism by which the word-forcer is actuated is the same by which the averaging-cams are operated, and they are positively geared together, so that the averaging-cams will make the same number of revolutions as the word-forcer—that is, a number equal to the number of words in the line; but the number of spaces must be one less than this number. The ejector-carriage is therefore given a primary setting by the dividing-plates one step beyond the position where it must begin to step for the ejection of spaces, and the ejecting mechanism is temporarily disengaged from the carriage, so that the carriage will take one step without ejecting a space. It will be noticed that the problem presented is to cause the ejector-carriage to move a constantly-variable distance in the aggregate, but a distance in which the aggregate of one less than the total number of steps taken will always be the same distance. This result is accomplished by designing the cams so as to move the carriage the same distance in four, five, six, seven, eight, nine, ten, eleven, or twelve equal steps, the aggregate of which will be equal to the width of a space-magazine zone. Referring to Fig. 91, it will be seen that a line has been set having any number of words containing false spaces which is exactly standard length. To justify this line, it is only necessary to withdraw the false spaces and insert true spaces of the same number and thickness. It will also be seen that this condition may occur for lines of any number of words. Hence the dividing-plates must be arranged so that no matter what plate is in line with the gage-block spaces of the exact thickness of the false spaces will be inserted. A reference to Fig. 91 will show that when the dividing-plates are constructed as heretofore described and mounted in a carriage there will be one point where all plates will be of uniform width, and if these points are arranged in the same vertical line the dividing-plate carriage will occupy the same lateral position, no matter what plate is in the horizontal plane of the gage-block. This point is taken as the zero-point, and everything is laid off from it. The dividing-plate

are set with this point opposite the center of the gage-block and locked there temporarily. The ejector-carriage is then set opposite the magazine carrying true spaces of the same thickness as the false spaces, and in such a position that all of the steps which it may take under the influence of the averaging-cams will be within the zone of that space-magazine—that is, it is set at the beginning of that zone. The number of false spaces in the line has determined the particular plate in contact with the gage-block, and has also caused the averaging-cams to be so set as to give the ejector-carriage a number of steps equal to the number of words; but we have seen that the number of steps which the carriage must take within a distance equal to the width of a space-magazine zone must be equal to the number of word-spaces in the line and not to the number of words. When the number of word-spaces in the line in any particular case is known, the length of each step of the carriage is known, and the carriage may then be set the length of one step back of the first position, where it would begin to eject uniform spaces equal in thickness to the false spaces, and after having been so set it is geared up to the previously-set dividing-plate carriage, so that every forward motion of the dividing-plate carriage will be communicated to the ejector-carriage when they have both been restored to their zero positions. With such an adjustment when the ejector-carriage has been given a primary setting one step beyond the beginning of the zone of the spaces to be ejected the first step given to it by the averaging-cams will be an idle step and will bring it to the point at which it will begin to step for the ejection of spaces. If the line have five words and four spaces and the five-word plate be in contact with the gage-block and the width of a space-magazine zone be one-half an inch, then each of the four steps to be taken will be one-eighth of an inch. If, therefore, the ejector-carriage be set one-eighth of an inch back of the beginning of the zone of the space-magazine from which spaces are to be ejected, its first step will bring it just to the beginning of that zone, and its succeeding four steps will cover the allotted distance. If the line contains six words and five spaces, the length of each step of the carriage must be one-tenth of an inch, and if the carriage be thrown into a position of one-eighth of an inch beyond the primary position for ejecting spaces the first step will not reach the primary position, and instead of ejecting the first space equal to the false space it will eject one .005" less than the false space, and the line will be .005" short. To avoid this error, a line of six words is put in the machine and the ejector-carriage is given a primary setting which, as above described, will throw it one-eighth

of an inch beyond the position for ejecting the first space and then the sixth-word plate, which is laterally adjustable, is forced slightly backward, so as to cause the plate to enter the space between the gage-block and the way a little farther, and hence draw the ejector-carriage up a little nearer to the position for ejecting the first space until the distance of the carriage is one-tenth of an inch beyond that position. This adjustment is made for each plate, and the carriage is thus made to throw one-eighth, one-tenth, one-twelfth, one-fourteenth, one-sixteenth, one-eighteenth, one-twentieth, one twenty-second, one twenty-fourth, one twenty-sixth beyond the point described for primary setting by each plate, so that its first step will bring it to that point. After the plates have been set to give the ejector-carriage its primary setting one step beyond the point where it will begin to eject spaces equal to the false spaces the dividing-plates will automatically set the carriage with the proper oversetting for all lengths of line and all combinations of spaces.

Index mechanism.—The index mechanism is a mechanism which is set by the space-key and controls the word-shaft so as to cause it to revolve a number of times equal to the number of words in the line and to operate the word-lifter, the word-forcer, the auxiliary line-pusher, the averaging-cams, the true-space ejector, and the false-space extractor. Other methods of controlling the revolutions of the word-shaft might well be employed in connection with my machine or with important features of the same, and therefore while I consider my index mechanism an efficient device for this purpose still I do not desire to be limited to the use of such a mechanism.

The index mechanism, like the dividing-plates and the averaging mechanism, is set by the operation of the space-key and is caused to step forward one step for every operation of the space-key. The apparatus is made in duplicate for the reason that while the justifying apparatus is in operation upon a line already set the index mechanism must be simultaneously set by the action of the space-key in setting the succeeding lines—that is to say, the succeeding line is being set while the preceding one is being justified. The apparatus is made double, therefore, and is provided with a shifting mechanism which will throw one or the other side of the mechanism into or out of engagement with the word-shaft, the part which is in engagement with the word-shaft operating to control its motion, while the part which is out of engagement with the word-shaft is stepped forward and set for the succeeding line. When the justifier-lever is moved to begin the justification of a line, the portion of the index mechanism which has already been set by

the operation of the space-key is thrown into engagement with the word-shaft and controls its operations, so as to cause it to make a number of revolutions corresponding to the setting of that portion of the index mechanism with which it is engaged.

Pivoted sticks.—The pivoted stick shown in Figs. 13 and 23 consists of a channel pivoted on the front of the machine in such a position that when its slot is vertical it will be immediately under the center of the type-raceway and will receive types as they are pressed down from the center of the raceway by the type-depressor bar. When the justifier mechanism is operated, the stick is turned upon its pivot and brought into horizontal position in line with the justifier-raceway. The line-pusher bar then advances entering the open end of the stick and pushes the line out of the stick into the line-carrier, which slides in a raceway extending from the position of the caliper mechanism to the position of the word-separating mechanism.

Caliper mechanism.—As the line is pushed into the line-carrier it meets the caliper-head, which has previously risen in its path, and by a spring connected to the gage-block lever is forced toward the advancing line of type. The line of type as it meets the caliper-head in its path pushes it before it until the rear end of the line passes the dog in the carrier, which rises behind the type in a slot in the end of the line-pusher. The line-pusher then retires and leaves the line of type held by the dog at one end and pressed upon by the caliper-head at the other. This action measures the length of the line. The caliper-head is connected by a series of compound levers with a gage-block or bulk-head, which stands opposite to the stationary ways of the dividing-plates and which takes position relatively to the caliper-head. As soon as the caliper-head has measured the line, and consequently set the gage-block, the locking mechanism comes into play and locks the gage-block fast in its set position. As soon as the gage-block has been firmly locked it is ready to receive the dividing-plate which happens to stand on its level, set there by the action of the space-key. The caliper-head now descends and leaves the way clear for the line-carrier to move forward through the line-raceway.

Line-carrier.—The line-carrier consists of a slide mounted in a way and connected to a long lever by means of which it is moved from one end of the line-raceway to the other.

The word-separating mechanism.—It will be remembered that when the line is set by the setter it contains a number of false spaces of uniform width. In order to complete the justification of the line, it is necessary to remove these false spaces and to insert spaces of proper width in their places to accom-

plish the justification. In order to do this, the line must be divided into its component elements—that is to say, into its words—and each of the false spaces withdrawn and suitable spaces inserted. When the line has been carried by the line-carrier from the caliper mechanism to the word-separating mechanism, it is brought to a standstill, and an auxiliary pushing device then begins to operate upon it, set in motion by the operation of the word-shaft, a belt running upon a transverse counter-shaft, to which it is connected by friction-disks, which so long as the word-shaft is moving will maintain a constant pressure or tendency to operate upon the auxiliary pushing device; but the disks will slip one upon another when the pusher is brought to a state of rest by contact with a stationary part. The types used in the machine are, as is usual with individual types, nicked on one edge, and as my machine is arranged the types are carried by the line-carrier and travel through the line-raceway on edge with the nicks downward. On the surface of the lower way of the line-raceway just beyond the extreme limit of the throw of the line-carrier is a plate narrower than the raceway and longer than any word, which has a vertical motion. This is the word-lifter. On the surface of the same way on each side of the word-lifter are two small wards which correspond in position with two nicks in the type. The false spaces have no such nicks. When the word-lifter is below or on the same level as the line-carrier and the auxiliary line-pushing device begins to operate, it will push a word out of the line-carrier and over the word-lifter until a false space comes in contact with the wards on the surface lower way on each side of the word-lifter. This will stop the further motion of the line, and the pusher being connected to a friction driving mechanism will also stop while still maintaining pressure upon the end of the line. The wards on the surface of the raceway are located a distance from the right-hand end of the word-lifter just equal to the width of the false space. When the above operation has been accomplished, the word-lifter will rise and carry one word and the succeeding false space upward to the level of the word-raceway. There is a word-forcing mechanism driven by a suitable lever which operates upon the upper way of the word-raceway and has a throw back and forth throughout the whole extent of the word-raceway. It is so timed in its operation that it is always beyond the end of the word-raceway on the right when the word-lifting mechanism lifts a word up to the level of the word-raceway. In the under surface of the upper way of the line-raceway immediately above the word-lifting device there is an elastic section corresponding approximately in length with the word-lifter, and which under

the influence of its springs has a limited downward motion equal to the throw of the word-lifter. It has a little greater extent of upward motion. When the word-lifter is down, the elastic section of the raceway is down, and when the word is pushed out of the line-carrier over the word-lifter it enters a channel of exactly the proper width to receive the types. On the under side of the elastic section there is a light flat spring secured to the right-hand end of the elastic section and lying in the path of the advancing type to exert upon them a certain amount of friction. When the word-lifter is raised, it pushes the elastic section upward above it by the type. When the word-lifter rises, carrying with it a word and one false space, it closes the open end of the line-raceway and prevents any more words from being moved forward until the word-lifter returns to the level of the line-raceway and into position to receive a second word. When the first word is swept from end to end of the word-raceway, the space-ejector mechanism will not have begun to eject true spaces; but before the second word is carried from end to end of the word-raceway a true space will have been ejected into the raceway by the ejector mechanism, and the word-forcer will take up this space and carry it before the word to the end of the raceway and push it and the first letters of the word into the galley. This operation will be repeated for each word, the false spaces being withdrawn after each word has reached the end of the word-raceway and before its last letters have entered the galley until the whole line is finished.

False-space extractor.—This mechanism has to perform several functions. It first pushes the word and all of its preceding words into the galley a distance sufficient to cause the last letter to be exactly aligned with the near edge of the galley, so that when depressed by the galley-depressor it will enter the galley without binding or catching upon its edge. It then recedes and carries with it a false space until it reaches the channel in which the false spaces are stored. It then pushes the false space into channel and is ready to return again to the raceway. As the false space and its extractor recedes a dog falls into its place to prevent the galley-follower from pushing the word back into the wordway.

The galley-depressor mechanism.—As the line of type in successive words is swept through the word-raceway each word is pushed by the false-space extractor into a channel in the galley or between the galley-depressor and a plate. When the galley-channel is filled with a line of type properly justified, the plate upon which the line of type rests is withdrawn from the rear, and the depressor descends, pressing the line of type and all of the preceding matter in the

galley down a requisite distance and ascends to its former position in line with the top of the word-raceway, the galley-plate returns to its former position, and the channel is again 5 formed for the reception of another line.

I have now described the general principle and general movements of the machine. The details of constructions will be described in the order in which the general groups have 10 been mentioned above by reference to the drawings, in which the details are illustrated.

The setter.—Referring to Figs. 1, 2, and 3, 1 is the bed of the machine, supported on suitable supports. 2 2 are vertical frames mounted upon the bed and which contain and support the setter. One of the frames 2 is shown in full elevation in Fig. 15. 3 is the main driving-shaft, to which power is communicated by the pulley 4. 5 is the line- 20 shaft, to which power is communicated from the driving-shaft by the train of gears 6 7 8 9, Fig. 3, and 10, Fig. 5, is the type-ejector-bar table, mounted transversely of the setter between the frame 2 2, to which it 25 is secured at each end and slightly inclined backward. From the front edge of the type-ejector-bar table there is a pendent flange 11, (shown in the same figures,) which serves as a support for various devices which are secured to the front side of it. Above the 30 type-ejector-bar table and resting upon it near the front, maintained in suitable supports between the frames 2 2, are a series of type-cases 12 12, each containing a number of 35 channels in each of which are placed types and characters constituting the whole range of the font. Each channel of course contains the same character. In front of the type-channels upon the type-ejector table is the setter-raceway 13, into which the types are ejected. This raceway is formed by a forward projecting portion of the table and a friction-bar 14, which is supported above the forward projecting part of the table. 40 The friction-bar is divided at the center of the machine into two parts, each operating independently and pressed downward by springs. The operation of this structure and the general operation of the type-setting machine is fully described in the Setter patent, No. 637,858, and therefore I do not think it necessary to go much into detail with reference to the structure of the type-setter.

Referring to Fig. 8, 15 15 are a series of 50 type-ejector bars, which consist of thin flat plates of steel mounted side by side upon the table and suitably guided so as to eject from the bottoms of the type-channels one type with each operation. The type-bars are 55 connected at their rear ends with auxiliary bars 16 16, which extend back to the rear of the setter and when in their extreme backward position impinge upon an elastic buffer 17, designed to check the backward motion 60 without jar. On the under side of the bars

16 there is a shoulder 18 and on the top of the bar a notch 19. 20 20 are a series of key-levers pivoted at 21, having rearward projections 22 and upward projections 23. 24 is a spring connected to the projection 22 for 70 retaining the type-lever in a position of rest, the front end being raised to its extreme limit. 25 25 represent a series of guide-pins secured to the rear of the table 13, to guide the arms 23 23. To the end of the projection 75 22 of each key-lever is pivoted a rod 26, on the end of which there is a latch 27. 28 is a shoulder on the under side of the bar 16, provided to engage an arm to return the bar to its normal position. 29 is a bell-crank lever 80 pivoted at 30, one arm of which extends upward and engages the shoulder 28, on the under side of the bar 16, and the other arm which is connected to a spring 31, by which the vertical arm of the bell-crank is held in 85 contact with the stop-bar 32, which is preferably covered with rubber or other elastic material to receive the recoil of the bell-crank lever 29. The top of each of the bars 16 is provided with a curved indentation 33, at 90 the rear of which the bar is cut down to form a shoulder 34. Secured to the driving-shaft 3 is a knife-blade 35. When the bars 16 are in a position of rest, the curved indentations 33 33 will stand below the driving-shaft 3, 95 concentric with it, and the shoulder 34 will be beyond the reach of the knife-blade 35. When the key-lever 20 is operated, however, the latch 27 will be raised out of the notch 19, unlocking the bar 16, the bar 16 moved 100 forward a short distance by the arm 23, and the shoulder 34 moved into the path of the knife-blade 35, which on its succeeding revolution will engage the shoulder 34 and move the bar 16 and its ejector 15 forward a required 105 distance to eject a type into the raceway. In doing so the bell-crank 29 will be pushed forward and the spring 31 stretched. As the driving-shaft continues to revolve the knife-blade 35 will pass away from the shoulder 34, and the bell-crank 29 will at once drive the bars 16 and 15 back to their normal 110 position. The stop-bar 32 will stop the bell-crank 29; but the momentum of the parts will carry the bar 16 back to its extreme position in contact with the buffer 17, and the latch 27 will fall into the notch 19 and lock the bar 16 in its position of rest. It will thus 115 be seen that the work cast upon the key-lever with each stroke consists only of releasing the latch 27 and moving the ejector-bar 16 forward a distance of about one-eighth of an inch, far enough to bring the shoulder 34 into the path of the knife-blade 35, when the constantly-moving parts of the apparatus 120 will do the rest.

Referring to Figs. 2 and 3, on the main driving-shaft 3, beyond the right-hand frame 2 2 is a keyed gear 36, meshing with another 125 keyed gear 37, which is secured to a counter- 130

shaft journalled in the bracket 38 and having upon its forward end a disk 39. On the face of the disk is a crank-pin 40 and a series of compound levers 41 and 41^a, by which the motion of the crank-pin 40 is communicated to a connecting-rod 42 and a type-assembling frame 43. 44, Fig. 1, is a bar secured to the frames 2 2 of the type-setter across the front, and upon this bar is mounted the type-assembling frame 43. The type-assembling frame is given a reciprocating motion back and forth across the front of the machine upon the bar 44. 45 and 46 are a pair of type-forcer feet suspended from opposite ends of the type-assembling frame 43 and facing one another, spanning the presser-rod 14 and just escaping the type-raceway on the ejector-table 13. The motion of the type-assembling frame 43 causes the forcer-feet 45 and 46 to travel each successively up to and away from the center of the type-raceway, so that any type which may be ejected into the raceway by the ejector-bars will successively be brought up to the center of the raceway and left there.

The setter is divided into two halves exactly alike in detail, except that the knife-blade, which is connected to the main driving-shaft on the left-hand of the center, is in the position shown in Fig. 8, while that on the right of the center at the same instant is at an angle of one hundred and eighty degrees from the position shown in Fig. 8, and the parts are so timed that when the type-assembling frame is upon the left side of the center, as in the position shown in Fig. 1, the knife-blade 35 on that side will be in position shown in Fig. 8 and will operate to eject types between the type-forcer feet 45 and 46 of the type-assembling frame, the other side of the machine being temporarily inactive. When the assembling-frame is at the other extreme of its travel and foot 45 is at the center and foot 46 at the end, then the knife-blade operating the other half of the ejector-bars will come into operation and will eject its type at that instant. It will be noticed that but one type is ejected at a time and that but one type is ejected for each half-revolution of the driving-shaft. The instant at which the ejection takes place, therefore, can be timed so that it will occur only when the type-assembling frame is at its extreme position, either right or left. An appreciable period of time is required to eject the type into the raceway, and for this reason it will be noticed that the type-forcer foot 45 when the carriage is in its extreme position to the left is some distance beyond the last type-channel. The same is true upon the other side, because provision must be made for the ejection of type from the last channel, and as all the ejections take place at the same relative instant the type must be able to get into the raceway and in front of the type-forcer

foot before the forcer-foot reaches it. In order to insure this and make the machine run with positiveness, the throw of the carriage is made somewhat greater than one-half the width of the type-cases.

The details of the construction of the type-forcer carriage and its feet and the presser-bar and its mode of elevation do not necessarily enter into this case, but are fully set forth in the Setter patent above referred to.

Referring to Figs. 8, 9, 10, 11 and 12, they show the means by which the motion of the space-key is communicated to the justifying-machine to cause the dividing-plates, the averaging-cam stop, and the index mechanism each to make a step in their prescribed courses. 47 is a space-key pivoted at 48 and connected, by means of a hook-lever 49, to the false-space bar. This key is similar to all the other keys of the keyboard, but is connected to a mechanism by which the setting of the justifier is accomplished. On the rear end of the false-space ejector-bar 16, (shown in Fig. 8,) which is connected with the space-key, is a slotted lug 50.

A bell-crank 90 lever is suitably supported and pivoted at 51, one arm of which, 52, engages the slot 50 in the end of the false-space ejector-bar 16 and the other end 53 a slot in the end of the bolt 54. 54 is a bolt which plays through a bushed hole in the frame 2, having a slot in one end and which is engaged by the arm 53 of the bell-crank lever. On the main driving-shaft 3 is a cam 55. (Shown in dotted lines in Fig. 8 and in full lines in Fig. 10.) The cam, as shown in dotted lines in Fig. 8, has a raised portion through about two-thirds of its circumference. 56 and 58 are the two arms of the lever, (shown in Fig. 43,) pivoted on the side of the frame 2 at 57. The upper end of 56 is perforated and provided with a bolt 62, which has upon its inner end a head 63. Referring to Figs. 11 and 12, the head of the bolt 62 stands opposite the end of the bolt 54, and when the bolt 54 is projected it will strike against the head 63, and if the cam 55 is in position shown in Fig. 8, with the point of its smallest diameter opposite the bolt 54, said bolt will be projected beyond the edge of the cam, and as the cam revolves the series of levers connected with the lever 56 will be operated by the cam. It is manifest that during the whole period of the revolution of the cam while the high part of the cam is opposite the pin 62 it cannot be projected beyond the edge of the cam. It can only be projected while the dead time of the cam is opposite the pin. Hence to insure the pin being projected at the proper moment the cam is so set upon the driving-shaft in relation to the knife-blade that when the knife-blade engages the shoulder 34 of the space-ejector bar the dead time will be opposite the pin 62, and this dead time is of such extent that it will permit the pin to be fully projected

before engaging the cam. When the cam has made a revolution and has come to a position shown in Fig. 11, the shearing-cam 64, which is upon its edge, will engage the 5 end of the bolt 62 and push it back through the end of the arm 56 into position shown in full lines in Fig. 10 and dotted lines in Fig. 11, and it will thus escape the cam and cease to operate its connected mechanism. Still 10 referring to Figs. 8 and 43, 59 is a rod connected to the lower end of the arm 58 and the upper end of an arm 60, which is keyed upon the counter-shaft 61. 61 will be designated as the "pawl-shaft," as it serves to 15 operate a number of pawls simultaneously for the purpose of causing the various mechanisms with which they are connected to take a step as it is operated.

Referring to Figs. 49 and 50, 65 is an arm 20 keyed upon the pawl-shaft 61. 67 is a pawl-lever loosely journaled upon a counter-shaft 72. 66 is a bar connecting 65 and 67, and 68 a pawl pivoted to 67 and engaging the ratchet-wheel 71. Further on in the 25 machine a spring is shown in Fig. 57, (marked 61^f), by which the train of levers and arms connected to the pawl-shaft are held up to their work and the pawl is returned to its normal position after it has made a stroke. 30 71 is a ratchet-wheel loose upon the counter-shaft 72 and engaged by the pawl 68. 72 is a counter-shaft mounted in suitable journals and moved in one direction by the pawl and ratchet 68 and 71 to set the dividing-plates, 35 averaging-cam stop, and index mechanism and in the opposite direction by the recovering devices of the dividing-plates and averaging-cam stop. 73 is a checking-pawl. Upon one end of the counter-shaft 72, Figs. 40 36 and 43, is keyed a beveled gear 74, which meshes with another beveled gear 75, keyed upon the shaft 76. The shaft 76 is journaled in suitable bearings at right angles to shaft 72 (shown in Figs. 38 and 39) and forms the 45 operating mechanism for elevating the dividing-plates. Referring to Fig. 51, 77 is a clutch-disk splined upon the shaft 72. Referring to Figs. 2, 49, and 51, 78 is a pinion keyed upon the opposite end of the counter- 50 shaft 72 from the beveled gear 74. The clutch-disk 77 is provided on its side next to the ratchet-wheel with a projecting pin 310. The ratchet-wheel 71 has in its side a series of holes 309 309, which are all in the path of 55 the pin 310 upon the clutch-disk 77 and located one opposite each tooth of the ratchet, so that when the clutch-disk 77 is pressed up against the ratchet the ratchet-wheel will be locked to the shaft, and its motion will drive 60 the shaft and the devices connected with it. When the clutch is disconnected from the ratchet-wheel, all the parts connected to the shaft will act independently of the ratchet.

Referring to Figs. 50, 51, and 52, 79 is a 65 rack meshing with the pinion 78 and moved

by it in a groove on the surface of a table 80, which is supported upon the main bed of the machine. The motion of the rack-bar in the groove is limited by a stop 81, which closes the end of the groove. The rack 79 is not 70 only moved by the pinion 78, but so long as the clutch-disk is in engagement with the ratchet-wheel is held stationary by it. Upon the rack-bar beyond the rack is the stop 81. To the far end of the rack-bar is secured a 75 chain 82 and counterweight 83. Constant pressure is therefore maintained upon the rack-bar 79, opposing the pull of the gear 78. So long as the clutch-disk 77 is in clutching 80 contact with the ratchet-wheel 71 the dividing-plates and the rack will be moved by the ratchet or held by it; but the instant the clutch is disengaged from the ratchet the weight 83, aided by the weight of the dividing-plate carriage, will return the rack-bar to 85 its primary position and also return the dividing-plates to their primary elevation. The primary position of these parts is a position in which the pin of the clutch will stand opposite one of the holes of the ratchet, so that 90 it will always register with one of those holes when the clutch-disk is thrown by its cam. A cam 110, Fig. 43, on the main driving-shaft, which moves the dividing-plate carrier by suitable levers, will simultaneously withdraw 95 the dividing-plates from contact with the gage-block, and the combined motion imparted to the dividing-plate carriage by the cam 110 and the counterweight 83 will restore it to its primary position. 84 is a dash- 100 pot, and 85 is the piston-rod of the dash-pot, which is connected to the rear end of the rack-bar 79 to check the sudden motion given to the parts by the counterweight 83.

The pawl-shaft 61, as shown in Figs. 2, 57, 105 and 82, is not one continuous unbroken shaft from end to end of the machine; but in consequence of the difference of level upon which the ratchet of the dividing-plates and averaging-cam stop and the ratchets of the index 110 mechanisms are located the shaft is divided into two parts, and the portion which operates the index mechanism is dropped down to a lower level, but connected to the portion which operates the dividing-plate ratchet by 115 a pair of arms and a connecting-link. Referring to Fig. 57, it will be seen that the pawl-shaft 61 penetrates the side support of the bracket 266, while the shaft 61^a, which is the other portion of the pawl-shaft, penetrates 120 the other support of 266 at a lower level. These arms and link are shown in Fig. 57. 61^b is a lever secured to the shaft 61 between the supports of the bracket 266. 61^c is a link connected to the end of 61^b, and 61^d is a lever 125 secured upon the shaft 61^a and to which the link 61^c is connected. 61^b and 61^c being of the same length will communicate the motion of the shaft 61 to the shaft 61^a as if the two shafts were one. 61^e is an arm secured upon 130

the shaft 61^a. 61^c is a spring suitably secured to the frame of the machine at one end and to the arm 61^e at the other end. 61^e is provided with a series of holes for adjustment of the spring upon the arm. This spring serves the important function of recovering all of the pawls after they have made a stroke and also of keeping the cam-lever 56 against its stop-pin 56^a.

Referring to Figs. 77, 78, 79, 80, 81, and 82, 86 and 87 are two levers secured to the pawl-shaft 61^a. 88 and 89 are two links, one connected to 86 and the other to 87 and at their far ends connected to the pawl-levers 90 and 91. 92 and 93 are pawls pivoted upon the levers 90 and 91. 94 and 95 are ratchet-wheels with which the pawls 92 and 93 engage when the wheels are in line with the pawls. The pawls 92 and 93 reciprocate with every movement of the pawl-shaft 61^a; but the ratchets with which said pawls engage are by another mechanism shifted into or out of the path of the pawls. That ratchet only, therefore, is moved which is in the path of its pawl, the other ratchet being free to move backward when out of the path of its pawl. When the space-key is struck, therefore, it will be seen that the bolt 62 is thrown into the path of the cam 55, which is in constant revolution, and as it turns it will move the train of levers connected to the bolt 62 and revolve the pawl-shafts 61 and 61^a a calculated distance, which is equal to one tooth of the ratchet-wheels 71, 94, and 95. It will thus be seen that each stroke of the space-key will cause the dividing-plates, the averaging-cam stop, and the index mechanism to step forward the distance of one tooth of their respective ratchet-wheels, and this will continue for as many spaces as are inserted in the line.

Dividing-plates.—Referring to Figs. 36, 37, 38, 39, 40, 41, 42, 43, 96 is a bracket secured upon the bed of the machine and in which the counter-shaft 76 is journaled at its two ends. The bracket is open in the center, so as to make space for a pair of gears 97 97, which are mounted upon the shaft 76. The shaft 76 is provided with a longitudinal groove 76^a, and a key 97^a is seated in a key-seat in the gear 97 and projects into the groove and slides therein, thus permitting the gears to slide on the shaft while turning with it. The gear 97 is provided with an elongated hub, so as to prevent the tilting and jamming of the gear upon the shaft. 98 98 are longitudinal dovetailed ways in the face of the bracket 96, and 99 is a carriage sliding in the ways. 100 is a pitman-rod pivotally connected to the carriage 99 at one end and to the lever 101 at the other end. The lever 101 is pivoted to the frame of the machine at 102 and has an arm 103, to which springs or counterweights 104 are attached. The tendency of the counterweights is to throw the

carriage 99 to the extreme limit of its motion toward the front of the machine; but this is prevented by the action of the third arm 105 of the lever 101, connected by a pitman-rod 106 to the bell-crank lever 107, one arm of which, 108, is provided with a cam-roller 109 and bears upon a cam 110, secured to the main line-shaft of the machine. The motion of the carriage 99, therefore, while constantly tending forward can only proceed as far as the cam 110 will permit. In the face of the carriage 99 are dovetailed ways 111 111, and in these ways is mounted a vertically-moving plate or carriage 112, to the front side of which is secured a series of horizontal inclined plates 113, which are parallel to one another and project at right angles from the carriage 112 and vary in their respective tangents a predetermined amount—such, for instance, as one one-hundredth, as described in the preamble of the specification. These are the dividing-plates. If the inclination of the first plate be one to one hundred, the second plate will be two to one hundred, and the third three to one hundred, and so on. In practice I do not use any plate less than three to one hundred, and the others increase in tangent up to thirteen to one hundred. On the back of the plate 112 are a pair of vertical racks 114 114. Through the center of the carriage 99 are a pair of vertical slots 115 115, through which pass the gears 97 97 and mesh with the racks 114 114. The plate 112, sliding in the ways of 111, has only a vertical motion, and therefore maintains the vertical racks 114 114 in a fixed line. The gears 97 97, passing through the slots 115 115 in the plate 99, are moved back and forth upon their shaft 76, but are kept always in mesh with the racks 114 114. Thus it will be seen that the dividing-plates 113 have a vertical motion under the influence of the gears 97 97 and a longitudinal motion under the influence of the weights 104, controlled by a cam 110. As the space-key is operated it will operate the gears 97 97 step by step through the ratchet 71 and raise the plates one at a time into the plane of the gage-block. Thus if the plates be arranged to represent the number of spaces to be inserted in a line and be placed in order one above the other, that having the smallest tangent, as shown in Fig. 42, at the top and that having the greatest tangent at the bottom, the plate designed to correspond with any particular number of spaces will when the space-key is struck a number of times equal to the spaces be brought into the plane of the gage-block, and when the whole carriage is moved forward under the influence of the counter-weights or springs 104 that plate which has been selected by the successive motions of the space-bar, and that plate alone, will be driven into the space between the fixed ways of the carriage and the gage-block. 116 is a

rack upon the upper rear edge of the carriage 99. 117 is a stud secured to the top of the bracket 96, upon which is journaled a hub having a pinion 118 at its lower end and a 5 pinion 119 at its upper end, both of the same size. The pinion 118 meshes with the rack 116 and is moved by it. 119 meshes with the rack 120 and moves it. Referring to Figs. 2, 54, 91, and 92, the rack 120 is connected to a rod 121, which passes through the space-ejector carriage and moves it forward. On the extreme end of the rod 121 are two set-nuts 300, which are designed to fix the position at which the rod 121 will begin to move the carriage. The space-ejector carriage is mounted in a way in which it may slide when drawn forward by the rod 121 or pushed back by its recovering device.

Opposite to the way of the space-ejector carriage are arranged a series of true-space magazines, each containing a number of true spaces of uniform width. I prefer to locate these magazines the same distance apart, and I designate this distance from one magazine 20 to another as the "zone" of a space-magazine. The space-ejector carriage as it travels past the space-magazines will travel from the zone of one space-magazine to the zone of another. It will be apparent that the simplest form of 25 construction is to locate the space-magazines an equal and a suitable distance apart and assume this distance as the zone of the space-magazine through which the ejector-carriage is to travel; but the zone may be differently 30 arranged and the space-ejectors made in various forms, so as to respond to the action of the space-ejector while in any particular zone or subdivision of its way and the space-magazines located in any position where they 35 may be acted upon by the space-ejectors.

It is only necessary that the path of travel of the space-ejector carriage should be divided into a certain number of equal parts, which I have called "zones," and that the 40 space-ejector bars should be arranged in these zones in such relation to the space-ejector as to be operated by it and in such relation to the space-magazines as to eject spaces from them to the word-raceway. If 45 now one of the space-magazines—say the center one—be filled with true spaces of the width of false spaces and those on each side of it be filled with spaces differing from the false space in width successively by a definite and equal amount—say, for instance, that the false space be .070" in width then the space on one side will be .065" and on the other side .075", and all the other magazines be charged with thinner and thicker spaces 50 in regular order, then the distance from midway between .075" and .070" to midway between .070" and .065" would be the zone of the .070" space, and all spaces ejected from this zone would be equal in width to the false 55 spaces. If now the ejector-carriage be set at

the beginning of the zone of the .070" spaces and be then coupled up to the dividing-plates, which have previously been set at the position they will occupy when the point of uniform width of all plates is in contact with 75 the center of the gage-block, the parts will be in such a position as to justify a line, whether longer or shorter than standard. If the line be longer, the space into which the plates are to travel will be less and the plates will 75 travel a less distance, and a point of one of the plates at which the plate is narrower than at the point of uniform width will contact with the gage-block, with the result that the space-ejector carriage will not be drawn up to 80 the .070" position, but will be drawn up to some position opposite the zone of a space less than .070"—say .045". Thus the dividing-plates will have subtracted from each 85 false space an amount equal to the gap divided by the number of word-spaces in the line. If the line be shorter than standard, then the gage-block will be set a greater distance from the ways of the dividing-plate carriage and the dividing-plate on the plane 90 of the gage-block will not make contact with it until the point of uniform width has passed the gage-block, and the space-ejector carriage being drawn forward a corresponding distance will stand in the zone of a space 95 thicker than .070", or, say, .085". Thus the dividing-plates will have added to the false-space thickness an amount equal to the gap divided by the number of word-spaces to determine the ideal space.

We have now seen the manner in which the space-key operates to set the dividing-plates in a position corresponding to the number of spaces in the line. We have also seen the way in which it causes the averaging-cam 100 stop 81 to be moved forward a number of steps corresponding to the number of spaces in the line, and we have seen how it causes one of the ratchets of the index mechanism to move forward a number of steps corresponding with the number of spaces in the line.

I have before described the general operation of the averaging-cams. It is only necessary at this point to say that after the averaging-cam stop 81 has taken the requisite 105 number of steps and attained the desired position the cam-carriage carrying the whole series of cams is pushed by a suitable mechanism up against the stop, the cams sliding on the shaft by which they are turned, thereby bringing the particular cam corresponding to the number of strokes given to the space-key into position beneath the pawl-lever of the stepping mechanism of the ejector-carriage. When the cam-shaft is now 110 revolved, the cam and the pawl-lever and its connected mechanism will cause the ejector-carriage to take as many steps as the number of revolutions given to the cam-shaft. The motion of this shaft, communicated to it 115

from the word-shaft, will be dependent upon the number of revolutions of the word-shaft, and the number of revolutions of the word-shaft is dependent upon the number of steps which the index mechanism has made under the influence of the space-key.

Index mechanism.—I will now pass to the index mechanism and take up its construction for the purpose of showing the manner in which the word-shaft is caused to make a number of revolutions equal to the number of words in the line.

Referring to Figs. 74, 75, 76, 77, 78, 79, 80, 81, 82, and referring particularly to Figs. 74, 75, and 76, 4 is, as previously stated, a driving-pulley. 3 is the main driving-shaft, supported at one end in the bracket 122, which is secured to the bed of the machine. Journaled in the main bracket is the word-shaft 123, and secured in the bracket is a stud. 124, 125, 126, 127, and 128 represent a train of gears. 125, journaled upon the main driving-shaft, and 128 upon the word-shaft are connected by a gear and pinion 126 and 127, which are loosely journaled upon the stud 124, but connected together. 129 is a friction-clutch secured to the main driving-shaft 3 and provided with a suitable spring. The bearing-face of the clutch makes contact with a similar bearing-face upon the hub of the gear 125. The gear 125 is loose on the shaft 3, but is pressed by the friction-clutch 128 against a collar 125^a, set upon the shaft, and is driven by the frictional contact of the clutch 129 and the collar 125^a. If any stop should occur in the mechanism driven by this train of gears which would have a tendency to break any of the parts, the clutch 129 would permit the pinion to slip, and thus save the parts.

Referring to Fig. 54, 130 is the space-ejector table supported upon two legs 131. 131. On the exterior of each leg 131 there is a boss, which are respectively marked 132 133. Through the center of these bosses the word-shaft 123 is journaled. It will be seen that it is supported, therefore, in three bearings—one in the bracket 122 and two in the legs 131 131 of the space-ejector table 130.

Referring to Figs. 77 to 82, 134 is a ratchet-tooth spring-clutch upon the word-shaft. The gear 128 has an elongated hub 135 projecting toward the clutch 134, and the face of this hub is provided with ratchet-teeth of similar size and adapted to mesh with the teeth of the clutch 134. The train of gears 125, 126, 127, and 128 being constantly in engagement with the driving-shaft run continuously; but they do not communicate any motion to the word-shaft or the devices connected to it except when the clutch 134 is in engagement with the hub 135. 136 is a spring bearing at one end against a fixed collar 137 on the word-shaft and at the other end upon the clutch 134 and constantly

pressing it toward the hub 135 and holding it in engagement with the said hub except when it is pressed backward by a suitable clutch-pin controlled by the index mechanism. Upon the periphery of the clutch 134 there is a shearing-cam 138, the pitch of which is such that when the clutch-pin is brought in contact with the shearing-cam it will force the clutch 134 backward out of engagement with the hub 135 in the course of a portion of a revolution of the clutch.

Referring to Fig. 82, 139 is a lever pivoted upon trunnions on the bracket 140 and having an arm 141, which extends backward to engage a cam 142 on the main line-shaft. 80 With every revolution of the main line-shaft the lever 141 is depressed and the lever 139 elevated. In the end of the lever 139 is a downwardly-projecting clutch-pin 143, which engages the shearing-cam 138 on the periphery of the clutch 134. When this pin 143 is thrown into contact with the shearing-cam 138, it has to resist the force of the spring 136 and overcome that force in order to be able to press the clutch 134 out of engagement 90 with the hub 135. To avoid the give of the lever 139 which would probably be incident to so great a pressure as is exerted by the spring 136, the pin 143 is held rigidly in a bracket 144, which is mounted upon the bed 95 of the machine and the end of which stands over the pin 143 and has a socket in its extremity in which the pin 143 plays. Above the pin 143 is a spring in the bottom of the socket of 144, which presses the pin down. It 100 is pressed upward by lever 139 and downward by a spring above. It thus follows the motion of the lever 139, and the bracket 144 serves to hold the pin in a rigid position and to resist the pressure of the spring 136. 105

Fig. 81. Journaled in two supports 145 146, which stand upon the bed of the machine, is a counter-shaft 147. Upon this counter-shaft are loosely journaled two hubs 148 and 149. On the exterior end of these 110 hubs are the ratchet-wheels 94 and 95, and on the inner ends the hubs are expanded and provided with annular grooves 150 151. The inner face of each of the expanded hubs is provided with a series of holes 152 and 153— 115 twelve in number—the ratchets 94 and 95 being each provided with twelve teeth. On the outside of the annular grooves 150 and 151 on the hubs there are laterally-projecting annular flanges 154 and 155, which are provided with a peripheral notch 156 and 157, respectively. On the center of the shaft 147 is journaled a gear 158, which is pierced by a pin 159, which projects through the gear 120 equally on each side. It is secured rigidly in the gear 158. The pin 159 is located in position which will cause it to enter one of the holes 152 or 153 as the hubs 148 or 149 are moved up to it. 160 is a lever pivoted at 161 125 and having a rearward-projecting arm 162, 130

with a roller on its rear end. 163 is a cam having a cam-groove into which the roller of the lever 162 fits. The cam 163 is keyed upon a counter-shaft 5^a, which is geared to the main line-shaft 5, so as to make a half-revolution for every revolution of the main line-shaft and gives to the lever 162 and 160 a movement to the right or left for each half-revolution of the cam 163 and for each full revolution of the main line-shaft. Upon the outer end of the T-lever 160 are two projecting pins 164 and 165. These pins enter the grooves 150 and 151 of the hubs 148 and 149, and when the cam 163 makes a half-revolution the hubs 148 and 149 will be shifted into or out of engagement with the fixed gear 158. 90 and 91, as before stated, are pawl-levers loosely journaled upon the shaft 147, the pawl-lever 90 having a pawl 92 and the pawl-lever 94 having the pawl 93 pivoted to them. These pawls, as above explained, take their motion from the pawl-shaft through the rods 88 and 89, respectively. The pawl-levers and pawls do not shift; but the ratchet-wheels do shift into and out of engagement with the pawls. In order to maintain the pawl-levers 90 and 91 in fixed positions relative to the other parts of the structure, a bushing 166 is provided upon the shaft 147, and the hubs 148 and 149 are journaled upon it. This bushing will hold the pawl-levers in position between the journaled blocks 145 and 146 and the bushing.

Fig. 79 shows a detail of a latch which may be used one on each side to hold the ratchet-wheels stationary upon the shaft 147 while the pawls are being recoiled, thus preventing the ratchet from following the pawl and also locating the ratchet when it is moved forward by its pawl and preventing its being overthrown. 167 is a bolt passed through the journal-support 145 and having a collar 168 fixed upon its outer end. On its inner end is a cone-shaped head larger than the pin, and 169 is a spring between the brackets 145 and the head of the bolt. Upon the exterior surface of the ratchet-wheels 94 and 95 are a series of conical holes corresponding in number with the number of teeth of the ratchet 50 and which are engaged by the bolts 167 167 when the ratchet is in its extreme position and in engagement with its pawl. When the ratchet is turned by the thrust of the pawl, the bolt 167 will be forced backward by slipping out of its conical hole, but will slip into the succeeding hole and hold the ratchet, so as to prevent it following the pawl upon its recoil or being overthrown.

Keyed upon the word-shaft 123 is a pinion 170, which meshes with the gear-wheel 171, mounted upon a stud 172 in a bracket 173. On the same stud is a pinion 174, meshing with the gear 175, secured upon one end of the counter-shaft 176, which is journaled in a bracket 177. Upon the opposite end of the

counter-shaft 176 is a gear 178, which meshes with another pinion 179. 179 is a pinion upon one end of a hub 180, loosely journaled upon a counter-shaft 181, secured in the brackets 145 and 146. Upon the opposite end of this hub 180 is another pinion 182, which meshes with and drives the gear 158. By this train of gears the motion of the word-shaft is communicated to the gear 158. The train of gears 170, 171, 174, 175, 178, 179, 180 and 182 are so calculated and proportioned that for every revolution of the word-shaft the gear 158 will be caused to make one-twelfth of a revolution on its counter-shaft 147. The motion communicated to this gear 180 and to its connected parts by the word-shaft is the reverse in direction of the motion communicated to the same parts by the pawls and ratchets 92, 93, 94, and 95. The purpose of this arrangement is that the gear 158 185 shall move backward as many twelfths of a revolution as the ratchet-wheel which controls it has moved forward. The lever 139 is provided at about its center with two projecting cross-arms 183 183 and 184 184. In 190 the ends of 184 are pivoted two hooks 185 185, which project toward the extremity of 139 and are spring-actuated to maintain them in an extended outward position. The cross-arms 183 183 have upon their ends dependent lugs 186 186, which form stops for the hooks 185 185 and prevent their being thrown outward by their springs beyond a desired point. One of the laterally-projecting flanges 154 or 155 of the hubs of 148 and 149, respectively, stand always under the point of one of the hooks 185, and when the hubs are revolved under the hooks the point of the hook over the respective flange will fall into the notch 156 or 157, as the case may be, 195 and allow the clutch-pin 143 to fall into engagement with the shearing-cam 134. When now the cam 163 turns and the lever 162 is moved and the hubs 148 and 149 shifted—as, for instance, from the position shown in Fig. 110 78 to the position shown in Fig. 81—the hub 148 will be carried into engagement with the pawl 93 and the notch 157 will be carried beyond the reach of its hook 185, the hook being restrained by the overhanging pendent 115 lug 186 of the cross-arms 183. The ratchet 94 will be carried out of engagement with its pawl 92, and the hub 149 will be thrown into engagement with the pin 159 of the gear 158. The flange 155 will press against the side of 120 its hook 185 and move it inward, but it will maintain a pressure due to its spring against the interior surface of the flange 155. If now the ratchet 94 has been stepped forward six steps by its pawl actuated by the space-bar, 125 the notch 156 will have been thrown six steps away from its hook 185. The cam 142, controlling the lever 139, acts upon it and elevates the pin 143 out of engagement with the clutch 134. Contact is at once made between the 130

clutch 134 and the hub 135, and the word-shaft begins to turn. As it does so through the medium of the train of gears just described the hub 149 and its flange 155 will be caused to move backward one-twelfth of a revolution for every revolution of the word-shaft. If, as has just been stated, the hub 149 has previously been stepped forward six steps by the pawl 92, the notch 156 will have been removed six-twelfths of a revolution away from its hook 185. Six revolutions of the word-shaft therefore must be made before the notch 156 will be brought back to the point of its hook 185. The cam which shifts the hubs 148 and 149 is timed to act a little before the cam 142, which lifts the lever 139. Therefore the flange 155 will be thrown into engagement with the driving mechanism before it is started, because the ratchet and disk 192 after having been set must first be brought into contact with its hook 185 and will press it toward the lever 139. When the cam 142 acts, the hook will be raised with the lever 139 and will be drawn back against its stop 186 by its spring, and when the lever 139 is released by its cam 142 the point of the hook 185 will, supporting the lever ride upon the periphery of the flange 155 until the hook 185 drops into the notch 156. The dropping of the hook 185 into the notch 158 will at the same time cause the pin 143 to be dropped in contact with the shearing-cam 138, and as that cam completes its revolution under the influence of the driving mechanism the clutch 134 will be drawn out of engagement with the hub 135, and the word-shaft will be disconnected from the driving mechanism and stopped, but only after it has fully completed its revolution. When the ratchet 94 was thrown out of engagement with its pawl and its further forward motion stopped, it was simultaneously thrown into engagement with the gear 158 and its reverse motion begun. By the same operation of the lever 160 the hub 148 was thrown out of engagement with the gear 158 and into its engagement with its pawl 93, which when moved by the space-key will step the ratchet 95 and the disk 154 forward as many steps as the space-key is struck and will carry the notch 157 forward as many twelfths of a revolution.

Word-shaft and its connections.—In the preceding sections we have described the mechanism by which the word-shaft is caused to make a number of revolutions equal to the number of words in the line. The connections of the word-shaft will now be described, by which the operation of ejecting the requisite number of spaces for justification into the word-raceway is accomplished. These operations consist in the reciprocation of the ejector and the stepping forward of the ejector-carriage a number of steps equal to the number of words in the line, so as to select spaces of uniform size or a certain number

spaces of one size and a certain number of an adjacent size, which in the aggregate will equal the number of spaces required and the aggregate thickness of which will equal the gap. These operations are performed in a very simple manner. The carriage having been given a primary setting by the dividing-plates, as heretofore described, one step beyond the true position from which it begins to step for the ejection of spaces, each revolution of the word-shaft causes the ejector-carriage to step forward upon its way a distance equal to the width of a space-magazine zone divided by the number of spaces to be inserted in the line.

Referring to Figs. 49, 53, 54, 55, 56, and 83, keyed upon the word-shaft 123 between the legs 131 131 of the space-ejector table is a cam 190, Figs. 54 and 55, the periphery of which is engaged by a pin 191 upon a lever 192, pivoted upon a post 193 and having connected to it a locking-cam 194. The pin 191 is held in contact with the cam 190 by the spring 195. Beyond the leg 131 on the right is a disk 196, which is journaled on the word-shaft, which has a cam-groove in its face 197. (Shown in dotted lines in Figs. 49, 54.) Pivoted upon a stud on the side of the leg 131 is an arm 198, on the side of which is secured a pin 199, upon which there is a cam-roller 95 which stands in the groove 197 and by which the lever 198 is operated through the agency of the cam-roller 199. To the upper end of the lever 198 is secured a connecting-rod 200, Figs. 49 and 83. 201 is a rock-shaft journaled in brackets 202 202, which are mounted upon the space-ejector table. 203 is a lever rigidly secured to the shaft 201 and at its lower end to the connecting-rod 200. The motion of the lever 198, produced by the cam-groove 197, is thus communicated to the shaft 201 by the connecting-rod 200 and the lever 203. 204 represents two arms secured to the shaft 201 and moved by it. 205 205 are two pitman-rods journaled to the ends of the arms 204 at one end and to the space-ejector slide 206 at the other end. The slide 206 is a square frame mounted in guides 207 207, which are secured at one end to the brackets 202 202 and at the rear end to suitable brackets 208 208, which are mounted upon the ejector-table.

Figs. 72, 83, 84: 209 is the word-raceway. 210 211 212 213 214 215 216 217 218 219 are space-magazines shown in vertical section in Fig. 71, front elevation in Fig. 72, and in horizontal section in Fig. 73. It will be noticed that the magazine 210 contains the thinnest space, while magazine 219 contains the thickest, and that 210 is at the left of the machine and 219 at the right of the machine. Later it will be seen that after the carriage is given a primary setting by the dividing-plates its motion is always from the thinner to the thicker space, Fig. 83. 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 760, 761, 762, 763, 764, 765, 766, 767, 768, 769, 770, 771, 772, 773, 774, 775, 776, 777, 778, 779, 780, 781, 782, 783, 784, 785, 786, 787, 788, 789, 790, 791, 792, 793, 794, 795, 796, 797, 798, 799, 800, 801, 802, 803, 804, 805, 806, 807, 808, 809, 8010, 8011, 8012, 8013, 8014, 8015, 8016, 8017, 8018, 8019, 8020, 8021, 8022, 8023, 8024, 8025, 8026, 8027, 8028, 8029, 8030, 8031, 8032, 8033, 8034, 8035, 8036, 8037, 8038, 8039, 8040, 8041, 8042, 8043, 8044, 8045, 8046, 8047, 8048, 8049, 8050, 8051, 8052, 8053, 8054, 8055, 8056, 8057, 8058, 8059, 8060, 8061, 8062, 8063, 8064, 8065, 8066, 8067, 8068, 8069, 8070, 8071, 8072, 8073, 8074, 8075, 8076, 8077, 8078, 8079, 8080, 8081, 8082, 8083, 8084, 8085, 8086, 8087, 8088, 8089, 8090, 8091, 8092, 8093, 8094, 8095, 8096, 8097, 8098, 8099, 80100, 80101, 80102, 80103, 80104, 80105, 80106, 80107, 80108, 80109, 80110, 80111, 80112, 80113, 80114, 80115, 80116, 80117, 80118, 80119, 80120, 80121, 80122, 80123, 80124, 80125, 80126, 80127, 80128, 80129, 80130, 80131, 80132, 80133, 80134, 80135, 80136, 80137, 80138, 80139, 80140, 80141, 80142, 80143, 80144, 80145, 80146, 80147, 80148, 80149, 80150, 80151, 80152, 80153, 80154, 80155, 80156, 80157, 80158, 80159, 80160, 80161, 80162, 80163, 80164, 80165, 80166, 80167, 80168, 80169, 80170, 80171, 80172, 80173, 80174, 80175, 80176, 80177, 80178, 80179, 80180, 80181, 80182, 80183, 80184, 80185, 80186, 80187, 80188, 80189, 80190, 80191, 80192, 80193, 80194, 80195, 80196, 80197, 80198, 80199, 80200, 80201, 80202, 80203, 80204, 80205, 80206, 80207, 80208, 80209, 80210, 80211, 80212, 80213, 80214, 80215, 80216, 80217, 80218, 80219, 80220, 80221, 80222, 80223, 80224, 80225, 80226, 80227, 80228, 80229, 80230, 80231, 80232, 80233, 80234, 80235, 80236, 80237, 80238, 80239, 80240, 80241, 80242, 80243, 80244, 80245, 80246, 80247, 80248, 80249, 80250, 80251, 80252, 80253, 80254, 80255, 80256, 80257, 80258, 80259, 80260, 80261, 80262, 80263, 80264, 80265, 80266, 80267, 80268, 80269, 80270, 80271, 80272, 80273, 80274, 80275, 80276, 80277, 80278, 80279, 80280, 80281, 80282, 80283, 80284, 80285, 80286, 80287, 80288, 80289, 80290, 80291, 80292, 80293, 80294, 80295, 80296, 80297, 80298, 80299, 80300, 80301, 80302, 80303, 80304, 80305, 80306, 80307, 80308, 80309, 80310, 80311, 80312, 80313, 80314, 80315, 80316, 80317, 80318, 80319, 80320, 80321, 80322, 80323, 80324, 80325, 80326, 80327, 80328, 80329, 80330, 80331, 80332, 80333, 80334, 80335, 80336, 80337, 80338, 80339, 80340, 80341, 80342, 80343, 80344, 80345, 80346, 80347, 80348, 80349, 80350, 80351, 80352, 80353, 80354, 80355, 80356, 80357, 80358, 80359, 80360, 80361, 80362, 80363, 80364, 80365, 80366, 80367, 80368, 80369, 80370, 80371, 80372, 80373, 80374, 80375, 80376, 80377, 80378, 80379, 80380, 80381, 80382, 80383, 80384, 80385, 80386, 80387, 80388, 80389, 80390, 80391, 80392, 80393, 80394, 80395, 80396, 80397, 80398, 80399, 80400, 80401, 80402, 80403, 80404, 80405, 80406, 80407, 80408, 80409, 80410, 80411, 80412, 80413, 80414, 80415, 80416, 80417, 80418, 80419, 80420, 80421, 80422, 80423, 80424, 80425, 80426, 80427, 80428, 80429, 80430, 80431, 80432, 80433, 80434, 80435, 80436, 80437, 80438, 80439, 80440, 80441, 80442, 80443, 80444, 80445, 80446, 80447, 80448, 80449, 80450, 80451, 80452, 80453, 80454, 80455, 80456, 80457, 80458, 80459, 80460, 80461, 80462, 80463, 80464, 80465, 80466, 80467, 80468, 80469, 80470, 80471, 80472, 80473, 80474, 80475, 80476, 80477, 80478, 80479, 80480, 80481, 80482, 80483, 80484, 80485, 80486, 80487, 80488, 80489, 80490, 80491, 80492, 80493, 80494, 80495, 80496, 80497, 80498, 80499, 80500, 80501, 80502, 80503, 80504, 80505, 80506, 80507, 80508, 80509, 80510, 80511, 80512, 80513, 80514, 80515, 80516, 80517, 80518, 80519, 80520, 80521, 80522, 80523, 80524, 80525, 80526, 80527, 80528, 80529, 80530, 80531, 80532, 80533, 80534, 80535, 80536, 80537, 80538, 80539, 80540, 80541, 80542, 80543, 80544, 80545, 80546, 80547, 80548, 80549, 80550, 80551, 80552, 80553, 80554, 80555, 80556, 80557, 80558, 80559, 80560, 80561, 80562, 80563, 80564, 80565, 80566, 80567, 80568, 80569, 80570, 80571, 80572, 80573, 80574, 80575, 80576, 80577, 80578, 80579, 80580, 80581, 80582, 80583, 80584, 80585, 80586, 80587, 80588, 80589, 80590, 80591, 80592, 80593, 80594, 80595, 80596, 80597, 80598, 80599, 80600, 80601, 80602, 80603, 80604, 80605, 80606, 80607, 80608, 80609, 80610, 80611, 80612, 80613, 80614, 80615, 80616, 80617, 80618, 80619, 80620, 80621, 80622, 80623, 80624, 80625, 80626, 80627, 80628, 80629, 80630, 80631, 80632, 80633, 80634, 80635, 80636, 80637, 80638, 80639, 80640, 80641, 80642, 80643, 80644, 80645, 80646, 80647, 80648, 80649, 80650, 80651, 80652, 80653, 80654, 80655, 80656, 80657, 80658, 80659, 80660, 80661, 80662, 80663, 80664, 80665, 80666, 80667, 80668, 80669, 80670, 80671, 80672, 80673, 80674, 80675, 80676, 80677, 80678, 80679, 80680, 80681, 80682, 80683, 80684, 80685, 80686, 80687, 80688, 80689, 80690, 80691, 80692, 80693, 80694, 80695, 80696, 80697, 80698, 80699, 80700, 80701, 80702, 80703, 80704, 80705, 80706, 80707, 80708, 80709, 80710, 80711, 80712, 80713, 80714, 80715, 80716, 80717, 80718, 80719, 80720, 80721, 80722, 80723, 80724, 80725, 80726, 80727, 80728, 80729, 80730, 80731, 80732, 80733, 80734, 80735, 80736, 80737, 80738, 80739, 80740, 80741, 80742, 80743, 80744, 80745, 80746, 80747, 80748, 80749, 80750, 80751, 80752, 80753, 80754, 80755, 80756, 80757, 80758, 80759, 80760, 80761, 80762, 80763, 80764, 80765, 80766, 80767, 80768, 80769, 80770, 80771, 80772, 80773, 80774, 80775, 80776, 80777, 80778, 80779, 80780, 80781, 80782, 80783, 80784, 80785, 80786, 80787, 80788, 80789, 80790, 80791, 80792, 80793, 80794, 80795, 80796, 80797, 80798, 80799, 80800, 80801, 80802, 80803, 80804, 80805, 80806, 80807, 80808, 80809, 80810, 80811, 80812, 80813, 80814, 80815, 80816, 80817, 80818, 80819, 80820, 80821, 80822, 80823, 80824, 80825, 80826, 80827, 80828, 80829, 80830, 80831, 80832, 80833, 80834, 80835, 80836, 80837, 80838, 80839, 80840, 80841, 80842, 80843, 80844, 80845, 80846, 80847, 80848, 80849, 80850, 80851, 80852, 80853, 80854, 80855, 80856, 80857, 80858, 80859, 80860, 80861, 80862, 80863, 80864, 80865, 80866, 80867, 80868, 80869, 80870, 80871, 80872, 80873, 80874, 80875, 80876, 80877, 80878, 80879, 80880, 80881, 80882, 80883, 80884, 80885, 80886, 80887, 80888, 80889, 80890, 80891, 80892, 80893, 80894, 80895, 80896, 80897, 80898, 80899, 80900, 80901, 80902, 80903, 80904, 80905, 80906, 80907, 80908, 80909, 80910, 80911, 80912, 80913, 80914, 80915, 80916, 80917, 80918, 80919, 80920, 80921, 80922, 80923, 80924, 80925, 80926, 80927, 80928, 80929, 80930, 80931, 80932, 80933, 80934, 80935, 80936, 80937, 80938, 80939, 80940, 80941, 80942, 80943, 80944, 80945, 80946, 80947, 80948, 80949, 80950, 80951, 80952, 80953, 80954, 80955, 80956, 80957, 80958, 80959, 80960, 80961, 80962, 80963, 8

224, 225, 226, 227, 228, and 229 are space-ejector bars. They are constructed, as shown in Fig. 83, wide at the rear end, narrow at the forward end, and still further narrowed at the extreme end and provided with a shoulder of a depth corresponding to the thickness of the space for which each bar is used. The purpose of this shoulder and its thin extreme end is to permit the thin end to lie in the ejector-groove and serve as a guide for the space ejected and at the same time to permit the stiffening of the end of the ejector-bar. Fig. 83 shows one of the bars ejected to its extreme limit, having placed a space upon the word-raceway 209. It will be seen that the space in position to be ejected is held between its adjacent space and the thin end of the ejector-bar under the pressure caused by the weight of the spaces above it. The portion of the bar back of the shoulder being of a width approximately equal to the thin end of the bar plus the space will, when the space is pushed forward, fill the place formerly occupied by the space, and when it recedes the succeeding space will be pushed by the weight of the spaces above it into the position formerly occupied by the space ejected. The rear end of each ejector-bar is provided with a vertically-projecting lug. The space-ejector table (shown in section in Fig. 54) has upon it a series of parallel grooves 230 230, in which the space-ejectors slide and by which they are guided. The space-ejector bars are ejected by a pushing device carried by the ejector-slide 206, which will be hereinafter described, and they are retracted by a pendent flange 231, which depends from the front end of the ejector-slide and extends transversely the whole width of the slide. On the return of the ejector-slide it makes contact with the vertical lugs upon the ejector-bars and carries them back to a uniform position, that position being the one shown in Fig. 83. In the rear end of the ejector-slide 206 there is a groove 232 running longitudinally of the machine and shown in section and in dotted lines in Fig. 54.

Referring to Figs. 55 and 56, 233 is a space-ejector carriage mounted upon a slide 234, which moves in the way 235 under the influence of the rod 121, which is drawn forward by the motion of the dividing-plate carriage, in order to give the space-ejector carriage its primary setting, and the lever 294, by which it is returned to its starting-point, which will be hereinafter described, is operated by a cam on the main line-shaft. On the top of the carriage 233 is a transverse way 236, and in it is a slide 237. Upon the top of the slide 237 is a pin 238, which projects in the groove 232 in the rear end of the space-ejector slide. This pin is surrounded by a sleeve. The motion of the ejector-slide 206 is communicated to the slide 237 by the pin 238, and the groove 232 per-

mits the location of the slide 237 at any point within the extreme limits of the motion of the space-ejector carriage 233. No matter what, therefore, may be the primary setting of the space-ejector carriage 70 the slide 237 will be carried with it in the groove 232, and when the ejector-slide begins to move it will carry the slide 237 back and forth at the point where the primary setting of the ejector-carriage has located it. 75

Referring to Fig. 84, pivoted to the under side of the slide 237 is the space-ejector bar forcer 239. It is located in a groove in the under side of the slide 237 and is permitted a certain amount of lateral motion in said groove in one direction only and held against the side thereof by a spring and supported by a supporting-plate across the groove. Upon the extremity of the ejector-bar forcer 239 is a pendent lug 240 and a pendant knife-edge 241. These are shown in Figs. 84 and 55. The knife-edge 241 is located with its straight side upon the center line of the forcer and its curved side to the exterior of the forcer. 242 242 are a series of stationary knife-edges, 90 one of which is set into each of the parallel ribs which form the grooves 230. The upper surfaces of the knife-edges stand below the level of the tops of the vertically-projecting lugs which are on the rear end of the ejector-bars. These knife-edges are located equal distances apart and form the boundaries of the zones of the space-magazines 210 211, &c., and have their beveled faces facing the beveled face of the knife-edge 241, as shown 100 in Fig. 84. When the slide 237 is advanced, carrying the forcer 239 with it, if the beveled face of knife-edge 241 comes in contact with the beveled face of one of the knife-edges 242 it will be pushed to one side, as 105 shown in Fig. 84, and the forcer will be brought into contact with the space-ejector bar which is on the side toward which the forcer 239 is moved. As now the space-ejector carriage moves step by step, the motion being from left to right, the space-ejector forcer will continue to eject spaces by the operation of the space-ejector bar of the size opposite which it has taken its primary setting, and this will continue until the two 115 knife-edges pass one another without touching, when the forcer having passed into the zone of the next sized space will eject that size space for as many steps as it may take after passing the knife-edge. It will be seen that if the primary setting of the carriage and the ejector-forcer is such that the first thrust is made from a position just beyond the knife-edge all the steps of the carriage will be within the zone of the space-magazine opposite which the primary setting takes place and all the spaces ejected will be of the same size, while if the primary setting be at any intermediate point the carriage will take a certain number of steps 120 125 130

in the zone of one sized space and a certain number in the zone of the next adjacent sized space on the right. No matter how short the step may be if the center line of the stationary knife-edge be passed the carriage will pass from the zone of one sized space to the zone of a thicker space and the number of spaces it will eject of each size will be equal to the number of steps it takes in each zone. This is the operation of ejecting spaces and of insuring the accurate passing of the space-forcer from the zone of one space to the zone of another.

By the term "space-supplying device" used in some of my claims I mean any device which acts either directly or through the intervening mechanism to supply the line with spaces, and it will be noted that this space-supplying device has a movement in two directions—in one direction to position the device so that the proper space may be ejected and in the other direction to eject the space.

I will now describe the mechanism by which the carriage is caused to make a requisite number of steps. It has been seen from the preceding description that usually one space will be ejected for one revolution of the word-shaft; but, as heretofore stated, the word-shaft revolves as many times as there are words in the line, which is one more than the number of spaces wanted. Hence the space-ejector mechanism must be disconnected from the word-shaft for one revolution; but for convenience of structure the stepping mechanism of the carriage is not disconnected, and in order to cause it to make a number of steps equal to the number of spaces within the prescribed distance it is, as heretofore stated, given a primary setting one step too far to the left, so that the first step will bring it to the theoretical position.

Referring to Figs. 50, 51, 52, 53, 54, 55, and 45 56, 250 is a spring-clutch splined upon the word-shaft and connected to the cam-disk 196 by a pin 251. 252 is a lever pivoted at 253 and at its rear end engaging a cam 254, which is timed to operate the lever before the 50 first step of the ejector-carriage takes place. The end of the lever 252 engages a groove in the clutch 250, and when the lever is operated it will throw the pin 251 out of engagement with disk 196 and permit the word-shaft to 55 make a revolution without actuating the space-ejector. In this way the space-ejector carriage is allowed to make one step without ejecting a space. The friction of the pin 251, pressed against the side of the disk 196 by 60 the spring of the clutch 250, might cause it to turn with the shaft, for which reason a spring-catch 196^a is provided to lock the disk. Upon the end of the word-shaft and keyed to it is a beveled gear 255.

65 Referring to Figs. 49, 50, and 51, 256 is a

counter-shaft journaled in brackets 257 and 258. 259 is a second beveled gear keyed upon the shaft 256 and meshing with the gear 255. 260 is a carriage sliding in a way 7c 261 on the table 80. On either end of the carriage 260 is a vertical support 262 262, through which passes the shaft 256. Splined upon the shaft 256 and between the supports 262 262 is a drum 263, provided upon its exterior with a series of nine cams differing 75 from one another in elevation, as shown in Figs. 51 and 54. The altitude of these cams is calculated so as to produce, through the medium of a ratchet mechanism, as step-by-step movement of the space-ejector carriage, 80 the steps differing in length as one or the other of the cams is in engagement with the ratchet mechanism.

I have previously described the means by which the averaging cam-stop 81 is given a 85 setting by the successive action of the space-key. The position of the averaging-cams 263 is dependent upon the location of the stop 81. When the stop 81 has been located by the successive action of the space-key, a 90 pushing device operated from the main line-shaft engages the carriage 260 and pushes the carriage and averaging-cams up against the stop 81. This brings one or the other of the cams into operative relation with the 95 pawl mechanism which operates the space-ejector carriage.

Referring to Fig. 50, 264 is a bar secured to the carriage 260 and projecting over the way in which slides the stop 81. The bar 100 264 extends to the back of the machine and at its rear end is provided with a head 265. Mounted upon the bed of the machine there is a bracket 266, upon which a number of levers are mounted and pivoted for co-operation with cams upon the main line-shaft and elsewhere. 267 is a bracket secured to the bracket 266, and upon the face of it is pivoted a bell-crank lever, having three arms 268, 269, and 270. The operating end of 105 268 stands opposite to the head 265 of the bar 264. 269 has upon it a roller 269^a and extends in the opposite direction and makes contact with the cam 271 on the main line-shaft. The third arm 270 has a spring 272 110 connected to it at one end, the opposite end of which is secured to a bracket projecting from the bed of the machine. The spring 272 keeps the arm 269 in contact with the cam 271 and permits the arm 268 to move 115 the carriage 260 only when the main line-shaft makes a revolution.

Referring to Figs. 54, 55, and 56, 273 is a lever pivoted at 274, one end of which projects over the averaging-cam 263 and is provided 120 with a roller upon its end, the other end of which projects an equal distance in the opposite direction, and is connected to a pawl-lever by a link 276. 275 is a pawl-lever 125 journaled upon the counter-shaft 277, which 130

is journaled in a bracket 278, which depends from the rear end of the space-ejector table 130 at one end and in a pendent bracket 279, secured to the table 266, at the other end. 5 Journalized upon the counter-shaft 277 is a disk 280, which serves as a friction-ratchet. Keyed upon the shaft 277 is a gear-wheel 281. On the under side of the space-ejector carriage is a rack 282, with which the gear 281 meshes, the rack being driven by the gear. 10 283 is a friction-pawl pivoted to the arm 275, making contact with the periphery of the friction-ratchet 280. The pawl 283 is maintained in contact with the friction-ratchet 15 280 by means of a spring. The cam-roller on the end of the pawl-lever 273 is maintained in contact with the averaging-cams by a suitable spring, which also serves to recover the pawl.

20 Referring to Fig. 55, the pawl-lever 275 is journaled upon the hub of the friction ratchet-wheel 280, which projects slightly beyond the eye of the lever. Beyond the hub of the disk and surrounding the shaft 277 is a 25 friction-clutch consisting of the ring 284, which bears against the end of the hub 280, a spring 285, surrounding the shaft and bearing against the ring 284, and a collar 286, keyed upon the shaft 277 and between which 30 and the ring 284 the spring 285 is located.

35 Referring to Fig. 56, 287 is a locking-cam secured upon a counter-shaft 288, journaled in a bracket 289. Secured to the upper end of the counter-shaft 288 is a lever 290, forked at the end and engaging a pin in the end of a pivoted lever 291. The opposite end of 40 291 engages a cam 292 on the main line-shaft. The locking-cam 287 is kept in locking contact with the collar 286 by the spring 293 except when the cam 292 holds it out of engagement with the collar.

45 Referring to Fig. 55, the locking-cam 194, mounted upon a suitable axis, which is journaled in the top of the post 193 at all times, except when the lever 192 is raised by the cam 190, will under the influence of the spring 195 bear against the under side of the friction ratchet-disk 280 and lock it fast 50 against turning.

55 The cam 190 is mounted upon the word-shaft and makes one complete revolution with every revolution of the word-shaft. The pawl and its levers are operated also by the word-shaft, and the averaging-cams are so constructed that they will operate the pawl to set forward the friction ratchet-wheel and also permit it to be recoiled in readiness for another step with each revolution. The cam 190 is so proportioned that 60 during the period when the pawl has taken a bite upon the ratchet-wheel and is moving it forward the cam 194 will be out of contact with the ratchet-wheel 280, and it will be free to move. The friction-ratchet, however, 65 is journaled loosely upon the shaft 277 and

only communicates motion to the gear-wheel 181 by means of friction which is created by the spring 285 pressing the ratchet-wheel against a friction-disk 299, keyed to shaft 277. The gear-wheel 281, the friction-disk 299, and the collar 286 are all three keyed to the shaft 277 and turn with it. The friction-clutch formed by the friction-ratchet 280 and the friction-disk 299 will permit the shaft 277 to turn freely while the friction-ratchet is 70 locked, when the space-ejector carriage is moved on its ways by the dividing-plates or its recovering-lever 294. It is of great importance that the motion of the space-ejector carriage should be regulated with great accuracy and that it should not be moved except at predetermined periods and distances. Hence the friction-ratchet as soon as it has made a step is locked by the locking-cam 194, controlled by cam 190, and held fast 80 until the pawl has taken a fresh bite of the ratchet-wheel and is ready to move it forward another step, when the cam 194 releases it.

85 When the carriage 233, under the influence of the ratchet-wheel 280 and the motion of 90 the pawl 283, actuated by the averaging-cam, has made all of its steps and has reached the limit of its motion, it is necessary to restore it to its primary position to begin the justification of the next line. This is done by lever 95 294, the extreme end of which contacts with a pin 295, which depends from the rear side of the carriage 233. The lever 294 is pivoted at 296 on the bracket 266, and the rear end is provided with a cam-roller 297, contacting 100 with a cam 298, mounted upon the main line-shaft. The cam 298 has a very acute portion, which occupies but a few degrees of the periphery of the cam. The action of the lever 294, therefore, is quick, and all the balance of 105 the portion of the revolution of the main line-shaft does not move the lever 294 at all, but leaves it free. It is, however, pushed before it by the carriage 233 and remains in contact with the pin 295 ready to restore the carriage 110 as soon as the elevated part of the cam 298 strikes the roller 297.

115 Referring to Fig. 43, it will be seen that when the cam 110 turns so as to escape the cam - lever 108 the weight and spring 104 will suddenly force the dividing-plate carriage 99 forward into the space between the gage-block 409 and the way of the dividing-plate carriage. This action will jam the bevelled plate which is in contact with the gage-block so tight into the space as to require 120 exertion of considerable force to withdraw it. The forward motion of the dividing-plate carriage will, as heretofore described, through the medium of the rack 116, pinion 118, and pinion 119 and the rack 120, give to the space-ejector carriage a primary setting, which must not be altered except by the forward 125 stepping mechanism, or the operation of justification will be disturbed and the result 130

destroyed. The rod 121 slides freely through the space-ejector carriage and moves it only when the nuts 300 make contact with the rear end of the carriage 233. The rod may 5 recede through the carriage without moving it. It will therefore be seen that it is essential after the dividing-plates have come to rest against the gage-block that they should never advance the slightest degree beyond 10 that position or they will alter the primary setting of the ejector-carriage. The tight wedging of the dividing-plate between its way and the gage-block makes it impracticable 15 to recoil the dividing-plate carriage, even by the use of the cam 110 and its connecting-levers, until it is released by the gage-block. To accomplish this result, the gage-block is withdrawn. The dividing-plate carriage, under 20 the influence of the weights and springs 104, would have a tendency to move immediately forward, and if it did so it would disturb the primary setting of the space-ejector carriage. This is prevented by the locking of the space-ejector carriage; but in order to insure that 25 the first motion of the dividing-plate carriage will be under the influence of the cam 110 and will be a backward motion and not a forward motion the space-ejector carriage after having received the primary setting is locked 30 and maintained locked until the cam 110 has begun to move the dividing-plate carriage backward.

The locking of the space-ejector carriage is accomplished in the manner above described. The gear 281, which meshes with the rack 282 of the same ejector-carriage and which has to move with it, is keyed upon the shaft 277. The collar 286 is also keyed upon that shaft 277 and has to move with it. 35 The locking mechanism heretofore described, consisting of the cam 287 and the levers 290 and 291, will normally maintain the shaft 277 and space-ejector carriage stationary, and this condition will continue at all times, except when the cam 292 on main line-shaft 40 contacts with and moves the lever 291. The cam 292 is so timed that immediately after the cam 110 has released the lever 108 and permitted the dividing-plate carriage to 45 thrust forward into contact with the gage-block and set the ejector-carriage the lever 291 (shown in Fig. 56) will, under the influence of the spring 293, drop off of the end of the cam 292 and the ejector-carriage will 50 be locked. This condition will continue until the main-line shaft has nearly completed its revolution, and during that period the gage-block will have been moved away from contact with the dividing-plate and the 55 cam 110 will have restored the dividing-plates to their primary position.

I have heretofore described the setting of the type, the insertion of false spaces, the work performed by the space-key in stepping 60 up the dividing-plate carriage, the averaging-

cam stop, and the index mechanism. I have also described the details of structure of the dividing-plates and their method of operation, the averaging-cam stop and its method of operation, the averaging-cams and their 70 method of operation, the index mechanism and its method of operation, the space-ejector carriage, and the mechanism by which it is given a primary setting, the word-shaft, and its connecting parts by which the 75 space-ejector carriage is stepped forward and operated to eject a suitable number of properly-selected spaces for justification.

There is another possible error which must be guarded against. The space-ejector carriage when drawn forward by the dividing-plate carriage and the rod 121 is moved very rapidly and being quite heavy would be likely to overthrow—that is, to be carried by its momentum beyond the point at which the 80 rod stops. To prevent this overthrow, a locking device is provided by which the carriage is locked to the rod whenever the nuts 300 are in contact with the rear side of the carriage. The structure shown in the drawings, Fig. 54, consists of a notch 121^a in the rod 121 and a latch 121^b in the carriage 233, held down by a spring 121^c.

It will be perceived that in order that the type-setter may not be delayed, that as soon as one line has left the pivoted stick the stick must return to its receiving position and the operation of setting go on without delay. The action of stepping the dividing-plate carriage up to the proper level stepping 100 the averaging-cam stop to its proper position, and stepping the index mechanism to its proper position is all done while the line is being set through the medium of the space-key and the pawls and counter-shafts connected with it. When the line is finished, it is necessary for the dividing-plate carriage to travel rapidly forward into the space between the gage-block and the ways of the carriage, and thereby to give the space-ejector carriage 105 a primary setting. At the same instant the averaging-cams must be moved up against the averaging-cam stop and the index mechanism must be shifted so as to throw the ratchet and its connected part, 110 which have been previously operated, into engagement with the train of gears connected to the word-shaft. The instant after this action has taken place the dividing-plates must be released and must return to their 115 primary position to receive a setting from the space-key when the next word is set. The averaging-cam stop must also simultaneously return to its primary position to begin its setting for the next line.

Referring to Figs. 36, 37, and 51, it will be seen that the ratchet-wheel 71 is loosely journaled upon the shaft 72, but is held against rotation by the pawl 66 and the dog 73. The side of the ratchet-wheel 71 is provided with 120

a series of holes 309, twenty-four in number and corresponding in number and location with the teeth of the ratchet. From the side of the clutch-disk 77 projects a pin 310, capable of engaging any one of the holes 309. The clutch-disk 77 is splined upon the shaft 72 and turned by it. When the pin 310 is in engagement with the ratchet, the ratchet will turn the shaft and its connecting parts. When it is disengaged, the ratchet being held stationary by its pawl and dog, the shaft and its connecting parts are free to move independently of the ratchet. The mechanism for shifting the disk 77 is shown in Figs. 36, 37, 50, and 51. 311 is a lever pivoted upon a bracket 312. The lower end of the lever has a pin which engages the groove of the disk 77. The upper end has a pin which engages the groove of a cam 313 on the main line-shaft. The groove of the cam 313 is so constructed as to maintain the disk 77 in contact with the ratchet through the whole of its revolution, except during a short period, when it is necessary that it should be disengaged in order that the dividing-plate carriage and averaging-cam stop may be recoiled to their primary position to begin receiving actuating impulses from the space-bar. Figs. 36 and 37 also show views of cam 313 disconnected from the shaft and in position opposite to the position shown in those figures. The number of holes in the side of the ratchet-wheel 71 being equal to the number of teeth in the ratchet, as the ratchet is turned one twenty-fourth of a revolution at each step. When the disk is disengaged from the ratchet, the ratchet will stand still, but the disk will at once return to its primary position with the dividing-plates, and in this position the pin will register with a hole in the ratchet and when the disk is thrown will enter it and lock the disk to the ratchet.

It will be noticed that immediately after the averaging-cams have been given their setting and have begun to operate upon the pawl-lever for stepping forward the ejector-carriage the averaging-cam stop recedes to its primary position and with the beginning of the setting of the new line it will begin to advance toward the averaging-cam carriage. If the period of time during which the justifying-spaces are being ejected was long enough to allow the averaging-cam stop to overtake the carriage, it would push the carriage before it and throw the cam in operation out of engagement with the pawl-lever and destroy the justification. These parts have to be timed, therefore, so that the averaging-cams will have finished their operation before the averaging-cam stop reaches the carriage. This is done by variation of speed. Experience has demonstrated that the time required to set the first four words of any line, however small they may be, is long

enough to accomplish the ejection of the justifying-spaces, no matter what their number may be, and as the lowest cam on the machine is a twelve-word cam—that is to say, adapted for the ejection of eleven spaces—the time required to set five words is always sufficient to permit the completion of the ejection of the spaces for twelve words. The averaging-cams will therefore always have finished the line before they can be overtaken by the averaging-cam stop. The machine as shown in the drawings does not illustrate a stop; but such a stop might be arranged so as to make it impossible for the setter to step forward the averaging-cam stop fast enough to disturb the primary setting of the averaging-cam carriage. The same is true of the recoiling of the averaging-cam stop and the dividing-plate carriage. It is possible to conceive a condition under which the setter might be operated to set type and require the operation of the space-key before the averaging-cam stop and the dividing-plate carriage had returned to their primary position and the clutch 77 reengaged the ratchet-wheel. In such event the ratchet will be moved forward without communicating its motion to the dividing-plate carriage or averaging-cam stop, and the justification would fail. This can be regulated by the introduction of a locking mechanism by which the space-bar will be locked when the ratchet is out of engagement with the clutch 77 and unlocked only when it is reengaged; but such locking mechanism is not essential, as the parts are timed to perform their several functions in succession without interfering with one another. I have now described all the mechanism necessary for the selection and ejection of the proper spaces to justify a line whether they be of the same size or varying sizes.

Caliper mechanism.—I come now to the caliper devices—that is to say, the devices by which the length of the line is measured and the gage-block is set so as to form the space into which the dividing-plate is thrust, by which action the space-ejector carriage is given a primary setting.

Referring to Figs. 15, 16, 17, 18, 19, 20, 21, and 22, I will first indicate the structure of the line-carrier, which is the mechanism into which the line is pushed upon leaving the stick and by which it is carried bodily from the caliper mechanism to the word-separating mechanism. 314 is a drum on the main line-shaft, having a cam-groove cut in its periphery. This structure is shown in detail in Figs. 2 and 15. Pivoted in the brackets 315 and 316 is a rock-shaft 317, upon the lower end of which is secured an arm 318, having a pin in its end 319, which takes into and is moved by the cam-groove of the drum 314. On the upper end of the shaft 317 is a segment of a beveled gear 320. Journaled in another arm of the same bracket

316 is a counter-shaft 321, upon the rear end of which is a segment of a beveled gear 322. The segments of gears 320 and 322 are shown in face elevation in Fig. 17. Upon the front end of the counter-shaft 321 is secured a carrier-arm 323, which extends downward on the front of the machine and has on its lower end a slotted section 324, which forms a guide for a sliding block 325, through which loosely passes the bolt 326, which is screwed into the line-carrier 327.

Referring to Fig. 1, extending across the front of the machine is a way 329, on which the line-carrier 327 is mounted and travels from the position in which it receives the line to the position in which it delivers it to the word-separating device. Above the way 329 is mounted another way 328, parallel to 329, which stands above the line-carrier. The space between these ways 328 and 329 is called the "line-raceway." Referring to Fig. 18, which is a transverse section of the ways in full size, it will be seen that the lower way 329 has a longitudinal groove cut in each of its sides near the top. Embracing the way 329 is the line-carrier 327, which has pendent flanges on the two sides with inwardly-projecting lugs and a vertical flange upon its upper rear edge, which forms an alining stop, against which the type may be pushed as they pass the presser-rolls, which are in front. Fig. 19 is a plan view of the line-carrier 327. It has an open slot in each end 330 and 331. Within the slot 331 is a pivoted pawl 332, maintained normally in a position of maximum elevation by a spring, the position being limited by a stop, Figs. 20 and 22. The pawl projects upward into the path of the types and lies behind them after they have passed over it, so as to resist the pressure of the caliper-head when it comes in contact with the type. 332^a 332^a are a pair of friction-plates lying in parallel grooves in the face of the line-carrier 327 and on each side of the slot 330. They are pointed at their ends toward the pawl and are sustained slightly above the surface of the carrier by springs. They serve to exert upon the forward end of the line a small amount of friction. The line when pushed onto the carrier lies between it and the upper way 328.

Before proceeding to the description of the caliper-head and the mechanisms which come into play in the subsequent operation of the machine I will turn for a moment to consider the structure which I think necessary to describe in connection with the type-setting and the delivery of the line to the pivoted stick and the devices for moving it from its vertical to its horizontal position. When the type are swept from one side or the other to the center of the machine, they are left in the raceway of the setter immediately over the mouth of the stick. They are pressed down into the stick by a depressing-blade. The de-

pressing-blade has two motions. Under normal conditions with each stroke of the type-forcer it is thrust downward, so as to press each individual type out of the path of the succeeding one; but when the line is completed it is necessary for the depressing-blade to press the whole line of type down out of the stationary part of the stick into the movable part of the stick, so as to enable the movable part of the stick when it moves to carry the whole line with it. This is accomplished by a mechanism which is shown in Figs. 5, 6, and 7. Referring to Figs. 23 and 24, 340 is the stationary part of the stick. On one side of the mouth of the stick is a shutter 341, pivoted in the recess in the block which constitutes one side of the mouth of the stick and pressed upward by a spring, so as to maintain a horizontal position across the mouth of the stick, as shown by Fig. 23. Back of the pivot of the shutter 341 is a shoulder in the recess, which limits the motion of the shutter against the upper pressing of its spring and keeps it horizontal. In the block which forms the opposite side of the mouth of the stick is a friction-plate 342, held in place by two screws 343 343. The shutter 341 is of such a length that when in a horizontal position it will close the mouth of the stick, making contact with the friction-plate. On the face of the wall of the stick above the shutter and on the shutter side there is a shoulder 344, which is located below the top of the stick a distance somewhat above the point reached by the depressor-blade in making its thrust for individual type. When a type is swept to the center of the raceway by one of the type-forcers, it is left in the position shown in Fig. 23, resting upon the shutter 341 and against the side of the friction-plate 342. The depressor-blade then presses it and the shutter downward a distance sufficient to enable the type to catch under the shoulder 344. The type is meanwhile pressed upward by the shutter 341, and is thus held between a pressure and resistance, so as to support it from falling. The second, third, and fourth types are treated in the same way with the same result until the type in the stick passes below the end of the shutter, when the friction-plate 342 will press them against the opposite wall of the stick and hold them fast. This structure is not essential, but may be varied in many ways.

Referring to Fig. 5, the type-depressing bar is numbered 345. It is pivoted to the end of the lever 346 and is guided in a groove in the back of the type-forcer guide 44. Upon the lower end of the bar 345 is a foot or blade 347, which is somewhat thinner than the width of the type and is bifurcated in its center, so that it touches the type at two points only—i. e., near their two ends. The purpose of the slotting of this blade is to permit the friction-bars 14 14 or parts connected to them to

pass through it. The lever 346 is pivoted at 348 upon a bracket secured to the main supports 2 2 of the setter. The lever is provided with a cam-roller 349, which makes contact 5 with the cam 350 on the driving-shaft 3. By this cam the lever is caused to make two motions with every revolution of the shaft. It will be remembered that with each complete reciprocation of the type-forcers two types 10 may be delivered at the center of the raceway. It is necessary, therefore, that each of these types should be pressed into the stick at the instant at which it arrives at the center of the raceway. Therefore the cam 350 is given two 15 elevations of equal size, so as to give the type-depressor bar two motions for each complete reciprocation of the type-forcer. On the rear end of the lever 346 is a projecting pin and cam-roller 351, which stands in the path of the 20 cam 352. The cam 352 is on the main line-shaft, and when the main line-shaft is set in motion by the action of the justifying-key the cam 352 will strike roller 351, raise the rear end of the lever 346, and depress the front 25 end far enough to force the contents of the stick down into the pivoted or movable portion of the stick and out of the stationary portion. The cam 352 is very acute, and as soon as it has passed the end of the lever 346 that 30 lever will instantly drop back on the cam 350 and continue its short reciprocation.

I will now describe the mechanism for moving the pivoted stick.

Referring to Figs. 13, 14, and 21, 355 is the 35 pivoted portion of the stick pivoted at 356. 357 is a link pivoted to the stick 358 at one end and at the other end to a reciprocating rod 359. The rod 359 lies in a groove in the upper side of the way 328 and on its rear end 40 is provided with a vertically-projecting pin 360. 361 is a bell-crank lever pivoted at 362 upon the bracket 363, secured on the inside of the main bracket 2. One end of the bell-crank lever has a slot which engages the pin 45 360, and to the other end is secured a rod 364, which extends to the rear of the machine and is connected at its opposite end to one arm of the bell-crank lever 365. To the same arm is attached spring 366, the opposite end of 50 which is secured to the bed of machine. The other arm of the bell-crank 365 is provided upon its end with a cam-roller 367, which is held in contact with the cam 368 by the spring 366 and maintains the pivoted stick 55 under the control of the cam. The cam 368 is so formed that with a revolution of the main line-shaft it will turn the pivoted stick from its vertical to its horizontal position, maintain it there for a period of about one- 60 third of a revolution of the main line-shaft, and then return it to its former position, when the main line-shaft will stop and the stick will remain in its vertical position until filled with a new line of type and the main 65 line-shaft is started again.

Secured upon the front of the type-setter frame is a bracket 370, Fig. 13, which extends half-way across the front of the machine and which forms a way for the line-pusher bar 371. The line-pusher bar is fitted 70 into dovetailed ways on the bracket 370. To the right-hand end of the line-pusher bar 371 is secured a rod 372. Referring to Fig. 3, the opposite end of the rod 372 is secured to a lever 373, pivoted upon a bracket 374, and 75 upon the rear end of the lever is a vertically-projecting pin 375, which takes into a cam-groove of the cam 376, which is secured upon the main line-shaft. The cam 376 is so located on the main line-shaft that after the 80 pivoted stick has been moved by the cam 368 into a horizontal position the cam 376 will move the lever 373 and the line-pusher bar 371 (shown in Fig. 13) forward into the open end of the pivoted stick 355, as shown in Fig. 85 21, and push the whole line into the line-carrier 327 until the last type has passed beyond the pawl 332 of the line-carrier, when the pawl will rise behind the type through a 90 slot in the end of the line-pusher, and the 95 line-pusher will be withdrawn to its normal position in a position to prevent the line from being pushed by the caliper-head farther back than the end of the pawl.

Fig. 21: 381 is the caliper-bar, made in 95 two pieces which are secured together by a thumb-screw 382. The mechanism by which the caliper-bar is operated is secured to that portion of the caliper-bar marked 383, while the caliper-head is secured to the 100 other part 381. In the position shown in the drawings, Fig. 21, the two parts of the caliper-bar are in the position to receive and to measure a line of maximum length. If the caliper-bar be extended by unscrewing the 105 thumb-screw 382 and moving the forward end of the caliper-bar forward and then setting the screw so as to elongate the bar, the caliper-head will be moved forward and its setting will determine the length of the line, 110 shortening the standard as the caliper-bar is elongated. In this manner the length of the line being set may be changed at will, so as to cause any desired inset for widening the margin or insetting an illustration, or if the dividing-plates by reason of a defective adjustment are introducing too much or too little space the error can be readily compensated for by lengthening or shortening the standard 115 by a readjustment of the caliper-head. 384 120 is a lug depending from the under side of the caliper-bar having vertical slots on each side which extend across the lug and the bar. (Shown in section in Figs. 47 and 48.) In these slots the two side bars of which the caliper-head is formed fit and slide. The caliper-head is formed, as shown in Fig. 47, of two plates secured together at top and bottom, and between them is a portion of the caliper-bar, which limits the motion of the caliper- 130

head. The lower lineway 329 has a longitudinal slot 380 through which the caliper-head reciprocates, as well as through the slot 330 in the end of the line-carrier. When in its 5 elevated position, as shown in Figs. 21 and 45, the caliper-head will stand in the path of the line of type. At its lower end the caliper-head has a projecting arm perforated with an elongated eye 386, through which it passes a crank-bar 387, upon which it slides freely back and forth under the influence of the caliper-bar. 388, 388 are two cranks keyed upon the rock-shaft 389, which is journaled in brackets upon the front plate of the 15 machine. 390 is a crank also secured to the shaft 389 and to the lower end of which is connected a rod 391. (Shown in Fig. 46.) The other end of the rod 391 is pivoted to an arm 392, which is journaled at 393 upon a bracket 20 394 upon the back of the machine. The free end of the arm 392 is provided with a cam-roller 395, which stands in the path of the cam 396 and is operated by it. The revolution of the cam 396 will cause the caliper-head 25 385 to rise to its point of maximum elevation into the path of the type, where it will be maintained for a length of time sufficient to enable the line-pusher to force the line of type against it and force it back by 30 the line until the line has passed its pawl or dog, when the pawl or dog will rise behind it and the spring 405^a will force the caliper-head against the line and the line against the pawl or dog, and thus measure the line and 35 give to the gage-block a setting dependent upon the length of the line.

The part 383, Fig. 21, of the caliper-bar is provided with a pendent lug 398. 399 is a lever pivoted at 400 on the frame of the machine. The upper end of the lever 399 is connected to the pendent lug 398 by means of a pin 401, upon which is journaled a square block 402. It slides in a guideway having parallel walls in the end of the lever 399. 40 45 By a similar construction the lower end of the lever 399 is connected to a bar 403, which reciprocates in staples 404, 404. The end of the bar 403, Fig. 37, is enlarged and slotted horizontally, so as to receive the end of the 50 gage-block lever 405, which is also provided with a squared way in its end, and a block sliding in said way, which is journaled upon a pin passing through the end of the bar 403. This provides for the change of motion from 55 a straight line to the arc of a circle. The gage-block lever is pivoted at 406 and is provided at its opposite end with a square slot, which is the guide for a block journaled upon a pin which passes through the block and 60 through the gage-block bar 407. The gage-block bar is guided in a staple 408 and in the locking device.

405^a is a spring secured to the gage-block lever at one end and to the machine-bed at the other. This spring serves the very im-

portant function of pressing the caliper-head against the type when they are pushed into the carrier by the line-pusher. It maintains a constant pressure upon the caliper-head and type until the gage-block is locked. As 70 soon as the gage-block has been locked the caliper-head descends and leaves the line-carrier free to move through the line-race-way.

409 is a gage-block pivoted upon the end 75 of the gage-block bar 407 and moved back and forth by the lever 405. The gage-block 409 may consist of a plate of hardened steel mounted in a frame and suitably pivoted on the end of the gage-block bar 407; but I prefer 80 to provide this block with a cushioned face, as shown in Fig. 94.

409 is a block pivoted to the end of the bar 407 and having a U-shaped face-plate 409^a, supported on springs 409^b and guided 85 in slots 409^c in the sides of the block 409. This cushion serves to steady the motion of the dividing-plates and causes them to come to a bearing on the gage-block without jar. The purpose of the gage-block, as heretofore 90 stated, is to form the movable side of the two fixed surfaces between which the dividing-plates are thrust to give a primary setting to the ejector-carriage, one being the ways of the dividing-plate carriage, which are stationary, and the other the gage-block, which is movable and which by its connections with the caliper-head will be moved in proportion to the caliper-head. The distance between the gage-block and the dividing-plate ways will 95 vary with the gap or difference between the length of the actual line and the length of the standard line. After the gage-block has been set it must be locked in its set position, because the dividing-plate carriage and its 100 dividing-plates are thrown against the gage-block with so much force that the gage-block must be for the moment stationary. Many forms of mechanism might be employed to lock the gage-block, and therefore I have 105 claimed the gage-block in combination with means for locking it; but I employ a structure (shown in the drawings, Figs. 36 and 37) which serves the purpose. Fig. 36 shows the gage-block in an unlocked position; Fig. 37, 110 in a locked position. The gage-block is locked by means of a spring and wedge. The unlocking is done by the action of a cam 415 on the drum 314. Fig. 43 shows a side elevation of the cam.

Referring to Figs. 36, 37, and 43, 410 is a block secured to the bed of the setter-table, the location of which is shown in section in Fig. 43. The block is pierced with two slots 115 at right angles to one another. The gage-block bar 407 passes through one of them and a wedge 411 through the other above the gage-block bar. The wedge when thrust into its keeper above the gage-block bar will lock 125 the gage-block bar firmly in its place and 130

hold it until the wedge is released. The locking must be very secure; but the locking and unlocking must be done suddenly. This is accomplished in the following manner: 412 is a lever secured to the wedge 411 at one end and at the other to a bar 414. The bar 414 passes through a keeper, and its end is curved out of line to stand in the path of the cam on the drum 314. 415 is a cam. (Shown in side elevation in Fig. 43.) It is of uniform height and extends about two-thirds of the periphery of the drum, being calculated to keep the gage-block unlocked at all times except for a brief period during which the dividing-plates are being thrust forward. The curved end of the bar 414 stands in the path of the cam 415. 416 is a spring, one end of which is connected to the lever 412 and the other end to a stationary point on the table of the machine. The pull of the spring will force the wedge into its keeper and lock the gage-block as soon as the end of the bar 414 falls off of the cam 415. Figs. 36 and 43 show the cam in contact with the end of rod 414 and the gage-block unlocked. Fig. 37 shows the end of rod 414 out of contact with the cam 415 and the gage-block locked by the action of spring.

Justification.—The construction and operation of the device by which the line is set and measured and the dividing-plates, averaging-cam stop, and index mechanism stepped forward by the operation of the space-bar have been traced. The action of the justifier line-key will now start the main line-shaft and actuate all of its connecting mechanism, and it remains now to follow the line after it enters the line-carrier to the end of its course, where it is divided into words, a predetermined number of true spaces inserted in place of the false spaces, the false spaces withdrawn, and the line delivered in the galley. The line when first formed contains false spaces and one additional, which, with the type and quads, will make a line approximating in length the standard, and seldom will two lines have the same length. It is necessary, therefore, to remove false spaces and replace them with spaces of a calculated thickness, but which in the aggregate will justify the line and cause it to have the same length as all other lines. In order to do this, it has been found convenient to divide the line in its course from the setter to the galley into words; but as each word is accompanied by one of the false spaces it must be withdrawn when the word is separated and a true space introduced in its place. To separate the line into words, a separate word-raceway is employed, different from and on a different level from the line-raceway. The words are pushed from the line-carrier out of the line-raceway onto a word lifter and then raised up to the level of the word-raceway, when the word-forcer engages them and forces them to

the end of the word-raceway. The separation of the line into words is accomplished by the coöperation of an auxiliary line-pusher, a word-lifter, and a word-forcer. These mechanisms will be described in their order. 70

An auxiliary line-pusher.—The auxiliary line-pusher is shown in Figs. 25, 27, 31, and 32. It consists of a slide 422^a, mounted in a slot in the upper side of the way 328 and provided on its lower forward end with a pivoted tongue 423^b, the lower side of which at the pivot is slightly above the level of the lower surface of the upper side of the line-raceway, so as not to obstruct the passage of the type. The forward end drops to the level of the surface of the line-carrier, so as to fall behind the type when they pass under it. The slide 422^a is T-shaped in cross-section, and its two arms rest upon the top of the upper way 328. Upon the upper side of the slide is the rack 424^b. 426^b is a counter-shaft mounted in suitable bracket-bearings 426^d. 425^b is a pinion keyed on said shaft and meshing with the rack 424^b. On the same shaft is a sheave 427^b, loosely journaled, but held between a friction-clutch 428^a, Fig. 2, which may be tightened so as to exert any desired pressure upon the sheave, but permit it to slip when a certain resistance is presented to the line of type upon which the auxiliary line-pusher is 95 bearing. The sheave 417 drives the sheave 427^b from the averaging-cam shaft by a belt 429^c. After the whole line has been pushed onto the lifting-table the parts must be restored to their primary position for another 100 line. The auxiliary pusher is restored by the backward motion of the line-carrier. The structure is as follows: To the rear side of the slide 422^a is secured a pendent flange 428^b, (shown in dotted lines,) to the lower end of 105 which is pivoted a hook 429^d. From the side of the hook projects a pin 430, which enters a groove 430^a in the rear side of the upper way. The groove is horizontal for a part of its course and is then slightly inclined upward, 110 so that as the pin on the side of the hook passes into the inclined portion of the groove it will raise the hook out of the path of the line-carrier when the line-carrier is swept through the line-raceway by its arm, and it 115 will engage the hook 429^d and carry the slide 422^a and its auxiliary line-pusher back until the hook is lifted by its groove out of the path of the carrier, at which point it is ready to advance again to push another line when the 120 word-shaft is again turned.

The word-lifter.—Referring to Figs. 25 to 34, inclusive, the counter-shaft 256 is geared to the word-shaft by means of a pair of beveled gears 255 and 259, which are of equal 125 size, so that the counter-shaft turns in unison with the word-shaft. On the front end of the counter-shaft 256 is keyed a cam-wheel 418, which has a cam-groove on each of its faces. The rear one operates the word-lifter 130

and is marked 419. The front one is marked 429^b. To the under side of the lower way of the line-raceway 329 is secured a pendent bracket 420, upon which is pivoted a lever 421, one end of which is provided with a projecting pin and cam-roller 422, which enters the cam-groove 419, by which the lever 421 and its connected parts are operated. The opposite end of the lever is forked, and in the fork is a sliding block 423, to which is pivoted the post 424 of the word-lifter.

Referring to Fig. 32, in this figure the end of the line-raceway and line-carrier, and the beginning of the word-raceway, the word-lifter, and presser-plate, and the auxiliary line-pusher are shown in section. 425 and 426 are the lower and upper ways of the word-raceway. The lower one, 425, overlies, and is supported by the lower lineway 329, and its end forms a stop for the line-carrier 327, Fig. 29. The upper surface of the lower lineway 425 is provided with a longitudinal recess narrower than its width, and in it fits and rests the word-lifter plate 427, which is mounted on the upper end of the word-lifter post 424. The surface of the word-lifter when in its recess is below or on the same level with the surface of the wordway 425 and the line-carrier. The surface of the end of the lower wordway 425 is of the same level as upper surface of the line-carrier, so that the types may be forced on the same level from the line-carrier to the word-raceway over the word-lifter. On the edges of the line-raceway, on each side of the recess in which rests the word-lifter plate, are wards 428, 428, which project upward into the path of the type. The types used in the machine are all provided with two nicks on their lower sides, as shown in Fig. 30. These nicks are provided for the purpose of allowing the type to pass over the wards 428. The false spaces which are inserted in the line by the setter are not provided with any such nicks, hence will be stopped by the wards. The wards are located a distance from the end of the word-lifter plate equal to the width of one of the false spaces. For this reason a word of types and one false space may be forced over the word-lifter; but the succeeding words will be stopped by the wards engaging the unnicked false space, and when the resistance of the wards stops the auxiliary line-pusher, its driving mechanism running so long as the word-shaft turns, will, through the friction-clutch, which is set to resist a pressure insufficient to injure the type or pushing mechanism, permit the driving mechanism to slip and injury to the types will be prevented, but a constant and uniform pressure will be maintained upon the types in the line-carrier and lineway. Immediately above the lifter and set into a recess in the upper wordway 426 is a spring-actuated follower or friction device 429, which follows the motion of the word-

lifter and maintains the type under constant pressure when raised from the level of the lineway to the level of the wordway. The follower 429 consists of a plate set in a recess in the under side of the upper wordway 426 and shown in detail in Fig. 32. The plate is supported by screws which limits its motion, and it is pressed downward by a spring. The normal position of the follower is shown in Figs. 25 and 27 and its elevated position in Figs. 31, 32, and 33. Secured to the under side of the follower is a flat steel spring 429^a, which normally hangs down in the path of the advancing type and exerts a slight friction upon them to prevent their being displaced as they are pushed into the wordway. 429^b 429^c are a series of friction-plates, similar in construction to 429, set in a groove in the under side of the wordway 426, supported by screws and pushed downward by springs. 85 Their lower surfaces extend but slightly below the surface of the way 426, the end toward the galley being lower than that toward the word-lifter, the latter end being slightly above the lower surface of the way 426. The last of these friction-plates is shown in Fig. 70, where it is illustrated as standing in the path of the type and forming a dog which falls behind the line of type when it is pressed into the galley and when the false space is withdrawn and prevents the line of type being pushed from the galley by the line-follower when the false-space extractor is retracted and before the line-depressor has forced the line into the galley. The cam 418 being geared to the word-shaft will make as many revolutions as the word-shaft, and as the index mechanism when the line was set was also set to cause the word-shaft to revolve the same number of times as there are 100 words in the line the cam 418 will turn and the word-lifter moved by it will rise and fall a number of times equal to the number of words in the line. Hence when the line word by word is pushed over the word-lifter the word-lifter is already geared to lift each word successively to the level of the wordways, where the word-carrier forces it through the wordways, the false space is withdrawn and a true space inserted, and the word delivered 115 to the galley. The wards 428 being on the sides of the wordway and not on the word-lifter, when the word is lifted up to the level of the upper wordway the types which constitute it and the unnicked false space will be 120 carried above the level and free of the wards. The end of the word-lifter will stop the succeeding word until the word-lifter returns to the level of the line-carrier, when the next word will be immediately forced onto the word-lifter by the auxiliary line-pusher, and as soon as the word-carrier has returned to its primary position the word-lifter will rise 125 and carry another word upon it up to the level of the lineway. 130

Word-forcer. (Figs. 31, 33, 34, and 35.)—This device forces the word through the wordway from the word-lifter to the galley. On the front face of the cam 418 is a cam-groove 429^b. Upon the pendent bracket 420 is pivoted lever 430^b, the full connection of which is shown in Fig. 1. It is a lever of the third kind. To its center, upon a stud, is journaled a friction-roller 431, and to the lower end is pivoted a connecting-rod 432. 433 is a lever pivoted to a bracket 434 on the bed of the machine and the upper edge of which is pivoted to the word-forcer 435. The levers 430^b and 433 are connected by the connecting-rod 432. The lever 433 is made in two sections, the end telescoping into the lower portion, so as to take up the curve of the end of the lever and convert it into a horizontal motion, so that it may drive the word-forcer upon the ways. The word-forcer 435 is mounted on the top of the way 426, Fig. 34, and overhangs its edges, guided by grooves 436 in the sides of the way, into which the overhanging sides of the forcer enter. On the side of the forcer is a pin 437, to which the lever 433 is pivoted and by which the forcer is driven. 438 439 are the feet of the forcer, which are made vertically adjustable. They extend down on each side of the way 426 and strike the false space behind the word on both ends to sweep it and the word before it through the word-raceway. The word-forcer, like the word-lifter, is, as above described, actuated by the word-shaft and makes one stroke with each revolution of the word-shaft, which, through the control of the index mechanism, makes revolutions equal in number to the words in the set line. Its motion is so timed by the location of its actuating-cam groove that it will occupy the position shown in Fig. 25 when the word-lifter is in the position of that figure and also of Fig. 31. It will then travel forward and sweep the type off of the lifting-table and carry them to the end of the word-raceway to the position shown in Fig. 1. The word-lifter will then fall to its primary level, and the auxiliary line-pusher will at once push another word on to the lifter as far as the false space will permit, Fig. 28. It will be remembered that the space-ejector mechanism is arranged so as to skip its action for the first revolution of the word-shaft. Hence it will not eject a true space into the word-raceway as the first word is swept by. The first word has, however, carried a false space with it. This is removed at the end of the raceway by a mechanism which will be hereinafter described. When the second word comes along, before it reaches the space-ejector a true space will be ejected into the raceway and be carried along ahead of the second word. Thus the first and second words will have a true space between them. The second word will also carry with it a false

space, which when it arrives at the end of the raceway is withdrawn, and so on for the whole length of the line.

False-space extractor.—It has been stated at a previous stage of this specification that when the line is set false spaces of uniform thickness are inserted between the words, that these spaces are inserted to enable the line to be divided into words, and that they are carried to the end of the word-raceway and then withdrawn. This latter action is accomplished by a mechanism shown in Figs. 57 to 65. Fig. 57 is a cross-section of the machine made by a vertical plane crossing between the space-ejector mechanism and the false-space extractor. Fig. 64 is a plan of the same mechanism, and Fig. 65 an enlarged plan. 123 is the word-shaft. On it is secured a cam 440, the edge of which serves to operate a lever to reciprocate the false-space extractor into and out of the raceway—i. e., transversely of the raceway—while a second cam upon the same shaft serves to reciprocate the same parts lengthwise of the raceway. The motion of the extractor is, first, to the left to force the false space into its channel; second, right; third, forward; fourth, to the left to align the word with the edge of the galley; fifth, backward to withdraw the false space.

Referring to Fig. 57, 440 is a cam on the word-shaft 123, the circumference of which is complete except for a single depression, which causes the cam-lever to make one throw for each revolution of the word-shaft. 441 is a cam-lever pivoted at 442 on the bed of the machine and provided at about its center with a cam-roller 443, which bears against the periphery of the cam 440. 444 is a spring attached to the cam-lever and to the bed of the machine by which the cam-roller 443 is maintained in contact with the cam. 445 is a right-angular bracket the lower vertical leg of which is secured to the machine-bed and carries the galley and a part of its operative mechanism, while the horizontal portion forms a table 446, upon which is mounted the false-space extractor. From the sides of the table 446 depend flanges 447 and 448. 447 is bolted to the side of the ejector-table 130 for support, and in 448 are pivoted two levers 449 and 450, which operate to depress the type in the galley and to actuate the galley-plate. To the upper end of the lever 441 is connected a pitman-rod 451, secured at its opposite end to a sliding bar 452, which is the false-space extractor. This bar is mounted in a guide-carriage 453. The false-space extractor 452 is provided at its forward end with a laterally-projecting blade 454, and on the end of the blade is a lip 455, projecting in the plane of the blade a distance somewhat less than the thickness of the false spaces. The lever 441 gives to the extractor a forward-and-back motion at right angles to

the raceway dependent upon the cam 440. The extractor is also given three steps of motion in a line parallel to the raceway to complete its functions. These motions are accomplished by the action of a cam 456, keyed to the word-shaft and having a peripheral cam-groove. In a transverse slot on the back end of the table 446 is supported a slide 457, retained at one end by a plate 458 and at the other by a plate 459, screwed to the table 446. In order to secure rigidity of this right-angled frame, a brace-bar 460 is secured to the end of the slide 457 and the end of the way 453, thus forming a rigid triangle. At the center of the slide 457 there is a projection, and to it is secured a cam-pin 461, to the lower end of which is journaled a cam-roller 462, which stands in the peripheral groove of the cam 456. The cam-groove is so cut that its first motion is to force the extractor-blade from position shown in Fig. 58 to the position shown in Fig. 59, thus forcing the false spaces just extracted and all those preceding it into and up the false-space channel 463. 463^a are springs set in the upper wall of the false-space channel to exert upon the false spaces friction enough to prevent their descending in the false-space channel when the space-extractor is withdrawn. The second curve of the cam-groove carries the extractor to the position shown in Fig. 60. At this instant the notch of the cam 440 comes opposite the roller 443, and the lever 441 and slide 452 are drawn forward by the spring 444 to the extreme limit of its throw. (Shown in Fig. 61.) The third curve of cam 456 carries the extractor from the position shown in Fig. 61 to that shown in Fig. 62, whereby the line of type is pushed into the galley; so that the last type will be in alignment with the end of the friction-plate 429^c, (shown in Fig. 70,) which will fall behind it when the false space is withdrawn and resist the pressure of the galley-follower. The cam 440 will then force the lever 441 and the extractor back from position of Fig. 62 to position of Fig. 58, when the revolution of the word-shaft will have been completed and the false space extracted and delivered in position ready to be forced into its channel. The step of forcing the false space into the channel might be as well performed at the end of the operation as at the beginning. Referring to Figs. 66 to 70, as the line is forced into the galley it rests upon the galley-plate 464 and is pressed in a direction opposite to its former motion by the line-follower 465. The line-follower is a thin plate of metal lying between the galley-depressor and the galley-plate and drawn forward by a rod or wire 468 and spring 471. (Shown in Fig. 85.) The follower operates a justifier-key lock, by which the justifier-key is prevented from moving to throw a fresh line into the justifier until the preceding one has been fully justified and

passed into the galley. This structure is shown in Figs. 85 to 90. On the end of the follower 465 is a post, and to it is secured a rod or wire 468. This wire extends across the whole length of the machine and is connected at its other end to a lever 469, pivoted at 470 on the front of the machine above the keyboard and immediately above the line-key. 471 is a spring by which the lever 469 is maintained in such a position as the position of the line-follower will permit. On the other end of the lever is a trigger 472. 473 is a plate pivoted at 474 on the face of the machine below the lever 469 and having on its upper end a projecting portion 475, which stands in the path of the trigger 472. The plate 473 is slotted at its lower end at 476, and the projection 475 is kept in contact with the trigger 472 by the spring 477. 478 is the line-key, pivoted at 479, having an arm 480, which is connected to the rod 481, by which the clutch is operated through which the justifier is thrown into operation. 482 is an arm connected to the justifier line-key and moving with it and standing immediately below the slot 476, so that when the slot is above the arm it may enter it and the line-key may be operated. When the slot is not above the arm, the justifier line-key will be locked and cannot operate. If the line is not fully in the galley or has not been properly justified, so that it is short, the plate 473 will stand in such a position that its slot will be to the left of the arm 482. If, however, too much type has been carried into the galley or it is over-spaced, the slot will stand on the right of the arm 482 and the justifier-key cannot be operated. Thus a check is always kept upon the justification and no line can be forced down into the pivoted stick until the preceding one has been perfectly justified. If a mistake occurs and it is necessary to cast a line aside because wrongly set or because not justified, the unjustified line is removed from the galley and the succeeding line already set allowed to go through the machine and take its regular place. The preceding line wrongly set is now reset correctly, and takes the place of the line that should follow it. When the matter is taken from the machine, the lines may be transposed and the error corrected.

Recurring to Figs. 65 to 70, the follower 465 is slotted at 483 and is guided by a block 483^a, which enters this slot and also serves as a support for the upper way 426 of the word-raceway.

Galley-depressor.—By the mechanism thus far described the line has been delivered in the galley resting on the galley-plate and waiting to be depressed out of the path of the line which is to follow. The delivery of the line in the galley completes the operation of the justifying mechanism. One of the first operations performed by the justifying

mechanism when it is started is to withdraw the type-supporting plate 464 and depress the line and all of the matter in the galley a suitable distance. The structure by which this operation is performed will now be described.

Referring to Figs. 64 to 69, 484 is a slide mounted on the table 446 in guides 485, and to the front end of which is secured a galley-type-support plate 464. 486 is a bar secured to the slide 484, and to the projecting end of which is pivoted the upper arm of the bell-crank lever 449. The said lever is pivoted in the flange 448 and has a horizontal arm to which is pivoted a square block 487, which is embraced by and slides in a way in the end of the lever 488. The lever 488 is shown in full plan in Fig. 64. It is pivoted on the side of the bracket 266 and is provided at its rear end with a cam-roller 489, which bears against the surface of a cam 490 on the main line-shaft, shown in side elevation in Fig. 57, against which it is held by the spring 491. This cam is so located upon the main line-shaft that with the beginning of its revolution the lever 488 will be operated. 450 is the second lever pivoted on the side of the flange 448, having a projecting finger 493 on one side of its pivot and connected at its opposite end to the line-depressor. 494 is a finger projecting from the angle of the bell-crank lever 449 and engaging the finger 493 of lever 492. The operation of the lever 488 by the cam 490 will retract the type-supporting plate 464, and at the same instant by the action of the lever 449 on lever 450, depress the type-depressor head and force both the line last admitted to the galley as well as all the matter previously set down into the galley a distance sufficient to carry the last line of type below a catch or spring provided in the side of the galley to prevent the rise of the type due to elasticity or other cause when the depressor head is raised. On the front side of the bracket 445 is the galley, which consists of a stationary part 495 and a removable part 496. The stationary part 495 consists simply of a vertical slot cut in lower way of the word-raceway, while the movable part 496 consists of a channel of a width equal to the standard length of line and long enough to receive a desired number of lines. 497 is a follower located in the removable part of the galley and held in place by two friction-plates 498 498, which are secured to its sides and pressed apart by a spring. The friction-plates 498 are each provided on its outer edge with a feather which takes into a guide-groove 499 499 in the side of the galley, and each plate is also provided with a thumb-button 500, by which they may be pressed together upon the plate 497, and thus withdrawn from the grooves in the sides of the galley and the follower removed. When a desired quantity of type has been set and

forced into the galley, the portion of the type in the stationary part of the galley may be pushed down into the removable portion, which may be detached from the machine and the set matter transferred to a larger receptacle. In the side of the stationary part of the galley is a retaining device 501, consisting of a plate having a projecting lip on its end let into the side of the galley and pressed forward by its spring. The lip is rounded, so that the type as they are pressed against it from above by the depressor-head will force it back against its spring and pass it, when it will spring out beyond the type and prevent their following the depressor back when it returns.

502 is the type-depressor. It is located above the upper way 426 of the word-race-way and parallel with it and immediately above the galley. It is slotted in its lower surface so as to straddle the way 426 and the end of the follower 465. It is secured to a rod 503, by which it is given a reciprocating motion. The rod 503 is held in a vertical position in guides 504 and 505, the latter of which is a socket and contains a spring 506, by which the rod and depressor are maintained at their position of highest elevation. The upward thrust of the spring is limited by a pin 507. To the rod 503 is pivoted the lever 450, by which it is moved down. The spring 506 recovers the lever as well as the rod and depressor.

I have now described the construction and operation of all the parts of my machine except the line-key, by which various mechanisms are thrown into connection with the main driving-shaft and set in motion. Referring to Figs. 85, 86, and 87, 478 is the line-key pivoted at 479 and having an arm 480 which is pivotally secured to a rod 481. 508 is a bell-crank lever pivoted on bracket 509, one end of the lever being secured to the rod 481 and the other end being provided with a pin 510, which controls the clutch by which the main line-shaft is thrown into and out of engagement with the driving-shaft. 511 and 512 are the two halves of a ratchet-toothed clutch. The portion 512 is secured to the gear-wheel 9, which is running constantly, being geared to the driving-shaft 3. 511 is splined on the main line-shaft. The spring 513 surrounds the main line-shaft and bears at one end on the collar 514, secured to the shaft, and at the other upon the portion of the clutch 511, pressing it against the stop-pin of the lever 508 when it is in engagement with the stop 515 and against the other portion of the clutch when the pin is withdrawn. 515 is a stop on the periphery of 511, and 516 a circular flange provided on its face with a shearing cam by which the portion 511 of the clutch is withdrawn from engagement with the other portion 512 and stopped and held stationary when so withdrawn. The pin 510

stands normally on the periphery of the portion 511 of the clutch and in contact with the stop 515, thus holding the clutch open and the main line-shaft and all of its connected parts stationary. When the justifier-key is depressed, the pin 510 is withdrawn from the stop, and the spring 513 immediately forces the two portions of the clutch into engagement and the main line-shaft starts to make a revolution. As soon as the stop 515 has passed the pin 510 the pin drops behind it and remains in contact with the face of the circular flange until the shearing-cam (which is a gradual widening of the flange 516) is reached. The contact of the pin with the cam will gradually draw the two halves of the clutch apart until their teeth are out of engagement and the stop reached, which will stop the main line-shaft.

20 In the construction of the machine I determine—

First. The thickness of the false space I propose to use, which is determined by convenience.

25 Second. The difference in thickness between the various sizes of true spaces which I propose to use, which is a constant increment of difference.

Third. I determine the uniform distance 30 which the space-ejector carriage has to travel after each setting, which is the width of each space-magazine zone.

Fourth. The difference of thickness between the true spaces with which the magazines are charged and the length of the true-space-magazine zone will determine the 35 unit of difference of inclination of the plates, which unit of difference is an angle whose tangent is dependent upon the difference in thickness of true spaces with which the machine is charged divided by the length of the 40 true-space-magazine zone. If the difference between true-spaces be .005" and the length of the true-space magazine-zone .500", then 45 $\frac{.005}{.500}$ equals $\frac{1}{100}$, which is the unit of difference of inclination between successive plates on each side of the point of coincidence of the operative faces of all plates.

Fifth. The plates are then adjusted longitudinally in their carriage, so that a point on the operative face of each plate will be in the same vertical line, and at that point the plates will all have the same width. A standard line is then placed in the machine, and the 55 caliper and gage-block are so connected that the gage-block moved by the caliper will stand a distance from the way of the dividing-plate carriage equal to the width of the dividing-plate carriage and the plates at 60 their point of uniform width. The particular dividing-plate which has been selected (although any one would do, for they are all of the same width at this point) is then forced into contact with the gage-block. The position thus assumed by the dividing-plate carriage will be a constant position for all numbers of words.

Sixth. The ejector-carriage is then so connected to the dividing-plate carriage that the ejector will be opposite the space-magazine 70 containing true spaces of the same thickness as the false spaces.

Seventh. The plates are then slightly readjusted longitudinally from the position of primary setting a distance sufficient for each 75 plate to cause the requisite oversetting of the space-ejector carriage so as to permit it to take one idle step before it arrives at the theoretically correct position of primary setting.

Operation: At the outset of this specification I stated in a very general way the series of operations by which the complete work of the machine was accomplished for the purpose of aiding the reader to understand the structure when described. I have now completed the description of structure, and I shall repeat the description of operation with somewhat greater detail in order that the entire correlation of all the parts may be clearly understood. When power is applied to the 90 machine, the main driving-shaft is set in motion, turning the parts secured to or geared to it. On the main driving-shaft are the following parts, the space-key cam 55, the type-depressor-bar cam 350, and the knife-blades of the type-ejector, and geared to the driving-shaft are the word-shaft clutch, the main-line-shaft clutch, and the type-forcer-driving mechanism. These parts run constantly. When the operator begins to set 100 type, he strikes the keys of the keyboard and throws the type-ejector bars into the path of the knife-blades on the driving-shaft, by which they are immediately forced forward, and a corresponding type is forced into the 105 setter-raceway beneath the presser-bar, which has by the ejector-bar been lifted a suitable distance to receive it. The types are swept from the point at which they enter the raceway to the center of the raceway by 110 one of the type-forcers, where the type-depressor blade at once presses them into the stationary stick. When a word has thus been set, a space must be inserted after it, so as to separate it from the succeeding word. 115 As heretofore described, I do not attempt at this stage to insert true spaces, but put in false spaces, which are subsequently taken out when the line is justified and substituted by true spaces. The operation of introducing a false space is the same as that of introducing a type; but the action of the space-key sets a series of mechanisms with the assistance of which the line is subsequently justified. The space-key throws the pin 62 into 120 engagement with the space-key cam 55, which with each revolution of the driving-shaft while the pin is in contact with the cam operates a series of levers connected to the 125 pawl-shaft 61 and 61^a and gives to that shaft 130

and its connected parts one step. This action steps up the dividing-plate carriage one step, the averaging-cam stop one step, and the index mechanism one step. The line is thus set with as many false spaces as there should be true spaces, and then one more false space is added, not because it is needed to justify the line, but because a false space is necessary for each word in order that it may be properly separated from the line and also because in my machine herein described the index mechanism must be given a number of steps equal to the number of words in the line, which is one more than the number of spaces. The line is now completed and is standing partly in the stationary and partly in the pivoted stick. The line or justifier key 478 must now be depressed to set the justifier in operation; but this is only possible when its lock 472 stands in a position to permit it, and this will be the case only when the preceding line has been fully justified and has pushed the follower 463 exactly to the edge of the galley. When starting the machine, the follower is pushed over to the proper point by hand to allow the operation of the line-key. The action of the line-key releases the clutch 511 and throws the main line-shaft into engagement with the constantly-running driving-shaft and starts the various devices connected to and actuated by the main line-shaft. The operations take place in a certain order, so as to prepare the way for one another.

35 For convenience of reference the successive steps of operation will be numbered.

First. The line-depressor 347, operated upon by its lever 346 and cam 352, pushes the composed line from the stationary into the pivoted stick 355.

Second. The line-carrier 327, connected to the end of arm 323, is returned from the left to the right hand end of the line-raceway, and by the same action the auxiliary line-pusher 423 is also returned to its primary position.

Third. The caliper-head 385 then rises through the raceway and through the slot 330 in the end of the line-carrier.

Fourth. The rotating stick 355 is now rotated from a vertical to a horizontal position.

Fifth. At the same instant the ejector-carriage, which when the previous line was justified was left on its way at the position of its last step, is thrown back to its primary position by the lever 294 and cam 298, Fig. 56, and it is there locked upon its draft-rod 121 by the latch 121^b falling into the notch 121^a.

Sixth. The line is then pushed from the pivoted stick into the line-carrier by the line-pusher 371, which pushes the caliper-head 385 before the line of type until the back end of the line of type has passed the dog 332, when the dog rises under the influence of its

spring into a slot in the end of the line-
pusher and behind the type. The spring 405^a, connected to the gage-block lever, will maintain a constant pressure on the caliper-head against the type and line-pusher and when the line-pusher is withdrawn will press the line against the dog and measure the length of the line. The gage-block being connected to and operated by the caliper-head will be moved by it and given a setting corresponding to the position of the caliper-head.

Seventh. The gage-block is now locked in its set position.

Eighth. The dividing-plates are then driven forward into contact with the gage-block by the weight and spring 104, permitted by the position of the cam 110, the only plate coming into contact with the gage-block being the one which stands on the same level with it, that plate having been selected by the number of strokes given to the space-key and the number of steps up which the dividing-plate carriage has taken. By the movement of the dividing-plate carriage the space-ejector carriage is given a primary setting because geared directly to the dividing-plate carriage.

Ninth. As soon as the space-ejector carriage is given its primary setting it is locked in position by the cams 194 and 287 and held there until the dividing-plate has been released by the gage-block and its carriage had returned to its primary position.

Tenth. At the same time that the dividing-plate carriage is thrown forward the averaging-cam carriage is also thrown forward against the averaging-cam stop and under its ratchet-lever 273 by its push-arm 268, operated by the spring 272 and controlled by the cam 271.

Eleventh. The caliper-head is now lowered out of the path of the line-carrier.

Twelfth. The clutch of the pawl-shaft is opened by the cam 313, releasing the dividing-plates and averaging-cam stop from their driving mechanism and allowing them to return to their zero positions.

Thirteenth. The gage-block is unlocked and withdrawn.

Fourteenth. The dividing-plates drop down to their primary level and are then gradually drawn back to a zero position by cam 110.

Fifteenth. The averaging-cam stop is also drawn back to its primary position by the weight 83.

Sixteenth. The galley-plate is then withdrawn by the levers 449 and 488 and cam 490, and

Seventeenth. The line-depressor is depressed and forces the line of type last justified down into the galley, together with the rest of the matter in the galley. The de-

pressor ascends and the galley-plate returns to its position on a line with the bottom way of the word-raceway.

Eighteenth. The pivoted stick is returned 5 to its primary position.

Nineteenth. The line-carrier is swept from end to end of the line-raceway by the motion of the arm 323.

Twentieth. Auxiliary line-pusher falls be- 10 hind the line on the carriage when it passes it.

Twenty-first. The index mechanism is shifted. The lever 160, acted upon by its cam 163, shifts the ratchet and disk, which has been stepped forward by its pawl when the 15 line was set, out of the path of its pawl and throws the other ratchet into engagement with its pawl.

Twenty-second. The word-shaft clutch now operates under the influence of cam 142 20 and throws the word-shaft into engagement with the driving-shaft and starts all the parts connected to the word-shaft, which are the auxiliary line-pusher, the word-lifter, the word-forcer, the averaging-cam shaft, the 25 space-ejector, and the false-space extractor. These parts operate simultaneously or successively.

Twenty-third. The auxiliary line-pusher driven forward by the belt on the sheaves 417 30 and 427, the latter driving the gear 425 and rack 424, maintains a constant pressure on the back end of the line of type and pushes the first word off the line-carriage into the race-way beyond and over the word-lifter until 35 the first false space, which has no nicks, engages and is stopped by the wards 428 428, located on each side of the word-lifter.

Twenty-fourth. The word-lifter 427 now rises under the influence of its lever 430 and 40 cam-groove 429 and raises the word and its following false space up to the level of the word-raceway.

Twenty-fifth. As soon as the word reaches the level of the word-raceway the word-forcer 435 moves forward and sweeps the word through the word-raceway and into the galley.

Twenty-sixth. Meanwhile the averaging-cams have revolved and caused the space-ejector carriage under the influence of the friction-ratchet 280 to take one step on its way, when the cam 194 will lock the carriage between steps.

Twenty-seventh. The space-ejector during 55 the first revolution of the word-shaft is thrown out of engagement with said shaft, and hence does not eject a space for that revolution and for the first step of the ejector-carriage.

Twenty-eighth. The first word carried through the word-raceway has carried with it a false space which must be withdrawn. This is done by the space-extractor 454, which, actuated by the lever 451 and the 65 slide 457, controlled and moved, respectively,

by the cams 440 and 456, moves forward into the raceway, pushes the word into the galley to align with the edge of the galley, and then withdraws the false space and forces it into its channel.

Twenty-ninth. Before the second word has been carried through the word-raceway the space-ejector has again engaged the word-shaft and operated and ejected a true space in the raceway ahead of the second word. 70 This first space is ejected after the space-ejector carriage has made its second step. The remaining steps equal to the number of spaces to be inserted less the one which has already been inserted must be taken within a total 80 distance equal to the width of a space-magazine zone, and the number of steps taken within the zone of each magazine determines the number of spaces of each size which are ejected. 85

Thirtieth. With each revolution of the word-shaft a word is swept through the raceway, a false space extracted, and a proper-size space is substituted for the false space extracted.

Thirty-first. It will be remembered that 90 when the space-key was operated it stepped forward the index mechanism a number of steps equal to the number of words in the line. This action moved the ratchet then in engagement forward as many twelfths of a revolution 95 as there were steps. The counter-shaft on which the disks are mounted is geared to the word-shaft twelve to one, one revolution of the word-shaft turning the disks backward one-twelfth of a revolution—that is to say, a 100 distance equal to one step forward. As the disk is revolved backward one of the hooks 185, resting on its periphery the notch 156 or 157, as the case may be, will arrive under its hook. When the word-shaft has made as many 105 revolutions as the notch had been advanced twelfths of a revolution when moved forward, the hook will fall into its notch 156 or 157 and the pin 143 in contact with its shearing-cam 134, and the word-shaft will be stopped, 110 the justification of the line having been completed.

Referring to Fig. 91, it will be seen that the problem of justification may be easily solved by the application of a simple mathematical 115 formula and the apparatus which is illustrated in this case. Figs. 91, 92, and 93 illustrate the operation of the selection of true spaces of correct thickness to justify the line. Fig. 91 illustrates the relative position of the 120 apparatus when a line of standard length happens to be in the machine. Fig. 92 is a similar view of the same apparatus, showing a line in the machine of somewhat greater length than the standard. Fig. 93 is a diagram showing the dividing-plate and gage-lock with the formula for the calculation and determination of the thickness of the true spaces for any length of line. If the line with the false spaces in it is of standard 130

length, then we know that it is only necessary to supply the same number of true spaces of the same thickness to justify the line; but in order that the space-ejector shall eject the proper number of true spaces of the same size as the false spaces for any number of words it is necessary that the ejector-carriage should for all lines of standard length, no matter what the number of words in the line may be, receive its primary setting at the same spot—that is to say, at the beginning of the zone of the magazine containing spaces of the same thickness as the false spaces. It will be remembered that the space-ejector is given its setting by the dividing-plate carriage, and therefore that the space-ejector carriage may take the same setting for all number of words the dividing-plate carriage must make the same travel for all number of words. With all lines of standard length the gage-block will occupy the same position. Hence to secure the same travel for the dividing-plate carriage for all number of words there must be some point intermediate of the ends of the plate at which all plates will have the same width. The plates are therefore so arranged in operative relation with one another, as shown in enlarged scale on the diagram Fig. 93, that the operative faces of all plates will cross at the same point when superimposed on one another, and at that point all plates will be of the same width, so that no matter what plate happens to be in operative relation with the gage-block it will enter the space between the two fixed points—that is to say, between the ways of the dividing-plate carriage and the gage-block exactly the same distance that every other plate will enter the same space—and thus the space-ejector is caused always to eject spaces of a width equal to false spaces, no matter what their number, whenever the line is equal to standard length. If the line be less than standard length with the false spaces in, it will be perceived that true spaces necessary to justify the line must be thicker than the false spaces and must be of a thickness equal to the thickness of the false space plus the shortage divided by the number of spaces. If the set line with false spaces in be greater than standard length, then the spaces required will be the thickness of the false space less the excess of length beyond standard divided by the number of spaces. It will be seen that if the line be shorter than standard the measurement of the line will set the gage-block correspondingly farther away from the ways of the dividing-plate carriage and the plates will travel into the space farther than they would have done if the line had been of standard length. Hence the ejector-carriage will be drawn up to a point where it will eject thicker spaces than false spaces. If the line be longer than standard, the gage-block will be moved inward and the dividing-plates

will not travel so far as with the standard line, and the space-ejector carriage will be set to eject thinner spaces than standard. The formula is a simple one.

$$T = F - \frac{E}{N}$$

70

T equals thickness of spaces to be determined. E equals excess or shortage of type-line with false spaces in, over, or under the standard. N equals number of spaces and the number of a corresponding plate. F equals false-space thickness. In the example given in Fig. 92 the false-space thickness is .70", the number of words in the line is seven, and the number of true spaces to be inserted is six. Hence N equals six, and the N plate, or the 6 plate, will be in operative relation to the gage-block. In the proposition shown in Fig. 92 the line is greater in length than the standard length. Hence it is necessary to insert true spaces of a less thickness than the false spaces to justify the line. The problem is to determine the value of E and to divide that quantity by the number of spaces to be inserted, which when subtracted from the thickness of the false space will give the true space required.

$$T = 70 - \frac{E}{6}$$

95

If now, the line having been measured by the caliper-head 385 and the gage-block 470 having been set correspondingly, the dividing-plate carriage with plate No. 6 in operative relation to the gage-block be driven forward, the 6 plate will make contact with the gage-block at 45, and the ejector-carriage will be set at a corresponding division upon its way opposite the space-ejector bar, which will eject spaces from the magazine containing true spaces .45" of an inch thick. It will set the carriage at the beginning of the 45 zone, and hence all spaces ejected will be .45". It will be perceived that what the dividing-plate has actually done has been to divide the gap or E by N, or six, and subtract the quotient from .070", or the thickness of the false space. We will then have the formula as follows:

$$45 \times 6 = 270. \quad 70 \times 6 = 420. \quad 420 - 270 = 150 \quad 115$$

Hence .150 equals E. The formula becomes

$$T = 70 - \frac{150}{6} \text{ or } 70 - 25 = 45,$$

which is the thickness of the true space. This same formula is applicable to any length of line, whether longer or shorter than the standard.

It will be perceived that in order that the machine may have sufficient range for justifying lines both shorter and longer than the standard the series of inclined plates shall be so arranged that at some point intermediate of the ends of the plate the operative edges of the plates will all intersect a

130

vertical line erected at right angles to the surfaces of all plates at that point—that is to say, all plates at that point will have the same width.

5 Having thus described my invention, what I claim, and desire to secure by Letters Patent, is—

1. In an organized machine for justifying a composed line of type containing false spaces, means for ascertaining the total difference between the length of said line and a standard line, a single mechanism for dividing said difference by the number of word-spaces in the line, and making the proper allowance for the false spaces contained in the line, a space-determining device for supplying the line to be justified with true spaces, connections between said device and said dividing mechanism whereby said device is primarily set for each line to be justified, combined with means for progressively moving said device in a number of steps equal to the number of word-spaces in the line from the position in which it is so set to cause it to determine the proper combination of spaces to justify the line.

2. In an organized machine for setting and justifying a line of type, means for setting the type into words, a space-key for inserting a false space between the words, means for ascertaining the total difference between the length of a set line and a standard line, means for dividing said difference by the number of word-spaces in the line, a space-determining device for supplying the line to be justified with true spaces, connections between said device and said dividing means whereby said device is primarily set for each line to be justified, combined with means controlled by the depression of the space-key during the setting of said line for progressively moving said device in a number of steps equal to the number of word-spaces in the line from the position in which it is so set to cause it to determine the proper combination of spaces to justify the line.

3. In an organized machine for justifying a composed line of type, means for ascertaining the total difference between the length of said line and the standard line, means for dividing said difference by the number of word-spaces in the line, a space-determining device for supplying the line to be justified with true spaces, connections between said device and said dividing means whereby said device is primarily set for each line to be justified, combined with means for moving said device progressively and permanently in one direction only, from the zone of one true space to the zone of another sized true space, in which progressive movement a proper proportion of each of the two sizes of true spaces will be selected to justify the line.

4. In an organized machine for justifying

a composed line of type, means for ascertaining the total difference between the length of said line and a standard line, means for dividing said difference by the number of word-spaces in the line, a space-determining device for supplying the line to be justified with true spaces, connections between said device and said dividing means whereby said device is moved to and left in a position determined entirely by the movement of said dividing means, this being primarily set for each line to be justified, combined with means for subsequently progressively moving said device in a number of steps equal to the number of word-spaces in the line from the position in which it is so set to cause it to determine the proper combination of spaces to justify the line.

5. In an organized machine for justifying a composed line of type, means for ascertaining the total difference between the length of said line and a standard line, means for dividing said difference by the number of word-spaces in the line, a space-supplying device capable of movement in two directions, connections between said device and said dividing means whereby said device is moved in one direction and set to select the proper size of space, and mechanism for progressively moving said device in the other direction in a number of steps equal to the number of word-spaces in the line to cause it to supply true spaces to the line.

6. In an organized machine for justifying a composed line of type, means for ascertaining the total difference between the length of said line and a standard line, means for dividing said difference by the number of word-spaces in the line, a space-selecting device for supplying the line to be justified with true spaces, connections between said device and said dividing means whereby said device is primarily set for each line to be justified, combined with means for moving said device from the position in which it is so set, by intermittent steps varying in number and length for different lines, the sum of said steps for any line aggregating a certain fixed distance which is the same for all lines to be justified.

7. In an organized machine for justifying a composed line of type, means for ascertaining the total difference between the length of said line and a standard line, means for dividing said difference by the number of word-spaces in the line, a space-supplying device capable of movement in two directions, connections between said device and said dividing means whereby said device is moved in one direction and set to select a certain size of space, mechanism for moving said device in the same direction from the position in which it is set a certain fixed distance the same for all lines to be justified, but by inter-

mittent steps varying in number and length for different lines, and mechanism for moving said device in the other direction between said steps to cause it to supply true spaces to 5 the line.

8. In an organized machine for justifying a composed line of type, means for ascertaining the total difference between the length of said line and a standard line, means for dividing 10 said difference by the number of word-spaces in the line, a device for supplying true spaces to the line, connections between said device and said dividing means whereby said device is set to supply one size of spaces, and 15 means for subsequently moving said device progressively and permanently in one direction only from the zone of one true space, to the zone of another sized true space, in which progressive movement a proper proportion of 20 each of the two sizes of true spaces will be selected to justify the line.

9. In an organized machine for justifying a composed line of type, a series of inclined plates, each plate differing in altitude from 25 the adjacent plate, by the same arbitrarily-selected increment, a space-selecting device for supplying the line to be justified with true spaces and connections between said series of plates and said device, whereby said device is 30 primarily set for each line to be justified, combined with means for progressively moving said device in a number of steps equal to the number of word-spaces in the line from the position in which it is so set to cause it to 35 select the proper combination of spaces to justify the line.

10. In a justifying-machine the combination of a series of inclined plates, each plate differing in altitude from its adjacent plate 40 by the same arbitrarily-selected increment; the plates being arranged in such operative relation to one another, that at some point intermediate of the ends of the plates, all plates will have the same width.

45 11. In a justifying-machine, the combination of a series of inclined plates, each plate differing in altitude from its adjacent plates and arranged in such operative relation to one another, that at or near some point intermediate of their ends, the lines of the operative faces of all plates will cross, substantially as described.

55 12. In a justifying-machine, the combination of a series of inclined plates, each plate differing in altitude from its adjacent plates and arranged in such operative relation to one another, that on one side of a plane intersecting the flat sides of the plates, they will gradually increase in width and on the other side gradually decrease in width, the relation of the inclination of the plates on each side of the plane being reversed, substantially as described.

65 13. In a justifying-machine, the combination of a series of inclined plates, each plate

differing in altitude from its adjacent plates by the same arbitrarily-selected increment, these plates being arranged in such operative relation to one another, that for a certain portion of their operative length, their relative inclinations increase progressively by said increment, and for the remaining portion of their operative length the same plates in the same order decrease progressively in inclination by said increment, substantially 70 as described.

14. In a justifying-machine, the combination of a series of inclined plates, each plate differing in altitude from its adjacent plate by the same arbitrarily-selected increment; 80 the plates being arranged in such operative relation to one another, that at a point intermediate of the ends of the plates, the operative edges of all of the series of plates will meet a right line at right angles to their side 85 surfaces.

15. In a mechanism for justifying a composed line of type, the combination of a device for measuring an unjustified line to ascertain the difference between the length of 90 the set line and standard, means set by the measuring device to establish a point a distance from a certain fixed point proportional to said difference, a series of inclined plates, each plate differing in altitude from its adjacent plate by the same arbitrarily-selected increment, and being adapted to be thrust between said two points, the plates being so arranged in operative relation to one another that for a certain distance between said two 95 fixed points all plates will enter an equal distance, and register the same width of space, substantially as described.

16. In a mechanism for justifying a composed line of type, the combination of a device for measuring an unjustified line to ascertain the difference between the length of the set line and standard, means set by the measuring device to establish a point a distance from a certain fixed point proportional 105 to the said difference, a series of inclined plates, each plate differing in altitude from its adjacent plate by the same arbitrarily-selected increment; said plates being arranged in such operative relation to one another, 110 that all plates will have the same width at a point intermediate of their ends, and this point for all plates will lie in a plane at right angles to all plates.

17. In a mechanism for justifying a composed line of type, the combination of a device for measuring an unjustified line to ascertain the difference between the length of the set line and standard, means set by the measuring device to establish a point a distance from a certain fixed point proportional 120 to said difference, and a series of inclined plates, each plate differing in altitude from its adjacent plate by the same arbitrarily-selected increment, each plate being adapted 125

to be thrust between said two points; a mechanism actuated by the type-setting device for selecting one of said plates corresponding to the number of spaces in the line, and a mechanism connected to the plate selected, which is adapted to be set by the setting of the plate selected, and which when operated a number of times equal to the number of spaces required for the line, will deliver a number of true spaces, which will justify the line.

18. In a type composing and justifying machine, the combination of means for assembling a series of types to form words, means operated by a key for inserting false-space blanks between said words, mechanism for measuring the actual length of the line set, to determine its difference from standard, means actuated by the measuring device to set a point a distance from a certain fixed point, proportional to the difference from standard, an inclined surface, the tangent of which is arbitrarily selected to indicate a certain number of spaces, means connected to the space-key for registering the number of spaces selected, and bringing the inclined surface corresponding to the number of words set into operative relation with the said points, the averaging mechanism in operative relation to and set through the action of the space-key, a true-space-selecting mechanism in operative relation to and set by the inclined surface, and means connecting the space-selecting mechanism with the averaging mechanism, whereby the space-selecting mechanism is caused automatically to select a suitable number of one or more sizes of spaces which in the aggregate will justify the line.

19. In a machine for justifying type, the combination with a mechanism for selecting a series of spaces of equal or different sizes for the purpose of justification, of an averaging mechanism in operative relation to the space-selecting mechanism for causing it to select spaces of the same or varying sizes as may be necessary to justify the line, and means for giving the averaging mechanism a setting dependent solely upon the number of word-spaces in the line.

20. In a machine for justifying type, the combination of a mechanism for selecting a series of spaces of equal or different sizes for the purpose of justification, an averaging mechanism in operative relation to the space-selecting mechanism and mechanism for setting said averaging mechanism during the composition of any line solely in accordance with the number of word-spaces in the line so that it will cause said selecting mechanism to select spaces of the same or varying sizes as may be necessary to justify said line.

21. In a machine for setting and justifying type, an averaging mechanism for determining what proportion of the total number of

spaces necessary in any line shall be of one size and what proportion of the next size in order to properly justify the line; a space-key, and connections between said averaging mechanism and said space-key, whereby said averaging mechanism is set by the depression of the space-key said setting being controlled solely by the number of such depressions of the space-key.

22. In a machine for justifying type, the combination of a series of magazines, said magazines containing spaces of different thicknesses, each size of space differing from its adjacent spaces by an approximately equal amount, the magazines being located in regular order according to size of spaces, a space-ejector suitably mounted to travel through the zone of one magazine, or from the zone of one magazine to the zone of another, the zones of all the said magazines being of the same width, and to eject a space from the magazine opposite which it is located at the instant of its stroke, and means for imparting to the said ejector a step-by-step motion and moving it one step for each operation of ejecting a space, the number of steps being equal to the number of spaces to be inserted in the line.

23. In a machine for justifying a composed line of type, the combination of a series of space-magazines, said magazines containing spaces of different thicknesses, each size of space differing from its adjacent spaces by an approximately equal amount, the magazines being located in regular order of size of spaces, a space-ejecting mechanism suitably mounted to travel through the zone of one magazine or from the zone of one magazine to the zone of another, the zones of all the said magazines being of the same width, and to eject a space from the magazine opposite which it is located at the instant of its stroke, and means for imparting to the said ejector a step-by-step motion and moving it one step for each operation of ejecting a space, the number of steps being equal to the number of spaces to be inserted in the line, and the total distance traveled during the step-by-step motion being equal to the width of one of said magazine zones.

24. In a justifying-machine, the combination of a series of magazines, said magazines containing spaces of different thicknesses, each size of space differing from its adjacent space by approximately the same amount, the magazines being located in regular order according to size of spaces, with a space-ejecting mechanism, mounted to travel the total distance between the extreme space-magazines, mechanism for giving to the space-ejector a primary setting in the zone of some one of the space-magazines, and mechanism for imparting to the space-ejector a step-by-step motion and moving it one step for each space ejected, the number of steps being

equal to the number of spaces required for the line, and the total distance of travel being a distance equal to the width of one of the magazine zones, as and for the purpose specified.

- 5 25. In a justifying-machine, the combination of a series of magazines mounted an equal distance apart; said magazines containing spaces of different thicknesses, each size of space differing from its adjacent space by approximately the same amount, the magazines being located in regular order, according to size of spaces, with a space-ejector mechanism, suitably mounted to travel the total distance between the extreme space-magazines, a mechanism for giving the space-ejector mechanism a primary setting opposite one of the space-magazines, dependent on the difference between the length of the set line and the standard and on the number of spaces to be inserted, a mechanism for operating the space-ejector a number of times equal to the number of spaces to be inserted and a mechanism for progressively moving said ejector mechanism in a number of steps equal to the number of word-spaces in the line, from the position in which the ejector is set to cause it to eject the proper combination of spaces to justify the line.
- 10 30. 26. In a justifying-machine, the combination of a series of magazines containing spaces of different thicknesses, an ejector mounted to travel past the magazines, the total path of the ejector being divided into a number of zones of equal width and in equal number to the number of magazines.
- 15 35. 27. In a justifying-machine, the combination of a series of magazines, mounted an equal distance apart; said magazines containing spaces of different thicknesses, each size of space differing from its adjacent space by approximately the same amount, the magazines being located in regular order, according to size of spaces, with a space-ejector mechanism suitably mounted to travel the total distance between the extreme space-magazines, a mechanism for giving to the space-ejector a primary setting opposite one of the space-magazines, dependent on the difference between the length of the set line and the standard and on the number of spaces to be inserted, and mechanism for giving to the space-ejector a step-by-step motion, the number of steps being equal to the number of spaces to be inserted, said steps in the aggregate being equal to the width of a space-magazine zone, and mechanism for operating the space-ejector a number of times equal to the number of spaces to be inserted.
- 20 40. 30. 28. In a justifying-machine, the combination of a series of magazines, having zones of equal width; said magazines containing spaces of different thicknesses, each size of space differing from its adjacent space by approximately the same amount, the mag-

azines being located in regular order according to size of spaces, with a space-ejector mechanism suitably mounted to travel the total distance between the extreme space-magazines, and to eject spaces from the magazine opposite to which it happens to be, mechanism for giving to the space-ejector a primary setting, corresponding to the difference between the length of the set line and the standard and to the number of spaces to be inserted in the line, mechanism for giving to the space-ejector a step-by-step motion, past the magazines, the number of steps being at least as great as the number of spaces to be inserted, the aggregate number of said steps equal to the number of spaces to be inserted, and the aggregate distance covered by said steps being equal to the width of a space-magazine zone, the mechanism for causing the step-by-step motion consisting of a series of cams mounted upon a common support, each cam differing from its adjacent cam in altitude, any of said cams being capable of being brought into operative relation with the space-ejector, and means for revolving the operative cam a number of times equal to the number of spaces to be inserted.

25 35. 29. In a machine for justifying type, a mechanism for causing the space-selecting mechanism to select spaces of the same or varying sizes as may be necessary to justify the line, which consists of the combination of a series of cams mounted upon a common support, each cam differing from its adjacent cam in altitude, any one of said cams being adapted to be thrown into operative relation with the space-selecting mechanism, and means for revolving the operative cam a number of times equal to the number of spaces to be selected.

40 45. 30. 30. In a machine for justifying type, the combination of a mechanism for selecting a series of spaces of equal or different sizes for the purpose of justification, with an averaging mechanism, in operative relation with the space-selecting mechanism, for causing it to select spaces of the same or varying sizes as may be necessary to justify the line; said averaging mechanism consisting of a series of cams, each cam differing from its adjacent cam in altitude, with means for bringing one of said cams into operative relation to the space-selecting mechanism, and means for revolving the operative cam a number of times equal to the number of spaces to be inserted.

50 55. 31. In a machine for justifying type, the combination of a mechanism for selecting a series of spaces of equal or different sizes for the purpose of justification, with a series of inclined surfaces, each inclined surface differing in altitude from its adjacent surface, the inclination of said surfaces gradually increasing from that having the least to that having the greatest inclination, with means controlled by the space-key of the

type-setting machine, for bringing one or the other of said inclined surfaces into operative relation with the selecting mechanism, and means for operating the selected inclined surface a number of times equal to the number of spaces to be inserted.

32. In a mechanism for justifying a composed line of type, the combination of a device for measuring the line to ascertain the difference between its length and the standard, means set by the measuring device to establish a point a distance from a certain fixed point, proportional to the said difference in length between the set line and the standard, and a series of inclined surfaces, each surface differing in altitude from its adjacent surface by the same arbitrarily-selected increment, each surface being adapted to be inserted between said two points, a series of magazines containing spaces of differing thicknesses, each size of space differing from its adjacent space, the magazines being located in regular order according to size of spaces, a space-ejector suitably mounted to travel past the magazines the full distances between the extreme magazines; said space-ejector being so connected to the inclined surface as to be given a primary setting by the inclined surface, when it is brought into operation between the two points, and means for operating the space-ejector a number of times equal to the number of spaces to be inserted in the line.

33. In a justifying-machine, the combination of a pair of space-magazines, said magazines containing spaces of different thicknesses, a space-ejector suitably mounted to travel past the magazines and to eject spaces therefrom, with mechanism for giving to the space-ejector a step-by-step motion, the number of steps being equal to the number of spaces to be ejected, the aggregate distance of the travel of the space-ejector, while ejecting spaces, being equal to the width of the zone of one of said space-magazines.

34. In an averaging mechanism for a justifying-machine, the combination of a series of cams, each cam differing in altitude from its adjacent cam, with mechanism for giving to the averaging-cams a setting corresponding to the number of spaces in the line and a space-selecting device and connections between said device and said cams for giving said device a step-by-step movement.

35. In a justifying-machine, the combination of a series of inclined plates, each plate differing in altitude from its adjacent plate by the same arbitrarily-selected increment, each plate being adapted to divide the total difference between the length of the set line and the length of the standard line into a number of equal parts, represented by the plate used, and equal to the number of spaces in the line, with a space-ejector mechanism, in operative relation to each of the series of

inclined plates and so connected thereto that the space-ejector mechanism may be given a primary setting by the operation of the plate used, mechanism for operating the space-ejector to insert a number of spaces equal to the number of spaces in the line, and an averaging mechanism in operative relation to the space-ejector for causing it to move from its position of primary setting, a desired distance, by a series of uniform steps equal in number to the number of spaces to be inserted in the line, and mechanism operated by the space-key of the type-setting machine in operative relation to the series of inclined plates, the averaging mechanism and the space-ejector-actuating mechanism, by which these three mechanisms are simultaneously set to perform their functions automatically in proper order.

36. In a justifying-machine, the combination of a series of inclined plates substantially such as described, a space-ejector and mechanism for actuating the same substantially such as described, and an averaging mechanism substantially such as described, in combination with a mechanism for setting these three mechanisms in operative relation to one another controlled by the space-key of the type-setting machine.

37. In a justifying-machine, ejectors for supplying spaces of the proper size to justify the line, a single actuating means to operate said ejectors to supply spaces to the line a space-key for inserting false spaces, and connections between said actuating means and the space-key, whereby said actuating means are set to actuate said ejectors a number of times dependent on the number of depressions of the space-key.

38. In a justifying-machine, a space-selecting device, means for giving said device a step-by-step motion, and connections between said means and the space-key, whereby said means are set to move said space-selecting device a number of steps dependent on the number of depressions of the space-key.

39. In a justifying-machine, the combination of a series of inclined plates, a space-ejector mechanism, and a series of space-magazines, the space-ejector mechanism being in operative relation to the inclined plates and adapted to be set by them, an actuating-shaft for actuating the space-ejector mechanism, the revolutions of which determine the number of spaces ejected; mechanism for controlling the number of revolutions of said shaft, called the index mechanism, and mechanism controlled by the space-key of the type-setting machine for setting the inclined plates and index mechanism to correspond with the number of spaces in the line.

40. In a composing and justifying machine, the combination of a key-lever adapt-

ed to insert false spaces into the line as it is composed, a pin controlled thereby, adapted to be projected into the path of a cam mechanism connected with said pin and actuated by the cam for setting such devices as are controlled by the space-key.

41. In a composing and justifying machine, the combination of a pivoted lever, having two motions, one of small and the other of large degree; the motion of small degree depressing single type into the stick, the motion of large degree depressing the whole line into the stick; a cam on the main driving-shaft, for imparting to the lever its motion of small degree, and a cam on the main line-shaft for imparting to the lever its motion of large degree, substantially as described.

42. In a type-setting machine, a receiving-stick composed of two parts, a stationary part and a pivoted part; the stationary part receiving the type as they are selected and the pivoted part transferring the whole line, when set, from the setter to the justifier.

43. In a type-setting machine, the combination of means for selecting type and delivering the same at a central channel, a stick located at the central channel to receive the type as they are selected, said stick consisting of a stationary part and a movable part; means for forcing the line of type as set from the stationary part to the movable part, and means for moving the movable part from its receiving position to its discharging position, substantially as described.

44. In a machine for setting type, the combination of mechanism for selecting and assembling a line of type in a vertical channel or stick, a movable portion of said channel or stick adapted to receive the set line when assembled, and transfer it to another mechanism; a raceway, and a line-carrier operating therein and located in position to receive the line from the movable stick, and means for forcing the line from the movable stick into the line-carrier.

45. In a type-setting mechanism, the combination with means for setting a line of type in a vertical position and a movable carrier for turning said line from the vertical to a horizontal position.

46. In a type setting and justifying mechanism, the combination with means for setting a line of type in a vertical position, a movable carrier for turning the said line from the vertical to a horizontal position and means for justifying the line while it is in the horizontal position.

47. In a type setting mechanism, the combination with means for setting a line of type in a vertical position and an oscillating carrier for turning the said line from the vertical to a horizontal position.

48. In a type setting and justifying mech-

anism, the combination with means for setting a line of type in a vertical position, an oscillating carrier for turning the said line from the vertical to a horizontal position and means for justifying the line while it is in the horizontal position.

49. In a type setting and justifying mechanism, the combination with means for setting a line of type and means for justifying the said line, of a line-raceway leading to the justifying mechanism, and a type-channel leading from the setting mechanism, a movable carrier adapted to be alined with the channel leading from the setter to receive the line, means to move the carrier into position to aline with the raceway to the justifier and means to eject the line from the carrier into the justifying-raceway.

50. In a type setting and justifying mechanism, the combination with means for setting type to form a line and means for justifying the said line, of a line-raceway leading to the justifying mechanism and a type-channel leading from the setting mechanism, an oscillating carrier adapted to be alined with the channel leading from the setter to receive the line, means to oscillate the carrier into position to aline with the raceway to the justifier and a reciprocating ejector to eject the line from the carrier into the justifier-raceway.

51. In a type setting and justifying mechanism, the combination with means for setting type to form a line and means for justifying the set line, of a line-raceway leading to the justifying mechanism and a type-channel leading from the setting mechanism, an oscillating carrier adapted to be alined with the channel leading from the setter to receive the line, means to oscillate the carrier into position to aline with the raceway to the justifier, a reciprocating ejector to eject the line from the carrier into the justifier-raceway and a cam-operated arm for operating the ejector, said arm being provided with means to allow the same to yield should the ejector strike an obstruction.

52. In a type-setting machine, a type-receiving channel, one side of which is provided with a spring-actuated shutter, adapted to close said channel and form a support for type entering it, the other side of said channel being provided with a spring-actuated friction-plate, mounted in the wall of the channel, and adapted to exert a pressure upon the side of the type as they enter the channel, to prevent their falling.

53. In a type-setting machine, the combination of a receiving-channel, provided on one side with a spring-actuated shutter, which normally closes said channel, an overhanging notch in the same wall of the channel as the shutter, and just below its edge, which forms an abutment against which the

shuttle may press the type which have been forced into the channel, substantially as described.

54. In a type-setting machine, the combination with means for selecting type, a stick located in position to receive the selected type, means for forcing the type into one end of the stick, means for moving the stick from its receiving position to a discharging position and means for forcing the type from the other end of the stick when it is in its discharging position.

55. In a type-setting machine, the combination with means for selecting type, a channel to which the selected type are delivered, a stick located in position to receive the type from the channel, means for forcing the type from the channel into one end of the stick, means for moving the stick from its receiving position to a discharging position and means for forcing the type from the other end of the stick when it is in its discharging position.

56. In a type setting and justifying mechanism, the combination with means for setting type to form a line, including a stick provided with a channel in which the type are assembled, and means for introducing the type into one end of the channel, a justifying mechanism, means for moving the stick from its receiving position to a position to deliver the set line from the other end of the channel to the justifying mechanism and means for forcing the line from the other end of the channel into the justifying mechanism.

57. In a type setting and justifying mechanism, the combination with means for selecting type to form a line and means for justifying the line, a line-raceway leading to the justifying mechanism and a type-channel leading from the selecting mechanism, an oscillating carrier adapted to be aligned with the channel leading from the selecting mechanism to receive the type which form the line, means to oscillate the carrier into position to align with the raceway to the justifier, and an ejector to eject the line from the other end of the carrier into the justifier-raceway.

58. In a type setting and justifying mechanism, the combination with means for selecting type to form a line and means for justifying the line, of a line-raceway leading to the justifying mechanism and a type-channel leading from the selecting mechanism, a carrier adapted to be aligned with the channel leading from the selecting mechanism to receive the type which form a line, means to move the carrier into position to align with the raceway to the justifier and means to eject the line from the carrier into the justifier-raceway, the type being received at one end of the carrier and delivered from the other.

59. In a typographic machine, a type-channel movable from a position in which

the channel extends lengthwise in a substantially horizontal direction to a position in which the channel extends lengthwise in a substantially vertical direction, means for assembling a line of type in one of said positions, and means for discharging the line from the channel when in the other position.

60. In a type-composing machine, the combination of a type-setter with a type-stick, suitably mounted to move in the segment of a circle from the point where the type are received to the point where they are discharged, said stick being provided with a type-channel through the same, and a spring-plate in said channel to exercise upon the type a restraining influence, means to introduce the type into the stick, means to rotate the stick, and means to eject the line from the stick.

61. In a type setting and justifying machine, means for setting a composed line of type, a movable stick adapted to receive the set line from the setter and transfer it to the justifier; a line-carrier for conveying the line from the setter through the justifier, means for transferring the composed line from the movable stick to the line-carrier, and means for retaining the line upon the carrier during its motion.

62. In a type-setting machine, the combination of a line-carrier with a line-raceway in which said line-carrier reciprocates, mechanism for reciprocating the carrier in the line-raceway, a movable stick, mechanism for pushing the composed line from the movable stick into the line-carrier, and mechanism for pushing the composed line out of the line-carrier into the word-separating mechanism.

63. In a type-justifying machine, a line-carrier, adapted to receive and carry a line of type, having a pawl set in one end of the carrier, and rising above its level, and having a longitudinal slot in the opposite end adapted to receive the line-measuring device.

64. In a type-justifying machine, an auxiliary line-pushing mechanism adapted to push the line from the line-carrier into the word-separating mechanism, which consists of the following operative parts in combination: a line-carrier suitably mounted to reciprocate in ways, a rack pinion and pulley mounted on the ways, said pulley being controlled by a friction-clutch, a pusher-blade connected to and operated by the rack, means operated by the retracting movement of the line-carrier, to set the auxiliary line-pusher in its primary position; and suitable wards in the line-raceway beyond the line-carrier, to arrest the forward movement of the line by the false spaces therein.

65. In a type-justifying machine, a word-separating mechanism consisting of a movable portion of the line-raceway, adapted to

carry the words one by one out of the plane of said raceway, wards located on the stationary part of said raceway, adapted to stop the unnicked false spaces in a line of type, while allowing the nicked type to pass, substantially as described.

66. In a type-justifying machine a word-separating mechanism consisting of the combination of a word-lifting table located in a raceway, wards located on the said raceway adapted to stop a series of unnicked false spaces in a line of type, while allowing the nicked type to pass, and mechanism for raising and lowering the lifting-table substantially as described.

67. In a type-justifying machine, a word-separating mechanism consisting of a word-receiving table, part of which is stationary, and part of which is movable; the movable part having a vertical motion, with wards located on the surface of the stationary part of the table, and on either side of the movable part, and adapted to stop a series of unnicked false spaces located between the words of a line of type, while allowing the nicked type to pass, and means for forcing the line on to the table.

68. In a type-justifying machine, a word-separating mechanism consisting of a word-receiving table, part of which is stationary, and part of which is movable; the movable part having a vertical motion, with wards located on the surface of the stationary part of the table on either side of the movable part, and a distance back of the end of said movable part, equal to the thickness of a false space; and adapted to stop a series of unnicked false spaces located between the words of a line of type, while allowing the nicked type to pass, and means for forcing the line on to the table.

69. In a type-justifying machine, a word-separator, which consists of the combination of a receiving-table, having wards upon its surface of a size suitable to permit nicked type to pass over them, but to stop unnicked false spaces, means for forcing the line on to the table, and against the wards, and means for removing the word which has passed the wards, and the false space which has made contact with them.

70. In a type-justifying mechanism, a word-separating mechanism, which consists of a combination of a table upon which the composed line is delivered, suitable wards on said table on either side, the same being arranged to pass beneath the nicks of the type, but adapted to engage the false spaces, means for pushing the line on to the table as far as the wards will permit, a word-lifter in the bed of the table, means for giving the said word-lifter a vertical motion, for lifting the word and the false space, which lies over the word-lifter to a higher level, and a word-forcer located upon the higher level, and

adapted to force the word over the word-lifter and through a word-raceway to a point of delivery.

71. In a type-justifying mechanism, the combination of a galley, means to deliver the words of a composed line and their accompanying false spaces into a position to be forced into the galley, a blade having a forcing-face to aline the word with the edge of the galley, and a retracting-shoulder, and means to impart to the said blade a two-way movement, to force the word into the galley and then retract the false space.

72. In a type-justifying mechanism, a galley, means to deliver the words of a composed line and their accompanying false spaces in position to be forced into the galley and alined with the edge thereof, in combination with a blade having a forcing-face and a retracting-shoulder, and means to impart to said blade a five-way movement, to force the word into the galley, to retract the false space, to force the false space into its receiving-repository to withdraw the blade to a position suitable for forward motion, and to move it forward to a position behind the word.

73. In a type-justifying mechanism, the combination of a receiving-galley for the type, means to deliver the words of a composed line and their adjoining false spaces in position to be forced into the galley, with a blade, having a forcing-face, and a retracting-shoulder; said blade being suitably mounted in ways in a frame, said frame being mounted on a slide-bar movable in a way, the movement of the blade and the bar being at right angles, and means to impart to the bar and the blade a five-way course, substantially as described.

74. In a type-justifying machine, the combination of a suitable galley, means to deliver the words with their adjoining false spaces, in position to be forced into the galley, with a blade, having a forcing-face, and a retracting-shoulder; said blade being suitably mounted in ways in a frame, said frame being suitably mounted on a sliding bar moving in ways, the movement of the blade and the bar being at right angles to each other, and means operated by cams to impart to the blade, five motions: first, to force the false space into its receiving-channel; second, to retract the blade to the position in which it begins its forward motion; third, to move it forward behind the word at the mouth of the galley; fourth, to move it against the false space, and the word to force the word into the galley; fifth, to retract the false space to the mouth of its receiving-channel.

75. In a machine for justifying type, a line-key, upon the depression of which the justifying mechanism is started, a galley for receiving the justified lines, a line-follower operating in the galley, a lock for locking the

line-key, and connections between said lock and said line-follower, whereby the line-key is locked out of operation whenever the last line to enter the galley has not been satisfactorily justified.

76. In a type setting and justifying machine, an adjustable stop adapted by virtue of its relative position to control the position of one of the mechanisms of the justifier, in combination with means controlled by the operation of the space-key of the setter, to cause said stop to change its relative position one unit of movement with each operation of the space-key, and a series of inclined surfaces adapted to control one of the devices of the justifier, the position of which is determined by the position of the stop.

77. In a type setting and justifying mechanism, an adjustable stop suitably mounted to move in ways, and adapted by virtue of its relative position to control the adjustment of one of the mechanisms of the justifier, in combination with a rack connected to said stop, and a pinion meshing with the rack, and a ratchet-wheel and pawl, and line of shafting suitably mounted to operate said pinion, and means to rock said shafting controlled by the movement of the space-key of the type-setter.

78. In a type-setting and justifying machine, a controlling mechanism for the space-ejector, which consists of a series of parts connected to and actuated by mechanism controlled by the space-key of the type-setter, so that the controller will take one step forward for each depression of the space-key, a space-key connected to the controller, a detent mechanism forming part of the controller, said detent being thrown into gear with the actuating mechanism of the space-ejector, so as to move backward when said actuating mechanism is operated, a clutch controlling the actuating mechanism, and itself controlled by the detent mechanism, the detent mechanism operating to check the actuating mechanism of the space-ejector when it has moved backward the same distance that it was moved forward through the action of the space-key.

79. In a type setting and justifying machine, a device for controlling the operation of the actuating mechanism of the space-inserting mechanism, which consists of a counter-shaft geared to the main driving-shaft, and controlled by a clutch, a controller connected to and operating the clutch, said controller adapted to be-set by the action of the space-key of the setter, and to take one step forward each time the space-key is operated and a space-key connected to the controller, and a detent mechanism through which the controller controls the clutch, whereby the detent is set in such a position that it will permit the actuating counter-shaft to make as many revolutions as the controller has

taken steps forward, and then trip the clutch and stop the actuating mechanism.

80. In a type setting and justifying machine, the combination of a space-ejecting mechanism with a counter-shaft geared to the main driving-shaft to actuate the same, a clutch controlling the counter-shaft, a detent mechanism consisting of a notched disk controlling the clutch, and a ratchet-wheel connected to the disk, and operating to move its notch forward when the ratchet-wheel is operated, a pawl in operative connection with the ratchet-wheel and with the space-key of the setter, whereby the pawl will operate its ratchet one step forward for each space set, the notched disk being adapted to move backward when the counter-shaft is started until its notch is brought back to the place from which it started, when its detent will operate the clutch and stop the counter-shaft.

81. In a type setting and justifying machine, a space-inserting mechanism and two controlling devices for the same, one of which is connected to the said mechanism to control the number of its operations to justify a line, while the other is disconnected from it and is being set to control the number of operations of said mechanism during the justification of the next line.

82. In a type setting and justifying machine, two devices for controlling the number of operations of the space-inserting mechanism so related to each other that one is connected with the space-key whereby it may be given a setting by the depressions of the space-key when the other of said devices is connected with the space-inserting mechanism, whereby it may control the number of operations of said mechanism, and mechanism set in operation at the completion of the setting of each line, for shifting the connections of said controlling devices.

83. In a type setting and justifying machine, a pair of detent-wheels, suitably mounted and each provided with a face upon which a detent may rest, when out of engagement, a slot in the face of each of said detent-wheels to permit the detent to enter into engagement, a ratchet and pawl for each detent-wheel to operate said ratchet-wheels, the ratchet-wheels being adjustable into and out of engagement with their respective pawls in the operation of the justifier, means controlled by the space-ejector mechanism of the setter, to rotate one of said detent-wheels, and its ratchet-wheel from a zero position, one unit of rotation with the ejection of each space introduced in the composed line until such line is complete, and then disengaging said ratchet-wheel from its pawl, and bringing the other ratchet-wheel into engagement with its pawl and operating it in like manner during the composition of the next line.

84. In a type-justifying machine a line-

- measuring device, consisting of the combination of means to support the composed line with the rear end thereof abutting against an abutment, with an adjustable measuring-head, means for holding said head in contact with the other end of said line, means controlled by the movement of said measuring-head to set a gage-block in a fixed position, and means to remove the measuring-head out of the path of the line.
85. In a type-justifying machine, a line-measuring device which consists of the combination of means supporting the composed line with one end thereof abutting against a fixed dog, with an adjustable measuring-head, means to advance said head in contact with the other end of said line and exert a desired pressure thereon, means controlled by the movement of said measuring-head to set a gage-block in a fixed position, and means to remove the measuring-head out of the path of the line.
86. In a type-justifying machine, a line-measuring device which consists in the combination of a line-support having a fixed detent, means to advance a composed line upon said support with one end of the line abutting against the said detent, a measuring-head suitably mounted to move horizontally and vertically, means to move the measuring-head into the path of the line on its support, and to hold it against the disengaged end of the composed line, a gage-block connected to and moved by the measuring-head, means to lock the gage-block in the position in which it has been set by the measuring-head at its contact with the line, and means to remove the measuring-head out of the path of the line.
87. In a type-justifying machine, a line-measuring device which consists of a combination of a measuring-head having a vertical and horizontal motion, a supporting-bar for said measuring-head, adapted to be extended or shortened to give primary position to said measuring-head to correspond with the length of line desired to be set.
88. In a type-justifying mechanism, a combination of means to measure the length of a composed line presented for justification, and to fix a gage-block in a corresponding position, with a space-ejector mechanism, having an adjustable space-ejector, an inclined plate suitably mounted to move from a zero position into contact with said gage-block, and means controlled by the movement of said plate to adjust the space-ejector into a position corresponding to the position of said plate, substantially as described.
89. In a type-justifying machine, the combination of a series of type-magazines having zones of equal width, with a series of ejector-blades mounted in suitable guides, one opposite each space-magazine, and adapted to eject spaces from said magazines, a series of knife-edge guides mounted between said ejector-blades, all of said guides being beveled on the same side on the end near the ejector with a space-ejector carriage traveling in ways past the magazines and having a pivoted space-ejector mounted thereon, which is provided with a knife-edge guide upon its lower end, the bevel of the end of which is on the opposite side from that of the other knife-edge guides, and means for giving to the space-ejector carriage a step-by-step motion upon its way as spaces are ejected.
90. In a justifying-machine, a series of space-magazines arranged side by side and a suitable distance apart, a space-ejector adapted to travel from the zone of one magazine to that of another, with a series of knife-edge guides located at the limits of zone boundaries, and a knife-edge mounted on the ejector and adapted to engage the knife-edge guides to cause the ejector to pass from the zone of one magazine to that of another.
91. In a justifying-machine, a series of space-magazines arranged side by side and a suitable distance apart, a space-ejector adapted to travel from the zone of one magazine to that of another, with a series of knife-edge guides located at the limits of zone boundaries, each knife-edge guide being beveled on the same end and same side to a sharp edge, and a knife-edge on the ejector beveled on the end adapted to engage the knife-edge guides, and on the opposite side from them, substantially as described.
92. A measuring and dividing instrument adapted to measure the distance between two fixed points and to divide that distance into equal parts, which consists of a triangular plate and a scale, the angle of said plate being such that when placed between said two fixed points, a fixed scale coöperating with said triangular plate will indicate the degree to which the said plate has moved from its zero position to contact with said point, substantially as described.
93. An instrument for justifying type, which consists of a plate or its equivalent, cut at an angle with reference to a base-line, the obliquity of said angle being calculated with reference to the number of spaces required for a given line, and also calculated with reference to a fixed scale and a scale, the instrument in its operation being adapted to indicate on said scale the width of the space required to justify said given line, substantially as described.
94. In a justifying-machine, the combination with means for measuring the length of a composed line and establishing two fixed points, bearing a relation to the difference between the set line and standard, of an instrument of triangular form laid off in accordance with a scale, means for introducing said instrument between said two fixed points

until it makes contact with them, a second instrument also laid off to the same scale as the triangular instrument, means to indicate on the second instrument the movement of the triangular instrument in the course of its introduction between the two fixed points, the angle of the triangular instrument and the degree of the scale to which both instruments are laid off being so arranged that as the number of equal parts into which it is desired to divide the distance between said fixed points is to the tangent of obliquity of the triangle of the instrument, so is the movement of the triangular instrument from a zero position to the point at which it makes contact with said fixed point to the degree of the scale to which the second instrument is laid off, whereby the extent of movement of the triangular instrument will indicate on the second instrument the unit of measurement, according to the degree of the scale, which will exactly divide into a given number of equal parts the distance between said fixed points.

95. An instrument adapted to divide into a given number of equal parts the distance between two given points of variable distance, which consists of a plate of triangular form in combination with a fixed scale, the obliquity of the angle of said plate, and the position of said scale being such that when said plate is introduced between said given points to contact with them, the position of the inclined plate will indicate a point on the scale which will correspond with a unit of measurement, which will exactly divide into equal parts the distance between said points.

96. In a type-justifying machine, the combination of a series of space-reservoirs suitably mounted on a space-ejector table, with the base of the columns of spaces sustained in the same plane on the surface of the table, a series of ejector-blades of different dimensions according to the width of the spaces to be ejected from the several magazines, suitable ways in which the ejector-blades are adapted to reciprocate, a space-ejector carriage, suitably mounted to move at right angles to the course of the ejector-blade, with means to control the position of said ejector-carriage according to the character of the spaces required to justify a composed line, a space-ejector suitably mounted on said space-ejector carriage, adapted to move at right angles to the movement of said carriage, and parallel to the movement of the space-ejector blades, a pivoted ejector-arm, secured to said space-ejector and provided with an ejector-head and a knife-edged guide, with means to maintain said arm in a normal position, a series of knife-edged guides which are suitably mounted on the ejector-table between the ejector-blades and adapted to coöperate with the knife-edged guide of the pivoted ejector-head, and means to impart to the

ejector-carriage a step-by-step motion upon its ways, as and for the purpose specified.

97. In a justifying-machine the combination of a space-ejecting mechanism, means for moving the space-ejector between successive actions of ejecting spaces, and means for locking the space-ejector after each movement while ejecting spaces. 70

98. In a justifying-machine the combination of a space-ejector mounted upon suitable ways, and adapted to be moved thereon, with means for giving to said space-ejector a step-by-step motion upon its ways, and means for locking the space-ejector upon its ways after each step, and during the operation of ejecting spaces. 75

99. In a justifying-machine the combination of a space-ejector mounted upon suitable ways, and adapted to travel thereon, a single means for moving the space-ejector from its primary position and giving it a setting upon its ways, said means being capable of independent movement to return to its primary position after setting the space-ejector, and means for restoring the space-ejector to its primary position independent of the setting means. 85

100. In a justifying-machine the combination of a space-ejector mounted upon suitable ways and adapted to travel thereon, means for giving to the space-ejector a setting upon its ways, said means being capable of independent movement to return to its primary position after setting the space-ejector, means for locking the ejector upon its ways 100 while its setting device is recovering its position, and means for restoring the space-ejector to its primary position independent of the setting means. 90

101. In a justifying-machine the combination of a space-ejector mounted upon ways, means for giving to said ejector a setting upon its ways, means for locking the ejector to its setting means while setting, and unlocking said means when the ejector is set, substantially as described. 105

102. In a type-justifying mechanism, the combination of a space-magazine containing different sizes of spaces, an ejector for ejecting spaces from the magazine, means for adjusting the ejector opposite the proper channel in the magazine, said means being controlled by the shortage of the line to be justified and the number of intervals therein and means for progressively moving said ejector, in a number of steps equal to the number of word-spaces in the line, from the position in which it is primarily set, to cause the ejector to determine the proper combination of spaces to justify the line. 115

103. In a type-justifying mechanism, the combination with a space-magazine containing different sizes of spaces, of an ejector movable laterally, a series of gages movable with said ejector, a stop coöoperating with the 120

gages to locate the ejector opposite the magazine-channel containing spaces for the line under justification and means for progressively moving said ejector, in a number of 5 steps equal to the number of word-spaces in the line, from the position in which it is so located to cause it to determine the proper combination of spaces to justify the line.

104. In a type-justifying mechanism, the 10 combination with a space-magazine having a number of channels for different sizes of spaces, of an ejector movable laterally to the channels, gages for locating the ejector opposite the channel containing one of the sizes of 15 spaces for justification, and means for progressively moving said ejector in a number of steps equal to the number of word-spaces in the line, from the position in which it is so set, to cause it to determine the proper combination of spaces to justify the line.

105. In a type-justifying machine, in combination with a series of space-channels, a space-determining device adapted to be set in operative relation therewith, a space- 25 pusher blade, a reciprocating arm operatively connected thereto, adapted to engage said blade at any of its positions and means for progressively moving said space-determining device, in a number of steps equal to 30 the number of word-spaces in the line, from the position in which it is so set, to cause it to determine the proper combination of spaces to justify the line.

106. In a justifying mechanism, the combination with a series of space-magazines, each adapted to contain different-size spaces, of means to determine the difference between a set line and standard and to divide said difference by the number of spaces in the said 35 line, a space-selecting mechanism controlled by said determining means to set said space-selecting mechanism in proper relation to said magazines, means for giving said space-selecting mechanism a step-by-step movement, whereby it will select a number of a certain-sized space and then change its position and begin to select spaces of a different size and continue selecting said second-size spaces until the whole number have been selected, a proper combination of two sizes of spaces being selected to justify the line, said selecting mechanism making a number of steps equal to the number of spaces to be selected.

107. In a justifying mechanism the combination with a series of space-magazines each adapted to contain different-size spaces, of means to determine the difference between a set line and standard and to divide said difference by the number of spaces in the said 45 line, a space-selecting mechanism controlled by said determining means to set said space-selecting mechanism in proper relation to said magazines, means for giving said space-selecting mechanism a step-by-step move-

ment whereby said selecting mechanism will select a number of a certain-sized space and may then change its position and begin to select spaces of a different size and continue selecting said second-size spaces until the whole 70 number have been selected, a proper combination of two sizes of spaces being selected to justify the line, said space-selecting mechanism making a number of steps equal to the number of spaces to be selected, the total distance traveled during the step-by-step movement for the justification of a single line being always the same without regard to the 75 number of spaces selected.

108. In a machine for justifying a composed line of type, the combination with a series of space-magazines, said magazines containing spaces of different thicknesses, each size of space different from its adjacent spaces by an approximately equal amount, the 80 magazines being located in regular order of size of spaces, of a space-selecting mechanism, means for determining the difference between a set line and standard and to divide said difference by the number of spaces in 85 said line, to set said space-selecting mechanism in relation to said space-channels, means for imparting to said selecting mechanism a step-by-step motion, and moving it one step for each operation of selecting a space, the 90 number of steps being equal to the number of spaces to be inserted in the line.

109. In a machine for justifying a composed line of type, the combination of a series of space-magazines, said magazines containing 100 spaces of different thicknesses, each size of space different from its adjacent spaces by an approximately equal amount, the magazines being located in regular order of size of spaces, of a space-selecting mechanism, means 105 for determining the difference between a set line and standard and to divide said difference by the number of spaces in said line, means for setting the space-selecting mechanism in relation to one of the space-magazines, means for imparting to the selecting mechanism a step-by-step motion and moving it one step for each operation of selecting a space, the number of steps being equal to the 110 number of spaces to be inserted in the line, and the total distance traveled during the step-by-step motion for the justification of a single line being always the same without regard for the number of spaces selected.

110. In a justifying mechanism, the combination of a series of magazines containing spaces of different thicknesses, a selecting mechanism mounted to travel past the magazines and select spaces from said magazines of a suitable width to justify a line under operation, the total path of the selector being divided into a number of zones of equal width and equal in number to the number of magazines.

111. In a justifying mechanism, a space-

determining mechanism governing the size of space for justification, means for varying said space-determining mechanism according to the shortage of the line to be justified divided by the number of spaces in said line and means for thereafter giving periodic variations to the space-determining mechanism, the amount of which variations is proportionate to the reciprocal of the number of spaces to be justified.

112. In a justifying mechanism in combination, means for holding a line to be justified, mechanism for measuring the same to determine the shortage and divide said shortage by the number of spaces in said line, a space-determining mechanism for governing the size of space to justify the line, means for varying said space-determining mechanism according to the measuring mechanism, and means for alternately placing the space thus determined and for giving a periodic variation to the space-determining mechanism, the amount of which variation is proportionate to the reciprocal of the number of spaces to be justified.

113. In a justifying mechanism in combination, means for determining the shortage of a line to be justified and divide said shortage by the number of spaces in said line, a space-determining mechanism for governing the size of space to justify the line, means connecting the shortage determining and dividing mechanism and the space-determining mechanism whereby the latter is varied according to the former, and means for alternately delivering the result of the space-determining mechanism and giving a periodic variation to the space-determining mechanism, the amount of which variation is proportionate to the reciprocal of the number of spaces to be justified.

114. In a justifying mechanism in combination, means for holding a line of type to be justified, mechanism for measuring the same to determine the shortage and divide said shortage by the number of spaces in said line,

a space-determining mechanism for governing the size of space to be placed in the line, means for varying the space-determining mechanism according to the measuring mechanism, means for delivering the determined size of space, means for giving periodic variations during the justification to the space-determining mechanism, the amount of which variations is proportionate to the reciprocal of the number of spaces to be justified in the line.

115. In a justifying mechanism, means for measuring a line to determine the shortage and divide said shortage by the number of spaces in said line, a series of spaces graded in respect to thickness adapted to be placed in such line and justify it, a connection between the measuring mechanism and such spaces, and means for varying such connection periodically during the justification, the amount of the variation being proportioned to the reciprocal of the number of spaces in the line to be justified and being adapted to accumulate to change the space determined upon.

116. In a justifying mechanism, a space-determining mechanism for governing the size of space for justification, means for varying said space-determining mechanism according to the number of spaces in the line and the measurement of the line whereby for a given number of spaces the variation is dependent upon the line shortage, means for thereafter giving periodic variations to the space-determining mechanism, the amount of which periodic variations is proportionate to the reciprocal of the number of spaces to be justified.

Signed by me at New York city, county and State of New York, this 29th day of March, 1900.
